ELEVATOR SYSTEM

Harold Waters, Hohokus, N. J., and William Frank Glaser, Eastchester, N. Y., assignors to Otis Elevator Company, New York, N. Y., a corporation of New Jersey

Application November 9, 1934, Serial No. 752,241

81 Claims. (Cl. 187—29)

The invention relates to elevator systems.

The invention is directed to the automatic control of certain operations of an elevator car or cars. The form of elevator control to which the invention especially relates is one in which the starting of the elevator car after each stop is under the control of an attendant in the car, while the stopping of the car is automatic, stops to discharge passengers being made in response to push buttons within the elevator car operated by the attendant as directed by the passengers, and stops to take on passengers being made in response to push buttons at the landings operated by the intending passengers themselves. Such control as applied to a plurality of elevator cars involves controlling the stopping of all cars by the push buttons at the landings, these buttons being common to the cars. Features of the invention reside in special adaptations of this form of control and the mechanisms involved, and in addition certain of the features are applicable to other forms of control.

The principal object of the invention is to provide a maximum amount of service with minimum car travel.

Elevator systems to which the invention is particularly applicable and in connection with which it will be described are very complex. As an aid to an understanding of the principles and features of the invention, operation of the systems chosen to illustrate these principles and features will first be outlined.

The cars are automatically picked out for travel above a predetermined landing. This landing may be the lower terminal landing or some intermediate landing. Each car is picked out for such travel whenever it has a car call registered for a landing above. As regards hall calls, a car is picked out for such travel when a hall call is registered for a landing above. Another car is picked out for such travel to help out the car already picked out whenever it becomes necessary to do so to provide the kind of service considered desirable for the particular installation.

Each car is started by manual operation on the part of the car attendant. When a car, in its travel in a certain direction, nears a landing for which a car button has been operated or for which a hall button for that direction has been operated, it slows down in response to that button and is brought to a stop at that landing.

Once a car is started in the up direction, it continues to travel in that direction after each of its stops until, in the event that it is the leading car, it answers the highest car call or down hall call.

When such highest call is answered, the car moves away from the landing for which such call was registered in the down direction when the attendant starts it. In the case of a following car, once it is started in the up direction, it continues to travel in the up direction after each of its stops so long as it is necessary to do so to provide service which is considered essential for the particular installation.

The system may be arranged so that each car, once started in the up direction, is caused to travel at least to a certain intermediate landing before it can be reversed.

In one specific embodiment chosen for purposes of illustration, a car is picked out to travel above the lower terminal whenever the car button in that car is pressed for a landing above and whenever an operated hall button for a landing above remains to be responded to.

Each car, once started in the up direction, continues its travel in the up direction after each stop until the highest operated car button in that car is responded to. Also, a car, once started in the up direction, continues its travel in the up direction after each stop so long as an operated hall button at a landing above the car remains to be responded to.

If the highest call registered be a down call, the leading car, as it nears the landing for which the call is registered, slows down in response to that call and is brought to a stop at that landing. When the leading car slows down preparatory to stopping at a landing in response to a down hall button at that landing or to the car button for that landing, under conditions where no push buttons are operated requiring further upward travel, it starts away from that landing in the down direction, after the stop has been made, upon the manual starting operation by the car attendant.

A following car continues its upward travel after each stop so long as a call is registered above the car but, if no car call is registered for that car for a landing above that car and no hall call is registered for a landing between that car and the leading car, at the time the leading car responds to the highest hall call which is registered, the following car slows down and stops at the next possible landing and starts in the down direction from that landing upon the manual starting operation of the car attendant.

The system may be arranged so that each car is caused to travel in the up direction at least to a predetermined intermediate landing. If, at the time it nears this landing, no calls are registered

which require further travel of the car above the predetermined landing, it slows down and stops at that landing and, upon the car being started, it leaves the landing in the down direction. However, if calls are registered which require travel of that car above the predetermined landing, it continues its travel past the predetermined landing without slowing down and stopping thereat unless the car button for that landing or up hall button at that landing is pressed.

The service rendered may be altered so as to cause each car, once started in the up direction, to continue to travel in that direction after each stop until the upper terminal floor is reached, 15 regardless of whether a push button for the upper terminal is pressed or not.

In another specific embodiment chosen for purposes of illustration, each car is picked out for travel above a predetermined landing when the 20 car button in that car for a landing above is operated. If no other car has been picked out for travel above the predetermined landing, a car is picked out to do so when a hall call is registered for a landing above. If a car has been picked out 25 for such travel, another car is also picked out for such travel when a hall button for a landing below the car already picked and requiring travel above the predetermined landing is operated. Once the car already picked out has answered the highest 30 call, another car is picked out for such travel when a hall button for any landing above the predetermined landing is operated.

A following car, once started in the up direction, continues its upward travel after each stop 35 only so long as a car call for a landing above remains to be responded to or an up or a down hall call for a landing between the car and the up car next above remains to be responded to. When the car answers its highest car call, it starts away 40 from the landing for which the call is registered in the down direction, provided no hall call between it and the up car next above is to be responded to. If one or more hall calls for landings between this car and the up car next above are 45 to be responded to and if the highest of these calls is a down call, the car, as it nears the landing for which such down call is registered, slows down in response to that call and is brought to a stop at that landing. After making such stop, it starts 50 away from that landing in the down direction upon the manual starting operation by the car attendant.

In another specific embodiment chosen for purposes of illustration, each car as before is picked 55 out for travel above a predetermined landing when the car button in that car for a landing above is operated. If no car has been picked out for travel above the predetermined landing, a car is picked out to do so when a hall call is registered for a landing above. If a car has already 60 been picked out for such travel, another car is also picked out for such travel when an up hall button is operated for any landing below the car already picked out and above said predetermined landing. However, another car is not picked out 65 for such travel under such conditions if the call which is registered is a down hall call. Once the only up car already picked out answers its highest call, either car call or down hall call, another car 70 is picked out for such travel when an up hall button is operated for a landing above the predetermined landing or when a down hall button is operated for a landing above the landing for which such highest call was registered.

75 An up travelling car cannot respond to a down

hall call unless it is the leading car. The leading car responds to a down hall call only in case no calls are registered requiring further travel of that car in the up direction. The leading car is started from a landing in the down direction when the slow down at that landing was in response to the down hall button for that landing or to the car button for that landing under conditions where no calls were registered requiring further travel of the car in the up direction.

An up following car continues its upward travel only so long as a car call for a landing above is to be responded to or an up hall call for a landing between the car and the up car next above remains to be responded to. When, upon 15 answering its highest car call, no such up hall call exists, the car is started away from the landing for which the car call was registered in the down direction upon the starting of the car by the car attendant.

In still another embodiment chosen for purposes of illustration, each car as before is picked out for travel above a predetermined landing when a car button in that car for a landing above is operated. However, as regards hall calls, no 20 car is picked out for travel above this landing when another car has already been picked out for such travel unless a hall call is registered which cannot be answered by a car already picked out during its travel above the predetermined landing in both directions. A car may also be 25 picked out for travel above the predetermined landing when another car has already been picked out for such travel when the unanswered hall calls for landings above the predetermined landing reach a predetermined number. When 30 two or more cars have been picked out for travel above the predetermined landing to help out each other, each following car continues its upward travel so long as unanswered calls exist above it.

Among the features of the invention is the manner in which the cars are picked out for travel above a predetermined landing.

Also, a feature of the invention is to automatically reverse the direction of travel of a car when it answers a call under conditions where no other calls are registered which require further travel of the car in the same direction.

Another feature resides in causing a car, once started in a certain direction, to continue to travel in that direction after each stop, at least until a predetermined intermediate floor is reached.

Still another feature is to cause the car to run past such predetermined intermediate floor without stopping when an unanswered call exists for a floor beyond, unless a stop is required at such floor to discharge passengers or to take on a passenger desiring to be carried in the direction in which the car is travelling.

There are several features of control with respect to a car which is not the leading one. These include:

a. Causing a following car to be slowed down, stopped and reversed at the next floor at which a normal stop can be made when the car ahead answers the farthest hall call, provided no hall call exists between the two cars or no car button is pressed in the following car requiring travel beyond such floor.

b. Causing a following car to continue to travel in a certain direction only so long as a car call is registered in it requiring further travel in that direction or a hall call exists between it and the car next ahead travelling in the same direction.

c. Causing a following car to continue to travel in a certain direction only so long as a car call is registered in it requiring further travel in that direction or a hall call exists ahead of it which 5 cannot be answered by a car ahead, regardless of the direction of travel of such car ahead.

d. Causing a following car to travel beyond a predetermined intermediate floor only when a car call exists therefor for a floor beyond, when 10 a hall call exists, for or beyond that floor and requiring travel beyond the floor, which is behind a car ahead of the following car, regardless of the direction of travel of such car ahead, or when the unanswered hall calls for floors beyond 15 reach a predetermined number.

A further feature of the invention involves causing any car selected to run beyond a predetermined intermediate floor to continue to travel to the terminal before reversing.

20 A further feature resides in advising the car attendant by signal as to the direction in which his car is set to travel.

Another feature resides in advising the car attendant by signal upon the arrival of his car at 25 the predetermined intermediate floor whether or not his car is selected to travel beyond that floor.

Another feature is to cause the hall lantern which is lighted at any floor at which a car is to be stopped to be in accordance with the direction in which the car is to leave the floor, regardless of its direction of approach, and to cause the period during which the lantern is lighted to be of a maximum duration without false or duplicate indications.

35 There are many other features and advantages of the system. These will be set forth in the following description and appended claims.

In the drawings:

Figure 1 is a simplified schematic representation 40 of an elevator installation in accordance with the invention;

Figure 2 is a schematic representation of the selector machine used in the control system;

Figure 3 is a detail in side elevation of the 45 selector switches and operating mechanism therefor;

Figure 4 is another detail of the same in front elevation, Figure 3 being taken along the line 3-3 of Figure 4;

50 Figure 5 is a fragmental detail of one of the selector switches and its operating cams as viewed from above, this view being taken along the line 5-5 of Figure 3;

Figure 6 illustrates the settings of the operating cams for the selector switches, these views being taken along the lines A-A, B-B, C-C, 55 D-D, E-E, and F-F of Figure 4;

Figure 7 is a detail in side elevation illustrating the advancer mechanism for the brushes and 60 pawls on the selector machine carriage, the counterbalance therefor, and the scale for setting the selector switches;

Figure 8 is a detail of the same in front elevation;

65 Figure 9 is a detail in side elevation of mechanism for retracting the pawls and a control switch operated thereby for the advancer mechanism;

70 Figure 10 is a detail of the same in front elevation;

for engaging the stationary contacts and the cam for operating the floor brush switch;

Figure 12 is a detail in front elevation of the stopping, reset, hall light, and automatic reversal brushes, and the operating cam shown in 5 Figure 11;

Figure 13 is a side view of the frame which carries the stopping brushes, illustrating the arrangement for controlling the manner in which the stopping brushes engage their cooperating 10 stationary contacts;

Figure 14 is a side view taken along the line 14-14 of Figure 12, showing one of the stopping brushes and also showing the manner in which it cooperates with a stationary contact;

Figure 15 is a side view taken along the line 15-15 of Figure 12, showing a reset brush in engagement with a stationary contact;

Figure 16 is a detail in front elevation of the remaining brushes shown in Figure 11;

Figure 17 is a view in side elevation taken along the line 17-17 of Figure 16, showing the details of the brush for controlling the point at which automatic door opening takes place and also showing the manner in which this brush 15 cooperates with a stationary contact;

Figure 18 is a top view, with parts broken away, showing the details of a floor brush switch;

Figure 19 is a view in front elevation showing the arrangement of the floor bars for several 30 floors;

Figure 20 is a schematic representation of the levelling mechanism;

Figure 21 is a detail in side elevation of a switch unit of the levelling mechanism;

Figure 22 is a top view of the same;

Figure 23 is a diagrammatic representation of the control panel showing the relationship of the coils and contacts of the various switches mounted thereon;

Figures 24a, b and c, taken together, constitute a simplified diagram of the power and control circuits for one elevator;

Figure 25 is a simplified diagram of the slow down and signal circuits for a second elevator, 45 similar circuits for the first elevator being contained in Figure 24b;

Figure 26 is a simplified diagram of the circuits for the car call and car position indicators;

Figure 27 is a simplified diagram of a modified form of control showing only enough of the circuits for two elevators to illustrate the manner in which the circuits differ from the circuits of Figures 24b and 25 and to illustrate the principles involved;

Figure 28 is a simplified diagram of another modified form of control showing only enough of the circuits for two elevators to illustrate the manner in which the circuits differ from the circuits of Figure 27 and to illustrate the principles involved; and

Figure 29 is a simplified diagram of still another modified form of control showing only enough of the circuits for two elevators to illustrate the manner in which the circuits differ from the circuits of Figures 24b and 25 and to illustrate the principles involved.

For a general understanding of the invention, reference may be had to Figure 1, wherein various parts of the system, chosen to illustrate the principles of the invention, are indicated by legend. Only one elevator, shown positioned at the first floor, is illustrated, but it is to be understood that the invention is applicable to any number of elevators. The elevator car is raised

and lowered by means of a hoisting motor. This motor drives a traction sheave over which pass the hoisting ropes for the car and counterweight. An electromagnetic brake is provided and is applied to effect the final stopping operation and to hold the car when at rest. It is preferred to employ a direct current hoisting motor and to supply power thereto at a variable voltage by a generator (see Figure 24a) of a motor generator set. The hoisting mechanism for the other elevators is the same.

A plurality of control switches are provided in the car, some of which are shown in Figure 1. These switches include a motor generator starting switch, a non-stop switch, a series of push button switches, an emergency stop switch and a car starting switch. All of these switches are for operation by the car attendant.

The car starting switch comprises a plurality of pairs of contacts designated 112, 581, 597, and 61. Bridging contacts 1230, 1231, and 1232 are mounted on a pivoted segment 1233 for bridging these pairs of stationary contacts. Segment 1233 is operated by means of operating handle 1234. The car starting switch segment may be moved into three different operative positions from neutral. Two of these operative positions are attained by movement of the segment counterclockwise about its pivot. In one of these positions, contact 1231 bridges contacts 581. Further counterclockwise movement causes contact 1230 to bridge contacts 112 and contact 1232 to bridge contacts 597. Contact 1231 is elongated so as to maintain contacts 581 bridged in this second position of the car switch. This second position is the full start position of the switch, to which it must be moved to effect the starting of the car.

The car starting switch also controls the closing and opening of the car gate and hatchway doors. The door and gate closing operation is effected by moving the car starting switch to its first or intermediate position, where contact 1231 bridges contacts 581. The bridging of contacts 581 also causes certain other control operations to take place, which will be discussed later. The preferred operation, however, is to move the starting switch immediately from neutral to full start position. The opening of the car gate and hatchway door is effected by operating handle 1234 to move segment 1233 clockwise about its pivot into position where contact 1232 bridges contact 61. The car cannot start unless the car gate and all the hatchway doors for that car are closed.

The slowing down of the cars preparatory to stopping to effect passenger transfers is initiated in response to the push buttons within the cars and also to push buttons at the landings.

The push buttons within the car are individual to the cars in which they are located. The pressing of a car button causes the car, upon its arrival at the proper slow down distance from the floor corresponding to the button pressed, to be slowed down and thereafter brought to a stop with the car level with the landing. There is only one car button in the car for each floor, these buttons serving both as up and as down buttons. That is, during up travel of the car, each button is effective to cause slow down to be initiated upon the arrival of the car at a certain distance below the landing, and, during down travel, the same button is effective to cause slow down to be initiated upon the arrival 75 of the car at a certain distance above the land-

ing. The car buttons, once pressed, are held in operated condition by means of a magnet 193. This magnet is in the form of an elongated coil which is controlled so as to be deenergized when the direction of car travel is reversed. This releases all operated car buttons. The coil is immediately reenergized as a part of the reversing operation, so that subsequently operated car buttons are again held in operated condition.

The push buttons at the landings are common to all the cars of the group and are capable of causing the slowing down of any one of them. Both an up hall button and a down hall button are provided at each intermediate floor served by the cars of the group. When an up hall button is pressed, the first available up travelling car is caused to slow down and thereafter to be brought to a stop at the floor at which the button is located. Similarly, when a down hall button is pressed, the first available down travelling car is caused to slow down and thereafter to be brought to a stop at the floor at which the button is located. A hall button may be provided also at each of the terminal floors. The hall buttons act through floor relays arranged on the relay panel. Each relay, once operated, is maintained so, permitting the push button which causes the operation to be released. The floor relays illustrated in the control system are of the latching type. Such a relay comprises an operating coil for causing the operation of the relay, latching mechanism for latching the relay in latched condition and a reset coil energizable to release the latching mechanism. The reset coil of an operated floor relay is not energized and therefore the relay is retained in operated condition until circuits are set up to answer the call registered thereby. The reset of the relay avoids causing other cars to be slowed down in answer to that call.

The floors are served in the natural order of floors for each direction of car travel, regardless of the order in which the push buttons for the floors are operated.

The slowing down of the car, preparatory to bringing it to a stop at a floor for which a push button has been pressed, is initiated by a selector machine for that car. The selector machines for the cars of the group also select the car which answers each operated hall button. These selector machines, in cooperation with other control apparatus, act automatically to select the first available car to respond to an operated hall button. This car may not be the car nearest the floor at which the button is located, but it is the car which is in effect the nearest car. The selector machine of the car to be stopped also causes further slow down to take place and finally causes the car to be brought to a stop at the floor landing.

Each selector machine is driven preferably by means of two steel tapes attached to the car. One tape extends from the top of the car to an overhead sheave. The other tape extends from the bottom of the car around a tension sheave and then up to a second overhead sheave. The tapes are wound on the overhead sheaves in a manner similar to the winding of a measuring tape, one being wound oppositely with respect to the other. The shaft upon which the overhead sheaves are mounted drives the selector machine through a chain and sprocket. One tape is unwound as the other is wound up in effecting the driving operation. This silent tape drive is 75

as positive as a sprocket chain and is unaffected by sliding or stretching ropes.

Each selector machine comprises a crosshead which is driven by a screw, which is in turn driven by the chain and sprocket, to move in accordance with movement of the car for which the machine is provided. The crosshead carries a carriage upon which is mounted mechanism for setting up circuits to cause the car to be slowed down and stopped at a floor. Mechanism is also mounted on the carriage for causing slow down to begin at a certain distance from the floor and for causing further slow down at fixed distances from the floor. The carriage is advanced from a neutral position with respect to the crosshead in starting the car and is brought to a stop after a certain amount of movement by engaging a stop. Thereafter the carriage moves with the crosshead. When circuits are set up to cause the car to be slowed down, the carriage is brought to a stop. This may occur before the carriage is fully advanced on a short run. In any case, the crosshead, which moves with the car, thereafter takes up the advance of the carriage so that when the car comes to a stop, the carriage is again in neutral. This relative action of the carriage and crosshead is utilized to control the slow down of the car.

Signals are arranged at the floors for advising intending passengers of the approach to the floor of a car which is to be stopped thereat to effect a transfer of passengers. These signals are preferably in the form of lamps usually known as hall lanterns. Each car is provided with both an up hall lantern and a down hall lantern at each intermediate floor, an up hall lantern at the lower terminal and a down hall lantern at the upper terminal. The up hall lanterns at intermediate floors are lighted during upward travel of their respective cars and the down hall lanterns at intermediate floors are lighted during downward travel of their respective cars. When circuits are set up incident to answering the highest call to cause the direction of an up travelling car to be reversed as the car comes to a stop, the down hall lantern for that car at the floor at which the stop is to be made is lighted instead of the up hall lantern at that floor.

A maximum duration of lighting of the hall lantern is provided. The hall lantern is lighted as soon as circuits are set up by the selector machine to cause the car to be slowed down and stopped at a floor. In case such circuits are set up before the carriage becomes fully advanced, the hall lantern for that car for the floor for which the circuits have been set up is lighted before the car starts. When full advance of the carriage has been obtained and the car has started, the proper hall lantern is lighted immediately circuits are set up to cause slow down and stopping of the car to take place. The hall lantern is maintained lighted during the slow down and stopping period and while the car is stopped at a floor. It is not extinguished until the car starting switch has been moved to start position to start the car. The circuits for the hall lanterns are controlled by the selector machines.

Mechanism is also provided for each car for causing the car, upon being brought to a stop, to come to an exact landing level in case of an overrun or an underrun. This levelling mechanism may be arranged on the selector machine.

Each car may be provided with a position indicator and car stop indicator. The position indicator indicates the position of the car and the

car stop indicator indicates the calls registered by the pressing of car buttons.

The electromagnetic switches for controlling the operation of each elevator are mounted on the control panel for that elevator.

Many of the mechanisms and elements which go to make a complete elevator system have not been illustrated in the drawings. Among these are the safety devices, including the safety governor, safety brake, buffers, limit switches, and various auxiliary switches included in the elevator car for operation by the car attendant. The system will be described in connection with the wiring diagrams as applied to a ten-floor installation. It is to be understood, however, that the system may be arranged for an installation of any number of floors.

Reference may now be had to Figure 2, which illustrates schematically a selector machine. This figure is principally used to give a more comprehensive understanding of the machine and its operation. It is not intended to show the details of construction, the details of the various parts of the selector machine being illustrated in Figures 3 to 22 inclusive. In the drawings showing details of construction, certain parts, not involved in the operation of the portion of the mechanism illustrated in a particular figure of drawing, are not shown in order that the construction and operation of such portion of the mechanism may be readily understood.

Referring first to Figure 2, the selector machine comprises a frame formed by a base plate 1250, four standards 1251, and a top plate 1252 supported by these standards. The standards are secured in sockets formed in bosses both on the base plate and the top plate. The base plate 1250 is formed with a centrally disposed pedestal 1253, which, together with a boss formed on the base plate at one side thereof, provides bearings for the selector machine operating shaft 1254. The driving sprocket 1255 for the selector machine is secured to the outer end of the shaft. This shaft drives a vertical screw 1256 through the intermediary of bevel gears 1257 and 1258. The vertical screw is supported at its lower end by a ball thrust bearing and at its upper end extends into a bearing in a boss depending from top plate 1252.

The vertical screw 1256 drives a crosshead 1260. This crosshead comprises a split nut 1261 and guides 1262 and 1263 connected to the nut by flanges and cooperating with vertically extending guide bars 1264 and 1265 respectively to prevent rotative movement of the crosshead and to guide it as it is driven upwardly and downwardly by rotative movement of screw 1256. The guide bars 1264 and 1265 extend from the base plate to the top plate and are secured to bosses formed on these plates.

The crosshead carries a plurality of switches 102, 51, 121, 131, 154, and 162. These switches are principally for controlling the retardation and stopping of the car. They also serve to determine the amount of acceleration on short runs. These switches are arranged within a box like frame 1266. The frame is formed with lugs 1267 (Figure 8) provided with apertures through which screws 1268 (Figure 2) extend into threaded bosses on the guide portions 1262 and 1263 of the crosshead, securing the frame to the crosshead. Each of the switches is of the same construction, the construction of one of them being shown in Figures 3 and 5.

Referring to these figures, a switch panel 1270

is mounted on a bracket 1271 secured to the frame 1266. A bearing bracket 1272 is secured to the face of the panel. This bracket comprises a pair of apertured lugs 1273 connected by an elongated web 1274. An elongated pivot pin 1275 extends between the lugs 1273 and is supported in the apertures. This pin is secured in place as by screws 1276. The contact levers 1277 of the switches are mounted in side by side relation on pin 1275 between the lugs. These contact levers carry spring contacts 1278 for cooperating with stationary contacts 1279 secured to the switch panel.

Each of these switches is of the same construction. The stationary contact of each switch comprises a contact stud provided with a tungsten contacting tip 1280 on its contacting end. The other end of the stud, which extends through the panel, is threaded and is provided with binding nuts for securing the stud to the panel and connecting the contact in the system. The movable contact for engaging the stationary contact is likewise tungsten tipped, this tip being carried by the end of the contacting spring 1278. The contacting spring is of leaf spring construction, preferably of a bronze alloy. It extends downwardly into a channel formed on the contact lever by lugs 1282, at which point it is secured to the lever as by a screw. This screw also secures a clip from which a flexible conductor 1283 extends to a binding post 1284. At the upper end of the contact lever, the spring extends through a slot which serves to protect the spring from being bent out of shape.

The contact lever is of insulating material and is pivoted on pin 1275 at a point below the lugs 1282. The contact lever is biased into position where the movable contact is disengaged from the stationary contact as by a spring 1286 extending from a locating slot in the panel to the contact lever at a point between the lugs 1282 where the securing screw for the movable contact serves as a spring seat. Below its pivot point the contact lever is formed with a depending stop arm 1287 arranged to cooperate with web 1274 to form a stop to limit the amount of movement of the contact lever by its biasing spring 1286. Above its pivot point the contact lever is formed with outwardly extending lugs 1290 provided with apertures through which extends a pivot pin for an operating roller 1291. This roller is positioned in the path of movement of cams 1292 and 1293 to move the contact lever about its pivot against the force of spring 1286 into contact engaging position.

The operating cams for the switches are secured to an operating shaft 1294 rotatively supported in bosses 1295 formed on the frame 1266. These cams are arranged side by side on shaft 1294. Each cam is arc-shaped, the camming surface being the arc of a circle with the center coinciding with the center of the operating shaft. The cam is clamped to the shaft by means of a clamping plate 1297 secured as by screws to a counterpart 1296 formed integral with the cam. The cams are positioned on the shaft so that the two cams for operating each switch straddle the operating roller 1291 for that switch.

With the car stopped at a floor the cams assume a position in which their leading edges are equally spaced from the rollers which they operate, so that the same amount of rotative movement is required in one direction as in the other to close each switch. The cams are set so that their leading edges are increasingly farther from

the rollers of the switches which they operate, in the order of switches 102, 57, 121, 131, 154, and 162. In other words, upon rotative movement of the operating shaft in either direction, the switches are closed in the order of switches 102, 57, 121, 131, 154, and 162. The relative positions of the cams of the various switches with respect to the rollers are shown in Figure 6, wherein the switches operated by the cams are indicated in parentheses above the respective pairs of cams.

The rotative movement of the cams to close the switches is effected by a split field torque motor 1298 through a train of gears 1300. The motor and gears are mounted on the frame 1266, the motor being positioned over the cams as illustrated in Figure 4.

Reverse rotative movement of shaft 1294 to return the cams to positions permitting the opening of the switches by springs 1286 is effected by movement of the elevator car in moving crosshead 1260. Referring back to Figure 2, in rotating shaft 1294 to effect the closing of the switches, the motor also acts through a gear 1301 and rack 1302 meshing therewith to vertically move a carriage 1303, either up or down, depending upon the direction of rotation of the shaft. This advances the position of stopping pawls 1304 and 1305 with respect to the crosshead 1260. These pawls cooperate with stopping lugs 1306, one for each floor, secured to one of the standards 1251, to bring carriage 1303 to a stop. Thus, the rack 1302 is stopped so that as the car continues to drive crosshead 1260, gear 1301 is rotated by the rack in a direction to move operating cams for the selector switches back to the positions illustrated in Figure 6.

Details of this portion of the mechanism are shown in Figures 7 and 8. The toothed rack 1302 which meshes with gear 1301 is secured to the carriage 1303 as by screws 1299. The carriage is guided in its upward and downward movement by means of guide bars 1307 and 1308. These bars extend into sockets provided in bosses formed on brackets 1310 and 1311. These brackets are secured to frame 1266 by means of screws 1305 extending into threaded bosses provided on extensions 1312 and 1313 of the frame. The carriage is formed with a horizontal extension 1314 which, as will be shown later, provides a support for the crosshead panel for the travelling brushes. Extension 1314 is formed with bosses provided with apertures through which the guide bars 1307 and 1308 extend, thereby forming guides for the carriage.

Upon clockwise rotative movement of gear 1301 as viewed in Figure 7, the rack 1302 and carriage 1303 are moved downwardly on the guide bars. This movement continues so long as operating shaft 1294 is rotated by motor 1298 until the carriage engages stop collar 1315 provided on guide bar 1308. A similar stop collar 1316 is provided on guide bar 1308 above the carriage to limit the amount of upward movement on the bars upon counterclockwise rotative movement of gear 1301 by the motor. This movement of the carriage on its guide bars is relative to frame 1266 and therefore to the crosshead 1260. The motor is controlled to effect this movement of the carriage in the same direction as the crosshead is to be moved. Thus the relative movement between the carriage and the crosshead is one of advancement. In other words, the carriage is advanced by the motor with respect to the crosshead.

The pawls 1304 and 1305 carried by the carriage 1303 are pinned to shafts 1317 and 1318 ro-

tatably supported by the carriage. These shafts extend through apertures provided in flanges 1320 on the carriage and apertures provided in bosses 1321 also formed on the carriage. Compression springs 1322 are arranged between spring seats formed on the pawls and on the carriage to bias the pawls outwardly from the carriage. The pawls are reversed so that pawl 1304 is biased by its spring for clockwise rotative movement about shaft 1317 while pawl 1305 is biased by its spring for counterclockwise rotative movement about shaft 1318. An arm 1323 is secured to each operating shaft 1317 and 1318 on the other side of boss 1321. These arms rotatably support rollers 1324. The pawls are retracted against the force of springs 1322 to clear the stopping lugs by pushing the rollers 1324 outwardly from the carriage 1303.

Referring back to Figure 2, the rollers are moved outwardly to retract the pawls by means of a cam 1330. The cam is carried by the cross-head through the intermediary of bell crank levers 1331 and 1332. An electromagnet 1333 carried by the crosshead is provided for controlling the action of cam 1330. This magnet comprises two coils 577 and 548. The control system is arranged so that the coil 577 is energized to effect the retraction of the pawls whereas, to permit the pawls to be reextended for operating with the stopping lugs, coil 548 is also energized to magnetically neutralize coil 577. Upon the energization of coil 577, the bell crank lever 1331 is pulled upwardly and, through link 1334, bell crank lever 1332 is also pulled upwardly, causing the cam to be extended outwardly to push rollers 1324 away from the carriage. This rotates the shafts 1317 and 1318 in a direction to force the pawls into retracted positions against the force of springs 1322.

In moving outwardly, cam 1330 acts through link 1335 to pull contact lever 1336 clockwise about its pivot to close a switch having three pairs of contacts, one pair 586 of which controls the energization of motor 1298. Thus the motor for advancing the carriage is not energized until the pawls are moved to retracted position.

The details of the mechanism for operating cam 1330 are shown in Figures 9 and 10. The upper bell crank 1331 for operating the cam is pivotally supported by a channel-shaped extension 1340 formed on bracket 1310. It is mounted on a pivot pin 1343 supported by extension 1340 and extending through apertures formed therein. One arm 1341 of the bell crank is connected to cam 1330 by a pivot pin 1342. The other arm 1344 of the bell crank extends substantially horizontally, being formed with two lugs 1345 at its pivot point to straddle extension 1340. At its outer end, arm 1344 adjustably supports a movable core 1346 for magnet 1333. The magnet is supported by bracket 1310, its stationary core being secured in an aperture formed in the bracket. The magnet coils 577 and 548 are held in position on the stationary core by means of the clip 1350 secured to extension 1340 by a screw.

The link 1334 is connected to bell crank 1331 by means of a pivot pin 1351 extending through apertures in the link and a lug formed on arm 1344. The link is similarly connected to arm 1352 of bell crank 1332. This bell crank is pivotally supported by an extension 1353 formed on bracket 1311. The upwardly extending arm 1354 of the bell crank is connected to cam 1330 by pivot pin 1355. The cam is formed with outwardly extending or stepped portions 1356 and

1357 at its upper and lower ends respectively. The purpose of this construction will be explained later. Cam 1330 is biased to its retracted position by arms 1344 and 1352 of the bell cranks, linkage 1334 and movable core 1346. A lug 1358 is formed on arm 1352 for cooperating with adjustable stop 1359 to bring the cam to a stop in its retracted position. The mechanism is illustrated with cam 1330 in extended position in Figures 9 and 10.

The switch operated by the cam is mounted on the panel 1360 secured by screws extending into threaded apertures in bosses 1361 formed on extension 1313 of frame 1266. The switch comprises three pairs of contacts 549, 583 and 586. Each pair of contacts is of the same construction. The stationary contact comprises a contact stud 1364 secured to the panel and having a tungsten-tipped contact point 1365. The movable contact 1366 for engaging the stationary contact is likewise tungsten-tipped. This movable contact is in the form of a leaf spring, preferably of a bronze alloy, which extends downwardly into a channel 1367 formed on the contact lever 1336, at which point it is secured to the lever as by a screw.

All three of the leaf springs are secured to the one contact lever 1336, the channels 1367 being arranged side by side. Slots are provided in the contact lever at the upper end through which the leaf springs extend. These slots serve to protect the springs from being bent out of shape. Connections are taken from the contacts at the contact studs and at the binding nuts for the securing screws for the leaf springs.

The contact lever is of insulating material and is pivotally mounted on shaft 1368 supported by bearing brackets 1370 secured to the panel. At its lower end the contact lever is formed with an arm 1371 to which the link 1335 which connects the lever to cam 1330 is pivotally secured.

The weight of the carriage 1303 and mechanism carried thereby, including the crosshead panel and parts mounted thereon, to be described later, is counterbalanced. Referring to Figures 7 and 8, the counterbalancing mechanism comprises a counterweight 1375 connected by a sprocket chain 1376 to a sprocket 1377 mounted on operating shaft 1294 to be rotated thereby. The chain is secured to the sprocket by a pin passing through the end link of the chain. After extending substantially half way around the sprocket, the chain passes upwardly over a pulley 1378 pivotally mounted on a pin 1380 supported by guide bars 1381 for the counterweight. These guide bars are secured to frame 1266 as by screws, and extend into slots 1382 provided in the counterweight to guide the counterweight in its upward and downward movement. Spacing bars 1383 are provided between the guide bars and frame 1266 to extend the counterweight outwardly a sufficient distance to clear the frame. With this arrangement, upon rotative movement of the torque motor 1298 in a direction to advance the carriage in the upward direction, the chain is unwound from the sprocket, lowering the counterweight. When the torque motor is rotated in the opposite direction to advance the carriage downwardly, the chain is wound onto the sprocket, lifting the counterweight. Thus the counterweight effectively counterbalances the weight of the carriage and parts carried thereby.

Referring back to Figure 2, the operation of

the mechanism so far described is as follows: Upon energization of coil 577, bell cranks 1331 and 1332 are pulled counterclockwise about their pivots. This extends cam 1330, which pushes 5 rollers 1324 outwardly, swinging pawls 1304 and 1305 about their pivots against the force of their biasing springs to retracted positions. Cam 1330, in moving outwardly, acts through link 1335 to swing contact lever 1336 to contact engaging 10 position. The resultant engagement of contacts 586 causes the circuit for motor 1298 to be completed. The motor acts through gearing 1300 to rotate operating shaft 1294. The direction of rotation is determined by the control 15 system, which will be described later.

Assume that the controlling mechanism is set for up travel of the elevator car. Under such conditions, the torque motor rotates shaft 1294 in a counterclockwise direction as viewed in Figure 7. Thus, the leading edges of the cams 1292 engage the operating rollers of selector switches 20 102, 57, 121, 131, 154, and 162 in the order named, to move these switches to closed positions. At the same time, gear 1301 moves rack 25 1302 in the up direction, causing upward movement of the carriage 1303. When the carriage 30 engages stop collar 1316 on guide bar 1308, it is brought to a stop. This prevents further rotational movement of gear 1301, which brings operating motor 1298 to a stop.

When circuits are set up to cause the car to be slowed down and brought to a stop at a floor, coil 548 of magnet 1333 is energized, neutralizing the magnetic action of coil 577. This releases bell 35 cranks 1331 and 1332 and cam 1330 is returned to retracted position. This return movement is effected quickly due to the kick off action of pawl springs 1322. Pawl 1305 is thus extended for cooperation with the stopping lug 1306 for the floor 40 for which the circuits have been set up. The mechanism which causes the setting up of these circuits acts to effect the neutralization of coil 577 and the retraction of cam 1330 at a point where pawl 1305, upon being extended by its biasing spring, is immediately beneath the stopping lug. Only pawl 1305 is effective for cooperation 45 with the stopping lugs during up car travel. Pawl 1304 is effective only during down car travel. Thus, pawl 1305 may be termed the up stopping 50 pawl while pawl 1304 may be termed the down stopping pawl. The return of cam 1330 to retracted position also causes movement of contact lever 1336 about its pivot to open the contacts. This causes the motor 1298 to be deenergized.

55 The small clearance between up pawl 1305 and the stopping lug is taken up by the upward movement of crosshead 1260 as a result of upward movement of the elevator car. The engagement of pawl 1305 with the stopping lug brings the 60 carriage 1303 to a stop. The crosshead, however, continues to be driven upwardly by the elevator car, so that gear 1301 is rotated clockwise as viewed in Figure 7 by rack 1302 as the continued upward movement of the crosshead takes place. 65 This rotates shaft 1294 clockwise, returning cams 1292 to the positions shown in Figure 6, resulting in the opening of selector switches 162, 154, 131, 121, 57, and 102 in sequence in the order named. The opening of these selector switches causes 70 the car to be slowed down and brought to a stop at the floor level, the car being stopped as a result of the opening of switch 102.

Had the controlling mechanism for the elevator car been set for down travel instead of up travel, 75 the torque motor would have been energized by

the closing of switch contacts controlled by magnet 1333 so as to rotate shaft 1294 in a clockwise direction as viewed in Figure 7. Under such conditions, the selector switches are closed by cams 1293 instead of cams 1292. Gear 1301 moves rack 5 1302 in the down direction, causing downward movement of carriage 1303 until it is brought to a stop by engaging stop collar 1315 on bar 1308. When circuits are set up to cause the car to be slowed down and brought to a stop at a floor during 10 downward travel, coil 548 is again energized to neutralize the magnetic action of coil 577. Cam 1330 is thereupon retracted and down stopping pawl 1304 is extended for cooperation with the stopping lug 1306 for the floor for which circuits 15 have been set up. When the engagement of pawl 1304 and the stopping lug occurs, the carriage is brought to a stop but the crosshead continues to be driven downwardly by the elevator car. Thus, gear 1301 is rotated counterclockwise as viewed 20 in Figure 7 by rack 1302 as continued downward movement of the crosshead takes place. This results in the return of cams 1293 to the position shown in Figure 6 and the opening of selector switches 162, 154, 131, 121, 57, and 102 in sequence 25 in the order named. This causes the car to be slowed down and brought to a stop at the floor level.

In the preferred arrangement of control which will be discussed later, the energization of coil 30 577 is effected to cause the energization of torque motor 1298 and this torque motor operates to complete the advancement of carriage 1303 before the starting of the car takes place. The carriage may be moved to full advanced position or it may 35 be brought to a stop before reaching this point. If circuits are not set up to cause the car to be brought to a stop at a floor before the carriage reaches full advanced position, the carriage is brought to a stop upon engagement with one of 40 the stop collars 1315 or 1316 and motor 1298 remains energized until such circuits are made. However, should such circuits be set up before the carriage becomes fully advanced, the torque motor is deenergized and the carriage comes to a 45 stop. The setting up of circuits to cause slow down and stop occurs when a stopping brush on the selector engages an "alive" contact, as will be shown later.

When circuits are set up to cause slow down 50 and stop with only a partial advance of the carriage, the clearance between the pawl and stopping lug is taken up by the starting of the car to move the crosshead an amount necessary to effect this engagement. When full advance of the carriage has been attained, however, the car will be in motion at the time the circuits are set up and the car continues to drive the crosshead after the pawls are released, taking up the clearance. In either case, continued movement of the crosshead causes the return of the cams of shaft 1294 to switch opening positions from the positions to which they have moved, opening all of 60 the selector switches which were closed.

Selector machines of a construction shown on 65 these drawings already built have been geared at a ratio of 120 to 1, i. e., the crosshead moves 1 foot for each 120 feet of car travel. A scale 1385 is secured to rack 1302 and is marked off in feet at this ratio. The scale is graduated the same 70 on each side of the neutral point, the ungraduated space in the middle being for the working clearance of the pawls. In other words, when the car is stopped at a floor during up car travel, the pointer 1386, which is secured to frame 1266, and 75

represents the position of the car, is at the line just below the central space. When the stop is made during down car travel, the pointer is at the line just above the space.

5 Each mark on the scale represents one foot, those marks opposite the numerals 1, 2, 3, 4, and 5 representing 10, 20, 30, 40, and 50 feet respectively. The scale and pointer are for setting the cams to operate at the proper points. Assume that it is desired to set the selector for full advance for a 1000 feet per minute installation. The stop collars 1315 and 1316 are set to permit full advance of the carriage in each direction. The approximate slow down distance in 15 feet for a 1000 feet per minute installation is 33 feet. With the car at the floor level, the carriage is moved in one direction to a point where pointer 1386 is opposite the 33 foot mark on the scale. The cam for switch 162 for the 20 direction in which the carriage has been moved is then set so that its leading edge engages the operating roller for switch 162 so as to just "crack" open the switch. The cam is then tightened on shaft 1294 in this position. The carriage 25 is then moved in the opposite direction to the 33 foot mark where the other cam for switch 162 is set and tightened in a like manner. The other selector switches are set to open at less distances from the floor, the setting being accomplished in a similar manner by moving the carriage to a point on the scale corresponding to the distance from the point at which it is desired to have the switch open. With the carriage moved the required amount in one direction, the leading edge of the cam for that direction for the switch which is being set is moved to position to just "crack" open the switch where it is tightened on the shaft, and the cam for that switch for the other direction of movement is 30 set in the same way.

It is to be noted that the cams 1292 and 1293 for operating these switches are formed in such way, as shown in Figures 3 and 4, that when the cam is moved to a point where it just "cracks" 45 open the switch which it operates, the screws which clamp the cam to the shaft are readily accessible through the opening 1387 in frame 1266. The angular distance between the leading edges of the cams for operating switch 162, which 50 cause the final stopping operation, and the horizontal is due to the working clearance for the pawls 1304 and 1305 and the amount of coast of the car after the opening of the switch.

If the selector were adjusted for an installation in which the car operated at a speed different from 1000 feet per minute, the cams on shaft 1294 would be adjusted differently. For example, for a 1200 feet per minute installation, the cams for operating switch 162 would be set to "crack" 55 open the switch at about 43 feet from the floor, i. e., with the pointer on the 43 foot marks on the scale. The distances at which the other switches would be caused to operate would be changed accordingly. For a 400 feet per minute installation, the cams for operating switch 162 would be set to "crack" open the switch with the car about 6 feet from the floor, i. e., with the pointer 60 on the 6 foot marks on the scale.

Regardless of the slow down distance, the carriage 70 may be operated to full advance position, i. e., 50 feet with the arrangement shown. Thus, for the 400 feet per minute installation, the cams for operating switch 162 when fully advanced would have to be rotated back to where the 75 pointer came opposite the 6 foot mark before

permitting the opening of the switch. Inasmuch as in the higher speed installations of around 1000 feet per minute average one and two floor runs would be made without advancing the carriage sufficiently to close switch 162, this switch 5 would not be brought into action on these short runs. Also, in these higher speed installations, the trailing edges of the cams for operating switch 162 may have to be cut off as shown in Figure 6 to insure that the trailing edge of the 10 cam for one direction of travel does not affect the closing of the switch during the opposite direction of car travel by engaging the operating roller of the switch ahead of the leading edge 15 of the cam for such opposite direction of car travel.

The outwardly extending or step portions 1356 and 1357 of cam 1330 are to prevent damage to the mechanism in case movement of the cross-head should take place without energization of 20 coil 577 of magnet 1333 to retract pawls 1304 and 1305. Referring to Figure 2, should upward movement, for example, of the crosshead take place without the pawls being pushed into retracted positions, the incline portion of cam 1330 25 between the trough portion and step portion 1357 would force operating roller 1423 for up pawl 1305 outwardly so that the pawl would clear the stopping lug as the upward movement of the crosshead took place. The incline portion of cam 1330 between the trough portion and the step portion 1356 would similarly serve to force down stopping pawl 1304 counterclockwise 30 about its pivot to clear the stopping lug in the event that downward movement of the crosshead took place without energization of coil 577 to move the pawls to retracted position. 35

The brushes for setting up the circuits to cause the car to be slowed down and stopped at the floors are carried on a panel 1391 mounted on carriage 1303. In order to set up these circuits, these brushes must engage "alive" stationary contacts. The stationary contacts 1392 with which these and other brushes moved by the crosshead cooperate are mounted on floor bars 40 1393 supported by standards 1251. The details of construction of this mechanism are shown in Figures 11 to 19 inclusive.

Referring to these figures and particularly to Figures 11 and 19, the floor bars are moulded 45 insulation and are secured as by screws 1396 to brackets mounted on standards 1251. These brackets are split to form two portions 1395 and 1396, which are clamped to the standards by means of screws 1397. The stopping lugs 50 1306 engaged by the pawls 1304 and 1305 are formed on the portions 1395 of the brackets on one of these standards. Portions 1396 of the brackets on both standards are formed with lugs to which the floor bars are secured by screws 55 1398.

Each stationary contact mounted on the floor bar is of the same construction. These contacts are mounted in apertures formed in the floor bar, the construction and mounting of one of these stationary contacts being illustrated in Figure 15. Referring to this figure, the stationary contact comprises a contact stud 1400 having a hexagonal head 1401 which fits into a corresponding hexagonal socket 1402 formed in 60 the floor bar. After extending through the aperture 1403 which extends through the bar from the socket 1402, the contact stud is clamped to the back of the bar by nuts 1404, which also serve as binding nuts to connect the contact in 65 70 75

the system. The hexagonal head of the stud is beveled at the end and is drilled (see Figure 17) to receive a tungsten contact tip 1405. These tips are engaged by the brushes during the 5 upward and downward movement of the cross-head.

Referring particularly to Figure 12, the brushes for establishing circuits to cause the car to be slowed down and brought to a stop at a 10 landing are designated 507, 510, and 514. Brush 507 is for cooperating with stationary contacts in one vertical column, the circuits to which are controlled by push buttons in the elevator car. When brush 507 engages one of these contacts 15 which has been rendered "alive" by the pressing of its controlling car button, circuits are set up to cause the car to be slowed down and brought to a stop at the floor for which the car button and contacts are provided. Brush 510 20 is for cooperating with stationary contacts in another vertical column, the circuits to which are controlled by down push buttons at the landings. When brush 510, in its downward movement, engages one of these contacts which 25 has been rendered "alive" by the pressing of its controlling down push button, circuits are set up to cause the car to be slowed down and brought to a stop at the floor for which the contact and down push button are provided. Brush 30 514 cooperates with stationary contacts in still another vertical column, the circuits to which are controlled by up push buttons at the landings. When brush 514, in its upward movement, engages one of these contacts which has been 35 rendered "alive" by the pressing of its controlling up push button, circuits are set up to cause the car to be slowed down and brought to a stop at the floor for which the contact and up push button are provided.

40 Each of these brushes 507, 510, and 514 is of the same construction, the details of their construction being shown in Figures 12 and 14. These brushes are carried by a switch frame 45 1410. This frame is in the form of a lever and is pivotally mounted on a shaft 1411 supported by the arms of a bracket 1412 secured to panel 1391. The actual engagement with the stationary contact is made by a rounded contacting element 1413. This element is secured to a 50 bronze alloy leaf spring 1414 by means of a clip 1415 and screw 1416. The clip is formed into a channel into which the contacting element and leaf spring extend. The contacting element is threaded to receive the screw which clamps the 55 element, spring and clip together as a unit. The spring is secured at its lower end as by a screw to a bracket 1417. This bracket in turn is secured to an insulating panel 1418 extending between and secured to the arms 1420 of switch frame 1410. This bracket is provided with a slot 1421 at its upper end through which an extension on the clip extends to protect the contact spring against being bent out of shape. One of the screws 1422 for securing bracket 1417 to 60 panel 1418 serves as a connector for the clip on the end of a flexible conductor connecting the brush in the system.

All three brushes are mounted on insulating 70 panel 1418 in the same way. The brushes are arranged in a side by side relation as shown in Figure 12. The switch frame is biased about its pivot in a direction to move the brushes toward contact engaging positions by springs 1423 extending between the contact frame and bracket 1412. An arm 1424 depending from the

frame cooperates with a screw 1425 mounted on bracket 1412 to form an adjustable stop to limit the amount of movement of the switch frame toward the stationary contacts by springs 1423.

An operating roller 1426 is pivotally mounted 5 on the shank of a screw 1427 secured to one of the arms 1420 of frame 1410. This roller cooperates with a plurality of trough shaped cams 1428 mounted in a vertical column, one on each floor bar 1393. These cams are arranged at one 10 end of the floor bars and are secured by the same screws 1398 that secure the floor bars to the portions 1396 of the bracket at that end of the bars. The roller and cams prevent the engagement of 15 brushes 507, 510, and 514 with their cooperating stationary contacts except when the roller has rolled down into the trough of the cams. When 20 the roller is in the trough of a cam as shown in Figure 13, springs 1423 force the frame about its pivot into position where the arm 1424 engages 25 stop screw 1425, in which position the contacting elements 1413 of the brushes are pushed into engagement with their cooperating stationary contacts on the bar on which the cam is mounted against the force of the leaf springs 1414, as 30 shown in Figure 14. As soon as the roller starts to move out of the trough onto a higher part of the cam, the switch frame is swung about its pivot against the force of springs 1423, disengaging 35 the brushes from their stationary contacts. Thus, as movement of carriage 1303 takes place, the brushes are caused to make momentary contact with their stationary contacts. This permits very accurate adjustments of the slow down distances. It also permits the operation of a maximum number of selector switches by their cams in making short floor runs in higher speed installations. This permits a maximum of acceleration on such runs, as will be seen from later 40 description.

As soon as brush 514 contacts with an "alive" contact during up car travel, or brush 510 contacts with an "alive" contact during down car travel, or brush 507 contacts with an "alive" contact during either down or up car travel, circuits 45 are set up to cause the energization of coil 548 of magnet 1333 which results in the deenergization of torque motor 1298, stopping relative movement between carriage 1303 and crosshead 1260 in the event that it has not already been 50 stopped by engagement of the carriage with one of the stopping collars 1315 or 1316 and to extend the stopping pawl for the direction of car travel for engagement with the stopping lug 1306 for the 55 floor for which such circuits have been set up. As soon as the clearance between the pawl and the stopping lug is taken up by movement of the crosshead, the carriage is brought to a stop in this position. The roller 1426 will have been moved slightly out of the trough of cam 1428 for that floor, thereby disengaging brushes 507, 510, and 514 from their cooperating stationary contacts for 60 the floor. Since further movement of the carriage is prevented during the slow down and stopping operation, the brushes remain in this position disengaged from their stationary contacts during this slow down and stopping operation.

Five other brushes are carried by panel 1391. These brushes are of the same construction as 70 brushes 507, 510, and 514, with the exception that the contacting elements 1432 are somewhat longer than contact elements 1413 of brushes 507, 510, and 514. These brushes, designated 515, 523, 519, 511, and 517, are mounted on an insulating 75

panel 1433. This panel is secured to panel 1391 by screws 1434. Spacers 1435 are provided on these screws between the two panels to extend the brushes toward the floor bars for proper co-operation with the stationary contacts.

The contacting elements 1432 of these five additional brushes are somewhat elongated to insure that the brushes are in engagement with their stationary contacts for a floor when the car-
10 rriage is brought to a stop preparatory to slowing down and stopping the car at that floor. As pointed out before, in discussing the scale 1385, certain working clearance is allowed for the pawls 1304 and 1305, which causes the pointer to register 15 ter with a different mark on the scale with the car stopped at a floor during down car travel than when it is stopped at the same floor during up car travel. For the same reason, each of the contacting elements of the five additional brushes 20 engages its stationary contact at a different point on the contacting element during stopping of the car at a floor during up car travel from when stopping the car at the same floor during down car travel.

25 Brush 515 and the stationary contacts engaged by this brush are for effecting the reset of the floor relays operated by up push buttons when response is made to such buttons during upward travel of the car. Brush 511 and the stationary contacts engaged by this brush are for effecting the reset of the floor relays operated by down push buttons when response is made to such buttons during downward travel of the car. Brush 511 and its cooperating contacts are also for effecting the reset of a down floor relay during up car travel under certain conditions of operation, which will be explained in discussing the control system.

Brushes 519 and 523 and their cooperating stationary contacts are for controlling the lighting of the hall lanterns at the floors, brush 523 controlling the lighting of up hall lanterns and brush 519 controlling the lighting of down hall lanterns.

Brush 517 and the contacts engaged thereby are 45 for causing the car to be slowed down and stopped in response to a down hall button when no higher call, registered either by a car button or a hall button, exists and when the up hall button for the floor at which the down hall button is located 50 is not pressed, and also for causing the direction of car travel to be reversed from up to down as the car is brought to a stop.

Panel 1391 also carries a cam 508 of insulating material for operating a series of floor brush switches carried by the floor bars. A floor brush switch is provided on the floor bar for each floor above the first floor, these floor brush switches being for controlling circuits to cause the direction of car travel to be reversed from up to down upon answering the highest operated car button when the up hall button for the same floor or the hall button for a floor above is not operated.

Each floor brush switch is of the same construction, the construction of one of them being illustrated in Figure 18. It comprises a stationary contact 1440 secured to the floor bar and a contact lever 1441 pivotally mounted on a pin 1442 extending between two sides of a bracket 1443 secured to the floor bar. The contact lever 1441 is arranged between the two sides of the bracket and is formed with a widened slot 1444 which extends over the pin to form the pivot. The contact lever is formed with an upwardly extending arm 1445 which also is formed with a slot 1446 to receive the pin 1447 secured to the arm 1448 of

operating lever 1450. This operating lever is pivoted on a pin 1451 extending between the two sides of the bracket. It is in the form of a bell crank and on its outer end is provided with a contact shoe 1452 for engagement by cam 508. A spring 1453 is arranged between the contact lever 1441 and the operating lever 1450 for biasing the contact lever into engagement with the stationary contact and the operating lever into extended position for cooperation with the cam.

Upon engagement of shoe 1452 by cam 508, the operating lever is moved clockwise as viewed in Figure 18, against the force of spring 1453. The operating lever acts through pin 1447 and slot 1446 to push the contact lever 1441 counter-clockwise about its pivot. This movement disengages the contact lever from stationary contact 1440. The initial movement of the contact lever is a sliding one, due to the lost motion occasioned by the widened slot 1444, thereby obtaining the advantage of rubbing contact engagement. As soon as this lost motion is taken up, the pivotal movement takes place, forcing the disengagement of the contact lever from the stationary contact against the force of spring 1453. Cam 508 is set to engage and open the floor brush switch on each floor bar above the first floor before the engagement of brush 507 with its cooperating stationary contact on that bar. The purpose of this will be seen from later description. Furthermore, cam 508 is of such length and is so positioned as to maintain the floor brush switch on any floor bar open until after brush 507 during upward movement has left the stationary contact on the floor bar above. The purpose of this also will be shown later.

An additional floor brush switch 607 is provided on a floor bar positioned beneath the floor bar for the first floor (see Figure 19). This floor brush switch serves a different purpose from that of the other floor brush switches, as will be shown later, the positioning being such that it is opened by cam 508 when a car is at the main floor and also so that the cam passes off the switch to permit it to reclose after a short advance of the carriage in the upward direction from its first floor position.

Referring particularly to Figure 16, the cross-head 1260 carries three different additional brushes 671, 64, and 621. These brushes are mounted on an insulating panel 1459 secured by screws to bosses 1460 formed on the framework of the levelling mechanism (see Figures 21 and 22), this levelling mechanism being secured to the crosshead, as will be explained later. These brushes are of the same construction as brushes 507, 510, and 514, with the exception of the contacting element 1461 of brush 64 and the contacting element 1462 of brush 671. Contacting element 1462 is of the same length as the contacting elements 1432 of the brushes mounted on insulating panel 1433. The contacting element 1461 of brush 64 is also elongated but is formed with a trough portion 1463 as shown in Figure 17. This trough portion is to break the circuit through the brush and its cooperating stationary contact just before the car reaches the floor (either the top or bottom terminal floor) for which the stationary contact is provided.

Brush 671 and its cooperating stationary contacts are for controlling the operation of the position indicator. Brush 64 and its cooperating stationary contacts are for controlling the automatic opening of the car gate and hatchway doors at the terminal floors. Brush 621 and its co- 70 75

operating stationary contacts are for effecting reversal of the direction of car travel at the terminal floors. Since panel 1459 moves directly with the crosshead, i. e., is not subject to the 5 advance mechanism, this panel does not in effect have the two centers occasioned by the pawl clearances, as in the case of the panels carried by carriage 1303. Thus the contact element of brush 621 may be shorter than the contacting elements 10 of brushes carried by panel 1433. Brushes 64 and 671, however, are longer, owing to the nature of the circuits in which they are utilized.

The arrangement of the stationary contacts on the floor bars is shown in Figure 19. This figure 15 shows floor bars for the first, second, third and fourth floors and for the upper terminal floor as well as a special floor bar below the one for the first floor. As there shown, stationary contacts are provided on each floor bar above the 20 special floor bar for cooperation with brushes 507, 510, 514, 515, 523, 519, 511, 517, and 671. Stationary contacts are provided only at the 25 terminal floors for cooperation with brushes 64 and 621. Floor brush switches are provided only on floor bars for floors above the first floor and on the special lowermost bar. Space is provided for additional stationary contacts and other mechanism on the right ends of the floor bars as shown. Such space may be desired for 30 special operations or circuits which are not described in this system. The floor bars are spaced in accordance with the distances between the corresponding floors. The floor bars are shown considerably spaced in Figure 2 in order that 35 the principles of operation of the selector machine may be readily seen from the illustration.

Referring to Figure 20 and also back to Figure 2, switching mechanism operable in association with other parts of the control system 40 to bring the car to exact landing levels regardless of whether underruns or overruns occur, will be described. This mechanism is illustrated as arranged on the selector machine to be operated through the intermediary of sprocket 45 1255, shaft 1254 and vertical screw 1256. The screw 1256, as pointed out previously, causes movement of the crosshead 1260 according to movement of the elevator car. A portion of the levelling mechanism is carried by the crosshead. 50 This portion comprises two levelling switch units, one for up levelling and the other for down levelling. Each switch unit comprises three contact levers 1470, 1471, and 1472, pivotally mounted on the framework 1473 of the mechanism. Levers 1471 and 1472 are free to pivot and are biased by springs 1469 against adjustable stops 1468 carried by the framework. Each of these levers carries a contact at its outer end. Contact 1474 is carried by lever 1472 and is adapted to 55 be engaged by contact 1476 carried by lever 1470. Contact 1475 carried by lever 1471 is adapted to be engaged by contact 1477 also carried by lever 1470. Lever 1470 also carries a contact 1478 for engaging a stationary contact 60 1480 mounted on the levelling switch framework. In the wiring diagram (Figure 24a), the pairs of contacts 1478, 1480, which serve as interlocks, are designated by single reference numerals 83 and 90; the pairs of contacts 1477, 65 1475, which serve as up and down levelling direction contacts, are designated by single reference numerals 82 and 87; and the pairs of contacts 1476, 1474, which serve as fast speed levelling contacts, are designated by single reference numerals 75 and 77.

Lever 1470 is biased by a spring 1469 in a direction to separate contacts 1477 and 1476 from contacts 1475 and 1474 respectively, and to engage contact 1478 with contact 1480. It is adapted to be moved about its pivot against the force of its biasing spring to separate contacts 1478 and 1480 and to engage contacts 1477 and 1475 and contacts 1476 and 1474 by magnet 1481. This magnet acts to move lever 1470 through an armature 1482 which is pivoted to the framework of the mechanism for attraction by the magnet, and which carries at its end opposite the pivot point an operating roller 1483 for engaging arm 1484 of lever 1470. Upon magnet 1481 being energized, armature 1482 is attracted and swung about its pivot. The armature acts through roller 1483 and arm 1484 to swing contact lever 1470 against the force of its biasing spring to separate contact 1478 from contact 1480. As this movement continues, contact 1477 10 engages contact 1475. Further movement causes contact lever 1471 to be swung about its pivot against the force of its biasing spring and thereafter contact 1476 to move into engagement with contact 1474, contact lever 1472 being swung about its pivot against the force of its biasing spring as this engagement takes place until armature 1482 is brought to a stop. When magnet 1481 is deenergized, the armature is swung outwardly about its pivot by the biasing spring 1469 15 for lever 1470 until it is brought to a stop by engaging adjustable stop screw 1479. This stop also limits the movement of lever 1470 by its spring 1469.

Contact lever 1470 also carries an operating roller 1486 which cooperates with levelling cams 1487 to effect the levelling operation. These cams are mounted on cam shaft 1488 which extends between base plate 1250 and top plate 1252, at which points it is supported by bearings. A cam is provided on this shaft for each floor for which a stop is to be made and the levelling cams are spaced along the cam shaft so that the distances between adjacent cams are in accordance with the distances between their respective floor landings. Each cam is helical and has a pitch equal to the pitch of the thread on screw 1256. The radius of the working face 1485 of each cam is a maximum at the central portion thereof and is a minimum at the end portions. These end portions are bevelled at 1489. A gear 1490 is secured to cam shaft 1488 to effect rotative movement thereof. This gear meshes in a driven relation with the corresponding gear 1491 secured to screw 1256 so as to rotate therewith.

The coils of the magnets 1481 of the two units have been designated in the wiring diagram as 166 and 167 (see Figure 24a), these coils being connected in series relation so as to be energized simultaneously as shown in this figure. When the car is at rest, the levelling magnet coils are not energized. Under such conditions, the levers assume operative positions in accordance with the illustration in Figure 20, i. e., with the back contacts 1478, 1480 in engagement and the forward contacts 1477, 1475 and 1476, 1474 separated. Also, the operating rollers 1486 are in non-retracted positions. With the car at a landing, the rollers assume a position with respect to the cam for that landing as shown in Figure 20.

The coils of the levelling magnet are energized during starting of the car and act upon levers 75

1470 to cause operation of the contacts in the manner previously described. The movement of levers 1470 also causes rollers 1486 to assume retracted positions where they clear the levelling cams during movement of the car. The levelling magnets are deenergized during slow down operation, the deenergization of these magnets releasing armatures 1482 which in turn release levers 1470. Under such conditions, the biasing springs 10 1469 tend to move all the levers toward the levelling cams. If the car is out of level with the floor when this takes place, the levelling cam for that floor is out of central position with respect to its rollers 1486, and is struck by the roller of one of 15 the levelling switch units, the roller which strikes the cam depending upon whether the car is above or below the floor. This restricts the movement of the lever 1470, upon which the roller is mounted, by its biasing spring 1469, which in turn prevents 20 the engagement of contacts 1478, 1480 and the separation of contacts 1477, 1475 and possibly of contacts 1476, 1474 of that unit, depending upon how much the car is out of level. The levers of the other levelling switch unit, however, are returned 25 to the position shown in Figure 20, separating the forward contacts and engaging the back contacts of that unit. The engagement of the back contacts 1478, 1480, as will be seen from later description, establishes a feed through the 30 closed forward contacts 1477, 1475 of the unit whose roller strikes the cam.

The forward contacts act, as will be described later, to cause the car to come to the floor level. As this levelling operation takes place, first contacts 1476, 1474, if closed, open due to the roller riding onto a lower portion of the cam, i. e., a portion of less radius, reducing the speed of the car. Further rotative movement of the cam permits roller 1486 of that unit to ride onto a still 40 lower portion of the cam and thus permits further movement of lever 1470 toward the cam. This results in the separation of contacts 1477, 1475, which causes the car to be brought to a stop at the exact landing level. The slight coast of the 45 car after the separation of contacts 1477, 1475 results in the engagement of back contacts 1478, 1480 and the disengagement of the roller from the cam.

The details of one of the levelling switch units 50 are shown in Figures 21 and 22. The portion of the framework 1473 upon which this unit is mounted comprises an elongated plate 1495 secured to the guide portion 1263 of the crosshead as by bolts 1496. The guide portion of the cross- 55 head is forked to cooperate with guide bar 1265 in guiding the crosshead, and the securing screws 1496 extend into threaded apertures in lugs 1497 formed on these forks. A guiding gib 1498 is pressed against the remaining face of the guide bar by adjustable screws 1500. A U-shaped strap portion 1501 is formed integral with the plate 1495 and receives the magnet 1481, the stationary core of the magnet being secured to the yoke of the strap portion. An extension 1502 is formed 60 on the strap and on this extension two of the lugs 1460 for supporting panel 1459 (Figure 11) are formed.

At the point that extension 1502 joins the strap portion 1501, the framework is provided with an 70 aperture to receive the pivot pin 1503 for armature 1482. The adjustable stop screw 1479 for the armature is secured to a lug 1499 formed on the armature and cooperates with extension 1502 to limit the movement of the armature and lever 75 1470 by biasing spring 1469 for this lever. The

movable core 1504 for magnet 1481 is secured to this armature. At its outer end the armature pivotally supports operating roller 1483, the roller extending into a slot formed in the armature. Arm 1484 operated by armature 1482 is engaged by roller 1483 at its outer end. The arm is mounted on shaft 1506 supported by brackets 1507 secured to plate 1495 by screws 1508. Arm 1484 is keyed to this shaft and another arm 1510 is likewise keyed to the shaft to comprise lever 1470.

The arm 1510 is formed with a boss 1511 to which a contact arm 1512 of insulating material is secured as by screws 1513. This arm carries movable contact 1478 for cooperation with stationary contact 1480. The stationary contact is tungsten-tipped and is secured in a contact stud 1516 mounted on a panel 1514 secured to extensions 1515 on brackets 1507. The panel is not shown in Figure 21 in order that the construction of other parts may be more readily ascertained. 20 The movable contact comprises a tungsten-tipped contact spring 1517 secured in a channel on the insulated contact arm 1512 by a screw, the construction being similar to the construction of contact spring 1278 and contact lever 1277 (see Figure 3).

At its outer end contact arm 1510 carries a V-shaped contact holder 1520 of insulating material. This contact holder carries contacts 1476 and 1477. These contacts are in the form of tungsten-tipped contacts on contact studs 1519 secured to the contact holder. Contacts 1475 and 1474, which are engaged by contacts 1477 and 1476 respectively, are carried by insulated contact arms 1521 secured to the levers 1471 and 1472. These levers are freely mounted on shaft 1506. The contact arms 1521 and contacts 1474 and 1475 are of the same construction as contact arm 1512 and contact 1478. The contact holder 1520 is formed with lugs 1522 for engaging contact arms 1521 after the engagement of contacts 1474 and 1475 by contacts 1476 and 1477 occurs. This arrangement is provided so that levers 1471 and 1472 are respectively moved along with lever 1470 after the contact engagements occur, thereby protecting the leaf spring contacts. 45

Connections are made from the binding posts for the screws which secure contacts 1474 and 1475 to contact arm 1521, contact 1478 to contact arm 1512 and contacts 1476 and 1477 to contact holder 1520, by flexible conductors to terminals on panel 1514. These flexible conductors are not shown, although the clip 1527 for one of them is indicated in Figure 22. These terminals comprise the contact stud for contact 1480 and terminal screws 1523 provided on the panel. 55

Arm 1510 is formed on the extension 1524 at right angles thereto. The supporting bracket 1525 for the roller 1486 which cooperates with the levelling cams is adjustably secured to extension 1524 as by screws 1526. The extension is formed with a slot through which contact arm 1512 extends. It is not thought necessary to review the operation of the levelling mechanism in connection with the details shown in Figures 21 and 22 as it is believed that the operation will be clear from the description already given in connection with Figures 2 and 20. In this case, the lines + and - of Figures 24a and b may be connected to the power supply mains. 65

Reference may now be had to Figures 24a, 24b, 24c, and 25, which illustrate diagrammatically the various control and power circuits. No attempt is made in these figures to show the coils and contacts of the switches in their associated posi- 75

tions, "straight" diagrams being employed, wherein the coils and contacts of the various switches are separated in such manner as to render the circuits involved relatively simple. The 5 relation of the coils and the contacts may be seen upon reference to Figure 23.

Figures 24a and 24c constitute a wiring diagram of the control system for one elevator. Figure 24b shows the slow down initiating and signal 10 circuits for that elevator. Figure 25 illustrates the slow down initiating and signal circuits for a second elevator, it being understood that the second elevator is provided with additional control and power circuits which may be identical with 15 those illustrated in Figures 24a and 24c. The slow down initiating and signal circuits are illustrated for only ten floors.

The numerals employed in designating the various elements of the control system are arranged 20 in sequence in these diagrams, the lower number 30 which indicates a grounded supply line, appearing in the upper left hand corner of Figure 24a, with the succeeding numbers following in numerical sequence from left to right downwardly 25 on the sheet of drawings. The circuits in Figure 24b are joined to the circuits in Figure 24a as indicated by the continuance of wires C- and C+, and the numbers continue in Figure 24b in the same sequence. The arrangement of numerals 30 in this sequence facilitates the location of any element referred to in the description.

Any suitable form of power supply may be provided for the elevator motor. One of the preferred arrangements is to employ a direct current 35 elevator motor and to cause current to be supplied to the motor at a variable voltage, as from a driven generator in accordance with Ward-Leonard principles. The generator of such arrangement has been illustrated. The driving 40 motor for the motor generator set and control arrangement therefor have not been illustrated. It is to be understood that either a direct current or alternating current driving motor may be employed, depending upon the kind of power supplied 45 to the building and the character of the installation, and that any suitable control arrangement therefor may be utilized, such, for example, as one embodying the principles of the arrangement disclosed in the application of Lindquist, 50 Waters, and Glaser, Serial No. 603,702, filed April 7, 1932. For convenience, it will be assumed that direct current is supplied to the building.

The armature of the supply generator is designated 55 256, its separately excited field winding being designated 255, its series field winding 242 and its interpole field winding 241. The armature of the elevator motor is designated 257, and its separately excited field winding is designated 36.

When the generator is driven by an alternating 60 current driving motor, an exciter driven by the driving motor is employed to supply current to the separately excited field windings of the supply generator and the elevator motor and to the coils of various electromagnetic switches. With 65 such arrangement, the lines + and - would be connected to the exciter terminals, the hall button circuits through the operating coils of the floor relays, however, being connected to the source of supply for the building so as to permit 70 operation of the floor relays at any time. In case of a direct current power supply, lines + and - would be connected to the power supply lines.

Discharge resistances 42 and 248 are provided 75 for the separately excited field windings 36 and 255 of the elevator motor and generator respec-

tively. A resistance 227 is arranged in shunt to generator series field winding 242. A resistance, arranged in steps 249, 246, 247, 250, 251, 252, and 253, is provided for controlling the strength of the generator separately excited field, and therefore the voltage applied to the elevator motor armature. A resistance, illustrated in sections 5 34 and 35, is provided in series with the elevator motor field winding 36. 214 is the release coil for the elevator electromagnetic brake. This coil is provided with a discharge resistance designated 213. It is also provided with cooling resistance 10 212. The contacts operated by the car gate and engaged when the gate is closed are designated 213. The door contacts operated by the various doors are arranged in series relation. For convenience, the door contacts are shown as a single pair of contacts designated 104.

The electromagnetic switches have been designated as follows: 20

A	First auxiliary stopping relay	
ANS	Auxiliary non-stop relay	
AR	Automatic reversal relay	
AS	Auxiliary speed relay	25
AU	Auxiliary up direction relay	
B	Second auxiliary stopping relay	
BK	Brake resistance relay	
C	Potential switch	
D	First speed switch	30
DC	Door close switch	
DO	Door open switch	
E	Second speed switch	
EE	Second speed relay	
F	Third speed switch	35
FB	Field boosting switch	
FF	Third speed relay	
G	Fourth speed switch	
GF	Governor field switch	
GG	Fourth speed relay	40
H	Brake and field switch	
HG	Generator field switch	
J	Minimum current field relay	
LD	Down levelling direction switch	
LE	Levelling fast speed switch	45
LU	Up levelling direction switch	
LZ	Levelling slow down relay	
NB	Night bell relay	
NS	Non-stop relay	
O	Safety handle relay	50
OB	First starting switch sequence relay	
OC	Second starting switch sequence relay	
P	Door operating relay	
PA, PB	Auxiliary direction switches	
PD	Down direction switch	55
PL	Direction levelling relay	
PU	Up direction switch	
Q	Load magnet	
TC	Topmost car call relay	
TH	Topmost hall call relay	60
UL	Up indicator light relay	
Y	Series field switch	
Z	Notch-back switch	

The magnet 133 of the selector for extending 65 cam 1330, hereinafter referred to as the stop magnet, is designated generally by the letters SM.

Throughout the description which follows, these letters, in addition to reference numerals, will be applied to parts of the above designated 70 switches. For example, "contacts C48" indicate that the contacts are on the potential switch C, while "operating coil H85" indicates that the coil operates the brake and field switch H. All electromagnetic switches are illustrated in deener- 75

gized position. All latching switches are illustrated in reset condition.

The operation of the control system illustrated will now be described. The motor generator set 5 may be started by the motor generator starting switch in the elevator car (see Figure 1).

According to the preferred arrangement, with the elevator motor at rest, the current supplied to the field winding is reduced, providing what may 10 be termed a "standing field". Resistance 35 is employed for this purpose.

The electromagnetic switch employed to connect the driving motor to the power mains is provided with additional contacts for interlocking the 15 driving motor control with the control for the elevator motor. These additional contacts are illustrated and designated 38 and 46. Contacts 38 separate to remove the short circuit for coil J33 of the minimum current field relay J upon the connection of the driving motor to the power mains, coil J33 being connected in series relation with the elevator motor field winding. Contacts 46 are in the circuit for the coil C44 of the potential 20 switch C. Relay J acts to insure the elevator 25 motor field being built up to substantially standing field value before the potential switch can operate, contacts J45 being connected in the circuit for coil C44 of the potential switch. With both contacts 46 and J45 in engagement, the circuit 30 for coil C44 of the potential switch is complete. This circuit is through potential switch contacts C37 and emergency stop switch 47. The circuit also includes various safety switches, limit 35 switches and the like which are indicated simply by legend.

The potential switch, upon operation, engages its contacts C48 and C55 in the feed lines to the control and field circuits. The potential switch also causes the engagement of contacts C376 and 40 the separation of contacts C37. Contacts C37 act to insert cooling resistance 43 in the circuit with the potential switch coil C44. Contacts C376 are arranged in a circuit common to the hall lanterns.

With the car at the lower terminal, the up direction switch PU is latched in operated condition and the down direction switch PD is in reset condition. With the up direction switch in operated condition, its contacts PU92, PU195, 45 PU216, PU281 and PU591 are in engagement and its contacts PU123, PU134, PU150 and PU164 are separated. With the down direction switch in reset condition, its contacts PD110, PD201, PD217, 50 PD280 and PD592 are separated and its contacts PD115, PD125, PD142 and PD155 are in engagement. The direction switches are also provided with latch contacts PU617 and PD611. Under the conditions assumed, contact PD611 are in engagement and contacts PU617 are separated.

60 The engagement of potential switch contacts C48 and C55, together with the engagement of direction switch contacts PU195, effects the energization of the car button magnet coil 193.

Owing to the fact that contacts PD611 of the 65 down direction switch are in engagement when the car is at the lower terminal, circuits are completed for the actuating coils PA603 and PB604 of the auxiliary direction switches PA and PB and the actuating coil AU608 of the auxiliary up direction relay upon the engagement of potential switch contacts C48 and C55. Switch PA, upon operation, engages its contacts PA544 and separates its contacts PA550. Switch PB, upon operation, engages its contacts PB526 and PB539 70 and separates its contacts PB525 and PB543.

Switch AU, upon operation, engages its contacts AU377 and AU534.

The engagement of potential switch contacts C48 and C55 also completes the circuits for the actuating coils NS564 and ANS565 for the non-stop relay and auxiliary non-stop relay, respectively. Non-stop relay NS, upon operation, engages its contacts NS392, NS540, and NS545. Auxiliary non-stop relay ANS, upon operation, engages its contacts ANS535 and separates its contacts ANS537. The engagement of contacts NS540 and NS545, together with the engagement of contacts PB539 and PA544, prepares the reset and stop circuits. The engagement of contacts NS392 together with the engagement of contacts C376 and PB526 completes the circuit for up lamp 521 at the first floor. This connection is to the power supply lines indicated as + and - and is through selector contact 522 and brush 523. The purpose of the contacts of the auxiliary non-stop relay ANS and auxiliary up direction relay AU will be explained later in the description.

The car is started by the attendant in the car moving the starting switch to full start position. 25 As previously explained, the starting switch has an intermediate position for effecting certain control operations and for effecting the closing of the car gate and the hatchway door for the floor at which the car is standing. For convenience of description, it will first be assumed that the starting switch is operated to the intermediate position and then to full start position in steps. It is to be understood, however, that in normal operation the car switch is moved to full start position immediately without pausing in the intermediate position.

Movement of the starting switch to its intermediate position causes the bridging of contacts 581. This completes the circuit for the coil DC573 of the door close switch. The circuit extends through a limit switch 571 arranged to be operated by the door operating mechanism, interlock contacts DO572 of the door open switch and contacts OC580 of the second starting switch 40 sequence relay. This switch causes the operation of mechanism (not shown) to move the car gate and the hatchway door at the first floor to closed positions.

The bridging of contacts 581 also completes the 50 circuit for coil P575 of the door operating relay P. Relay P is a latching relay, being provided with an operating coil and a reset coil. Coil P575 is the reset coil and acts, upon energization, to cause the relay to be reset. Relay P, upon being 55 reset, separates contacts P52 and engages contacts P131, the condition of the contacts as illustrated. Contacts P52 are arranged in the circuit for coil DO51 of the door open switch, while contacts P131 are in the circuit for the coils of speed 60 switches D, E, F, and G.

Upon movement of the door operating mechanism a certain distance, a limit switch 50 in circuit with door open switch coil DO51 is closed. The circuit for coil DO51 is not completed, however, as contacts P52 of door operating relay P are separated. As the door and gate near closed position, limit switch 571 is opened, breaking the circuit for coil DC573 of the door close switch, discontinuing the operation of the door operating mechanism, and the door and gate are brought to a stop as they reach closed positions.

If the attendant, after he has effected the closing of the door and gate, desires to open them, or if he desires to arrest the movement of the door 75

and gate in closing, he may do so by moving the starting switch back through off position to door opening position. Assume that the gate and door are closed and that the attendant moves his 5 starting switch to door open position. Starting switch contacts 61 are bridged in this position, completing a circuit for the operating coil P56 of the door operating relay. The circuit extends through a portion of resistance 60, contacts 10 OB62 of the first starting switch sequence relay, contacts D53 of the first speed switch and the emergency switch, this latter switch being illustrated as provided with two blades 47 and 54, the present circuit passing through blade 54. Relay 15 P operates to engage its contacts P52, completing the circuit for the actuating coil DO51 of the door open switch. Switch DO causes the operation of the door operating mechanism to move the door and gate to open positions.

20 Upon movement of the door and gate a short distance in the opening direction, limit switch 571 closes, preparing the circuit for coil DC573 of the door close switch. Just before the door and gate reach open position, limit switch 58 opens to 25 break the circuit for coil DO51, discontinuing the operation of the door operating mechanism and the door and gate are brought to a stop.

Returning to the operations resulting from movement of the starting switch to intermediate 30 position, the bridging of starting switch contacts 581 completes a circuit for the operating coil SM577 of the selector stop magnet. The circuit extends through resistance 578, contacts AS579 of the auxiliary speed relay, and contacts OC580. 35 This magnet extends the cam 1330 to move the pawls into position where they do not engage the stopping lugs, and engages the three pairs of switch contacts, as previously described, these contacts being designated on the wiring diagrams 40 as SM549, SM583 and SM586. Contacts SM583, upon engagement, establish a self-holding circuit for the magnet. Contacts SM549 are in the slow down initiating circuits and serve as an interlock. Contacts SM586 complete the circuit 45 for the coil A585 of the first auxiliary stopping relay. The circuit is through a portion of resistance 584 and start switch contacts 581.

Stopping relay A, upon operation, engages contacts A532 and A594 and separates contacts A524 50 and A541. Contacts A541 open the reset circuit for the floor relays, the purpose of which will be seen later. Contacts A524 open the circuit to the hall light brushes 519 and 523, thus breaking the circuit to lamp 521 to extinguish the up light at 55 the first floor. Contacts A532 prepare the circuit for effecting automatic reversal. This operation will be explained later. Contacts A594 are in the circuit for the selector machine advancer motor.

60 So far, the operation which transpires as a result of moving the starting switch to intermediate position has been described. Assume, now, that the starting switch has been moved immediately to full start position from off position, which is 65 the normal operation. Assume also that a call has been registered for a floor a greater distance above the first floor than the distance which the advancer motor advances the brushes. The reason for this assumption will be seen as the description 70 proceeds. The control operations previously described as effected as a result of movement of the starting switch to intermediate position take place as before, contacts 581 remaining bridged in full start position. Due to the bridging of contacts 112 and 597, other control operations occur

at the same time as those effected by the bridging of contacts 581.

The bridging of starting switch contacts 597 completes the circuit for coil B587 of the second auxiliary stopping relay through a portion of resistance 584, and contacts A594. Relay B, upon operation, separates contacts B66 in the automatic door opening circuit and engages contacts B147 to complete the circuit for coil FB144 of the field boosting switch. Switch FB, upon operation, engages contacts FB140 to establish a self-holding circuit through contacts of one of the speed relays. This holding circuit is shown extending through contacts FF141 of the third speed relay, but it is to be understood that the relay employed would be determined by the requirements of the particular installation. It also engages contacts FB233 to short-circuit a variable portion of the generator field control resistance.

The bridging of contacts 597, together with the engagement of contacts A594, completes the circuit for the selector machine advancer motor. The circuit extends through advancer motor armature 589 and field winding 588 connected in parallel by contacts PU591, advancer motor field winding 590, resistance 593, contacts 594 and starting switch contacts 597. The advancer motor operates to close selector switches 102, 57, 121, 131, 154, and 162 in the order named. At the same time, the advancer motor advances brushes 501, 510, 511, 514, 515, 517, 519, 523, the cam 508 and the pawls 1304 and 1305, as previously described, the direction of current flow through the advancer motor armature being such as to cause the advance to take place in the up direction. The advancer mechanism is brought to a stop by stop collar 1316.

The advancer motor is preferably adjusted so as to effect the closure of the selector switches and the advancing of the brushes, cam and pawls at a fairly rapid rate so that all the selector switches will be closed and the brushes totally advanced before the closure of the door and gate is effected. With this arrangement, the car is started when gate contacts 103 and hatchway door contacts 104 close as the gate and the door for the floor at which the car is positioned reach closed positions. The engagement of gate contacts 103 and door contacts 104 completes the circuit for coil H95 of the brake and field switch and coil HG100 of the generator field switch. This circuit is through a portion of resistance 96, contacts OC91 of second starting switch sequence relay, selector switch 102, up direction switch contacts PU92, terminal stopping switch 93, starting switch contacts 112 and emergency switch 54.

Switch H, upon operation, engages contacts H41, H67, H171, H205, and H211 and separates contacts H210, H210 and H615. Switch HG, upon operation, engages contacts HG97, HG237, HG254, HG570, and HG599 and separates contacts HG183 and HG277. The engagement of contacts HG97 by-passes contacts OC91 of the second starting switch sequence relay in the circuit for the coils of switches H and HG. Contacts HG599 engage to by-pass contacts 597 of the starting switch in the circuit for the coil of switch B and the circuit for the brush advancer motor. Contacts H67 are in the automatic door opening circuit. Contacts H615 are in the circuit with the coils of direction switches PU and PD, and serve to prevent the operation of these switches until the car has been brought to a stop. Contacts HG183 are arranged in the circuit for

the generator auxiliary separately excited field winding 184, preventing the completion of this circuit so long as switch HG is operated. These contacts also control the circuit for the coil Y172 of the series field switch. Contacts H171, when in engagement, prepare the circuit for coil Y172 of the series field switch. Contacts HG211 and contacts H270 control the connecting of the generator separately excited field winding 255 to the generator armature 256. These contacts, upon separation, break the shunt circuits for resistance 266, which is of a high value, inserting this resistance in the circuit connecting the generator field winding to its armature. Contacts H205 and H211 complete the circuit for the brake release coil 214. Contacts H210 control a discharge circuit for the brake release coil. The purpose of this arrangement will be explained later. Contacts HG237 and HG254 connect the generator separately excited field winding 255 to supply lines + and -.

The completion of the circuit for the generator separately excited field winding causes current to be supplied from the generator armature 256 to the hoisting motor armature 257 and, the brake being released as a result of the energization of its release coil 214, the elevator motor starts the car in the up direction. The elevator motor field is brought up to full strength as the starting of the elevator motor is effected, owing to the short-circuiting of resistance section 35 by contacts H41. The circuit for the generator field winding, upon starting the elevator motor, is through resistance steps 245, 246, 252, and 253. Contacts FB233 have been illustrated as short-circuiting step 251 but it is to be understood that the amount of resistance actually short-circuited by these contacts will be determined by the characteristics of the particular installation. The purpose of contacts FB233 is to apply a rather high value of voltage to the generator field winding 255 initially, forcing the field strength of the generator to be more rapidly built up.

Contacts HG570 complete the circuit for coils OB568 and OC569 of the starting switch sequence relays. Relay OC engages contacts OC136 to prepare the circuits for the coils of the speed switches. It separates contacts OC91 to insert cooling resistance 96 in the circuit for the coils of switches H and HG. Contacts OC576 in conjunction with contacts HG570 by-pass contacts 581 of the starting switch. Contacts OC580 break the initial energizing circuit for the operating coil of the stop magnet SM and also for the reset coil 575 of the door operating relay. First starting switch sequence relay OB, upon operation, separates contacts OB62 to break the circuit for the operating coil P56 of the door operating relay, preventing the manual reopening of the doors until the car is again brought to a stop.

Upon the closing of selector switch 121 by the advancer motor, a circuit is completed for coil AS114 of the auxiliary speed relay. This relay engages contacts AS533 and AS547 and separates contacts AS579 and AS616. Contacts AS579 are in the initial energizing circuit for coil SM577 of the stop magnet. This arrangement prevents the starting of the car upon movement of the starting switch to start position in the event that the advancer mechanism is for any reason in an advanced condition. Contacts AS616 are in the circuit which controls the coils of direction switches PU and PD, and act to prevent the operation of these switches to reverse the direction

of car travel in the event that the advancer mechanism is for any reason in an advanced condition. The purpose of contacts AS547 and AS533 will be explained later.

The brake, upon being released, effects the separation of contacts 196, which act to remove the short-circuit for the operating coil BK203 of the brake resistance relay. This relay operates to separate its contacts BK206 to insert cooling resistance 212 in circuit with brake release coil 214, and engages its contacts BK120, which completes the circuit for the coil D117 of the first speed switch. The circuit extends through contacts OC136, contacts P137, contacts BK120, selector contacts 121, up direction switch contacts PD115, terminal stopping switch contacts 116 and emergency switch 54.

Switch D operates to engage its contacts D170 and D224 and to separate its contacts D53. Contacts D53 are in the door operating circuits and serve to prevent the energization of the coil of the door open switch DO while the car is running. Contacts D170 complete the circuit for the retiring magnets 166 and 167 for the levelling switches. These magnets operate to attract the levelling rollers of the selector so as to cause them to clear the levelling cams as floors are passed at which stops are not to be made. The retraction of the rollers causes the engagement of levelling switch contacts 75, 77, 82, and 81 and the separation of levelling switch contacts 83 and 80, as previously explained.

The engagement of contacts 75 and 77 completes the circuit for the actuating coil LE174 of the fast speed levelling switch and coil LZ13 of the levelling slow down relay through a portion of resistance 70. Switch LE engages contacts LE191 in the circuit for generator auxiliary separately excited field winding 184. The purpose of these contacts will be explained later. Switch LZ separates contacts LZ192 which also control the circuit for field winding 184, as will be explained later.

Contacts D224 of the first speed switch, upon engagement, short-circuit step 253 of the control resistance for the generator field winding 255. This increases the voltage applied to the generator field winding. This in turn increases the voltage of the generator armature, with the resultant increase in the speed of the elevator motor.

The coils of certain relays are arranged in circuit with the generator field winding 255. As the current in the generator field winding builds up as a result of the operation of switch D, a point is reached where sufficient voltage is applied to the actuating coil EE264 of the second speed relay to cause this relay to operate. Upon operation, relay EE engages contacts EE130 to complete the circuit for the actuating coil E127 of the second speed switch.

Switch E, upon operation, engages contacts E157 and E223. Contacts E157 prepare the circuit for the coils of speed switches F and G. Contacts E223 short-circuit step 252 of the generator field control resistance. This further increases voltage applied to generator field winding 255, causing corresponding increase in the speed of the elevator motor. As the current increases in the generator field winding circuit, a point is reached where sufficient current is supplied to coil FF263 of the third speed relay to cause this relay to operate. Upon operation, relay FF separates contacts FF141 to break the holding circuit for switch FB. This switch is maintained

operated by contacts B147. The purpose of this arrangement will be explained later. Relay FF also engages contacts FF153 to complete the circuit for coil F152 of the third speed switch. 5 Switch F, upon operation, engages contacts F222 to short-circuit step 251 of generator field control resistance, illustrated as subject also to contacts FB233.

Upon the current supplied to the generator 10 field winding increasing to a further point, coil GG225 of the fourth speed relay is energized sufficiently to cause this relay to operate. Relay GG, upon operation, engages contacts GG161. This completes the circuit for coil G160 of the 15 fourth speed switch. This switch, upon operation, engages contacts G221, G261, and G265 and separates contacts G40 and G267. Contacts G265, upon engagement, connect resistance 274 across the actuating coils FF263 and EE264 of 20 the third and second speed relays, resistance 274 acting as a cooling resistance for these coils. Contacts G267, upon separation, break the circuit through resistance 266, thereby disconnecting the generator field winding 255 from the generator armature. Contacts G221, upon engagement, short-circuit step 246 of generator field control resistance, while contacts G40 remove the short-circuit for all but a portion of section 34 of the elevator motor field control resistance. 30 The resulting increase in generator voltage and the weakening of the elevator motor field causes further increase in the speed of the elevator motor. Contacts G261 short-circuit a portion of resistance 271 in circuit with coil Z234 of the notch-back switch.

The coil Z234 of the notch-back switch is connected across the generator armature. The operation of switch Z is thus delayed until after the operation of switch G and until the generator voltage rises to a predetermined value. Upon 40 operation, switch Z engages contacts Z260 and separates contacts Z31 and Z231. Contacts Z231 control step 247 of the generator field control resistance. Contacts Z260 connect voltage coil 45 Q235 of the load switch across the generator armature. The separation of contacts Z31 removes the short-circuit for the remaining portion of resistance 34 in the circuit with the elevator motor separately excited field winding. The 50 resultant weakening of the elevator motor field causes the elevator motor to come up to full speed.

Load switch Q is provided with a current coil Q244 in addition to its voltage coil Q235. These 55 coils act cumulatively when the elevator motor is lifting above balanced load to cause the operation of the switch, the operation of the switch being delayed until after switch Z operates. The switch is provided with forward contacts Q220 60 and with back contacts Q262 and Q232. Contacts Q262 separate to insert the remainder of resistance 272 in circuit with voltage coil Q235 while contacts Q232 separate to remove a shunt for step 250 of the generator field control resistance. Resistance step 250 is maintained 65 short-circuited, however, by contacts G221. Contacts Q220 short-circuit the remaining step 245 of generator field resistance to compensate for the load conditions.

70 Governor operated switch 200 controls the governor field switch GF to provide speed regulation. Upon a predetermined amount of overspeed, governor switch 200 closes to complete the circuit for coil GF197 of the governor field switch which 75 operates to engage its contacts GF204 and GF32.

Contacts GF32 short-circuit section 35 of the elevator motor separately excited field control resistance, already cut out by contacts H41, and a portion of resistance section 34. The shunting of the portion of resistance section 34 strengthens the elevator motor field to reduce the speed of the motor. The other contacts GF204 establish a self-holding circuit for the coil GF197, maintaining the switch operated until the direction of travel is reversed. The purpose of the 10 governor field switch is served particularly under 15 full load conditions during downward travel.

As the current in the generator field winding builds up as a result of the operation of the speed switches, a point is reached where sufficient voltage is applied to coil O226 of the safety handle relay to cause the operation of this relay. Upon operation, relay O engages contacts O94 to by-pass contacts 112 of the starting switch. This arrangement permits the return of the 20 starting switch to off position without stopping the car, upon the speed of the elevator car reaching a predetermined value, say 40% of normal full speed. It also permits the car to be stopped by centering the car switch before the car reaches 25 40% normal full speed. This is particularly useful where it is desired to stop quickly in emergencies.

The coil PL236 of the direction levelling relay is connected through resistance 273 across the 30 generator armature. This relay also has a coil PL72 which is energized upon engagement of the potential switch contacts C48 and C55 through a portion of resistance 70. These coils act cumulatively during the up direction of car travel to 35 cause the operation of the relay upon the generator voltage reaching a predetermined value, say, that which it attains during an average of four feet of car travel. Once the relay is operated, it is maintained operated by coil PL72 until the car 40 starts its travel in the down direction. During down car travel, these coils act differentially. Upon the generator voltage applied to coil PL236 reaching a predetermined value, the relay is 45 caused to drop out. Upon operation, the relay engages contacts PL180 and separates contacts PL171. The purpose of these contacts is served during levelling of the car, as will be explained later.

Assume that the call previously assumed to be 50 registered was registered in response to the pressing of the up push button 295 at the seventh floor. The pressing of this button energizes coil 313 of its floor relay, the relay acting to engage contacts 349 and to separate contacts 367. Assume 55 also that a passenger has been taken into the car at the first floor and that this passenger desires to alight at the eighth floor. Upon the passenger signifying his destination, the attendant presses car button 407 for the eighth floor. This 60 button is maintained operated by car button magnet 193. Assume further that the car attains a speed of 1000 f. p. m. under full speed operating conditions. A six-floor run has been 65 assumed so that in an average installation the car will have reached substantially full speed before the car arrives at the slow down point for the seventh floor.

Upon the arrival of the car at a certain distance from the seventh floor, say fifty feet, brush 70 514 engages contact 427, rendered "alive" by the engagement of floor relay contacts 349, establishing a circuit for coil SM548 of the stop magnet. This coil neutralizes coil SM577, releasing cam 1330 and permitting the pawls to be ex- 75

tended to permit up pawl 1305 to engage the stopping lug for the seventh floor. The circuit for coil SM548 is through seventh floor relay reset coil 331 and contacts 349, bus bar UH7, contact 5 427, brush 514, contacts PA544, contacts NS545, resistance 546, contacts AS547, coil SM548 and contacts SM549. The release of the cam also effects the opening of contacts SM549, SM583, and SM586.

10 The opening of contacts SM549 and SM583 breaks the circuits for coils SM548 and SM577. The opening of contacts SM586 breaks the circuit for coil A585 of the first auxiliary stopping relay. This relay drops out, separating contacts A594 15 and A532 and engaging contacts A524 and A541. The separation of contacts A594 breaks the circuit for the advancer motor and coil B587 of the second auxiliary stopping relay. The second auxiliary stopping relay drops out to separate 20 contacts B147 and engage contacts B66. The engagement of contacts B66 prepares the automatic door opening circuit, while the separation of contacts B147 breaks the circuit for coil FB144 of the field boosting switch. The dropping out 25 of the field boosting switch to separate its contacts FB233 does not affect the running of the car as the resistance controlled thereby is maintained short-circuited by speed switch contacts, illustrated as contacts F222 of the third speed 30 switch.

The engagement of contacts A541 completes a circuit through brush 515 and contact 428 to effect the reset of the up seventh floor relay, this circuit extending through the reset coil 331 and 35 contacts 349 of the relay, contacts PB529, contacts NS540 and resistance 542. Although a circuit was completed for reset coil 331 by the engagement of brush 514 with contact 427, the amount of current supplied to this coil through 40 that circuit was not sufficient to cause the relay to be reset. The current supplied to this coil through the circuit completed through brush 515 and contact 428 by the engagement of contacts A541, however, is sufficient to reset the relay, 45 which separates its contacts 349 and reengages its contacts 367.

The engagement of contacts A524 completes the circuit for the up light 433 at the seventh floor this circuit being through contacts C376, contacts PB526, brush 523, contact 434 and contacts NS392. The up hall lantern at the seventh floor is lighted considerably before the car arrives at the seventh floor, and, under the conditions assumed, before the car has started to slow down. 50 With the equivalent of a fifty foot advance obtained by the advancer mechanism, this lamp would be lighted as soon as the car arrived at a distance fifty feet from the floor. It will be seen that where a plurality of cars are operating 55 and any one of them may respond to the registered call, a maximum duration of lighting is provided by this arrangement as the lamp is lighted as soon as the car for which it is provided is selected to be the one to make a stop in response 60 to the call, even though actual slow down does not take place until some point later. Also, there is no false or duplicate lighting of hall lanterns as the floor relay is reset at the same time the hall lantern is lighted, preventing any other car 65 lighting its corresponding hall lantern in response to the registered call.

As the car continues in motion, the up pawl 1305 engages the lug for the seventh floor, bringing the sliding carriage 1303 and rack 1302 to 70 a stop. Brush 523 is still engaged with contact

434 at this time so that the up hall lantern at the seventh floor is maintained lighted. Continued motion of the crosshead causes the pinion 1304 to ride up the rack 1302. As this movement takes place, a point is reached when selector switch 6 162 is opened. For a 1000 F. P. M. installation, switch 162 would be set to open with the car at about 29 feet from the floor. Continued movement of the crosshead opens selector switches 154, 131, 121, 57, and 102 in sequence, at predetermined distances from the landing, as the car continues its travel to the seventh floor.

10 The opening of selector switch 162 breaks the circuit for the coil G160 of the fourth speed switch. This switch engages contacts G40 and G267 and separates contacts G221, G261 and G265. Contacts G265 disconnect cooling resistance 274 from the coils EE264 and FF263. Contacts G261 reinsert the portion of resistance 271 in circuit with coil Z234 of the notch-back switch. Contacts G221 insert resistance steps 243 and 247 in circuit with the generator field winding, contacts Z231 of the notch-back switch being maintained separated. Contacts G221 also insert resistance step 250 in circuit with the generator field winding under conditions where the load switch Q has been operated. Contacts G40 short-circuit section 34 of the elevator motor field winding control resistance.

15 The weakening of the generator field and strengthening of the elevator motor field as a result of the deenergization of the fourth speed switch G causes the elevator car to slow down. The reengagement of contacts G261 reconnects generator field winding 255 to the generator armature 256 through resistance 266, this connection being such as to cause a voltage to be applied to the field winding by the generator armature of a polarity which opposes the voltage applied by the supply lines. This assists in weakening the generator field. The amount of weakening obtained in this manner is determined by the value of resistance 266, which is preferably of a high value.

20 The opening of selector switch 154 deenergizes coil F152 of the third speed switch. Switch F separates contacts F222 to remove the short-circuit for step 251 of the generator field control resistance. This causes further weakening of 25 the generator field with consequent further slow down of the elevator car.

25 The opening of selector switch 121 breaks the circuit for coil E127 of the second speed switch. This switch separates contacts E157 and E223. The separation of contacts E223 reinserts resistance step 252 of the generator field control resistance in circuit with the generator field winding. This further weakens the generator field and causes further slow down of the elevator 30 car.

35 The opening of selector switch 121 breaks the circuit for coil D117 of the first speed switch which separates contacts D170 and D224 and engages contacts D53. The separation of contacts D224 removes the short-circuit for resistance step 253 in circuit with the generator field winding, causing further slow down of the elevator car to take place. The engagement of contacts D53 connects resistance 65 across supply lines + and - in the automatic door opening circuit, this circuit extending through selector switch 51, contacts B86 and contacts H67. Selector switch 51 is arranged in shunt to coil P50 of the door operating relay and prevents ener- 40

gization of this coil to effect the opening of the door and gate at the seventh floor at this time.

Contacts D170 break the circuit for retiring magnets 166 and 167 for the levelling switches.

- 5 As a result, the leveling rollers are permitted to assume positions for cooperation with the leveling cam for the seventh floor. The car being below the seventh floor, the up leveling roller engages the seventh floor leveling cam, causing 10 contacts 82 to be maintained in engagement and also causing contacts 75 to be maintained in engagement in the event that the car is a certain distance below the floor at the time that the rollers are re-extended. Owing to the fact that the 15 down leveling roller does not engage the cam, contacts 77 and 81 are permitted to separate and contacts 83 are permitted to reengage. The reengagement of leveling contacts 83 completes the circuit for coil LU81 of the up leveling direction switch. This circuit extends through coil 20 H95 of the brake and field switch, resistance 84 and contacts LD80 of the down leveling direction switch. Assuming leveling contacts 75 to be maintained in engagement, the leveling fastspeed 25 switch LE and leveling slow down relay LZ are maintained operated.

Switch LU, upon operation, engages contacts LU175, LU181 and LU187 and separates contacts LU85. Contacts LU85 are interlock contacts arranged in the circuit for coil LD86 of the down leveling direction switch. Contacts LU175 and LU187 serve as direction contacts for the generator auxiliary field winding 184. Contacts LU181 are in series with contacts PL177 in a shunt circuit for step 186 of the control resistance for the generator auxiliary field winding. The purpose of this arrangement is served in case of an overrun of a floor in stopping during down car travel. Contacts LU175 and LU187 prepare the circuit for 40 field winding 184 but this circuit is not completed owing to the fact that contacts HG183 are separated.

Upon the opening of selector switch 57, the short-circuit for operating coil P56 of the door 45 operating relay is removed. This causes the door operating relay to operate, which engages its contacts P52 to complete the circuit for coil DO51 of the door open switch. Switch DO causes the 50 operation of the door operating mechanism to move the door and gate to open positions as the car arrives at the seventh floor. The exact setting of switch 57 is determined by the requirements of the particular installation. Switch P also separates its contacts P137 to prevent the 55 reestablishment of the circuits for any of the speed switches, once the door opening operation is initiated.

The opening of selector switch 102 occurs just 60 before the car arrives at the seventh floor. The opening of this switch deenergizes coil HG100 of the generator field switch. Switch HG opens to separate its contacts HG97, HG237, HG254, HG570, and HG599 and reengages its contacts HG183 and HG271.

The separation of contacts HG570 breaks the circuit for coils OB568 and OC569 of the starting switch sequence relays, assuming that the starting switch has been returned to neutral. Relay 65 OC separates contacts OC136 and OC576 and reengages contacts OC91 and OC580 and relay OB reengages contacts OB62.

The separation of contacts HG237 and HG254 disconnects the generator main separately excited field winding 255 from the supply lines. At 70

the same time, however, the generator auxiliary separately excited field winding 184 is connected to the supply lines by contacts HG183. The excitation of the generator is now effected through the auxiliary field winding 184. Switch Y is also operated as a result of the engagement of contacts HG183 and separates its contacts Y230 to disconnect resistance 227 in parallel with the generator series field winding 242. This 10 strengthens the field of the generator for the leveling operation. The engagement of contacts HG271 connects resistance 276 in parallel with resistance 266 in the circuit connecting the generator field winding 255 to the generator armature. This causes stable operation to be obtained 15 during operation of the car on the auxiliary field winding. It minimizes the effects of residual flux by causing the main field winding to provide a magnetomotive force which opposes that due to field winding 184 and which increases upon any 20 tendency of the generator armature voltage to increase and thus decreases the net magnetizing force, and vice versa, thus producing a state of substantial equilibrium.

Assuming that the car is in the fast speed leveling zone at the time that contacts HG183 engage, contacts LE191 are in engagement, short-circuiting resistance section 186 and a portion of section 185, causing the car to travel at a fast leveling speed. As the car runs from the fast speed to the slow speed leveling zone, contacts 75 are separated, deenergizing fast speed leveling switch coil LE74 and coil LZ73 of the leveling slow-down relay. Switch LE drops out to separate its contacts LE191. This removes the short-circuit for sections 185 and 186 of the control resistance for field winding 184, decreasing the generator voltage and causing the car to run at a slow leveling speed.

Relay LZ is delayed in dropping out after the breaking of the circuit for its coil, as by a dash pot (see Figure 23). The purpose of this arrangement is to minimize the possibility of overruns during stopping operations due to the time constant of the auxiliary field winding 184. The insertion of both resistance sections 186 and 186 as the car enters the slow speed zone decreases the voltage applied to the field winding to a sufficiently low value to obviate the effect of the lag of the field, thus insuring the desired retardation. The later reengagement of contacts LZ192 short-circuits section 186 to insure the generation of sufficient voltage to bring the car to the floor.

Just before the car reaches the exact level with the seventh floor landing, leveling contacts 82 are separated. The circuit for coils H95 and LU81 is thus broken. Switch H drops out, causing the separation of contacts H41, H67, H171, H205, and H211 and the engagement of contacts H210, H270, and H615. The separation of contacts H171 deenergizes series field switch Y to effect the reengagement of contacts Y230. The separation of contacts H67 breaks the circuit for coil P56. This cannot interrupt the opening of the door and gate, however, as contacts P52 are latched in engagement. The separation of contacts H205 and H211 breaks the circuit for the brake release coil 214. This causes the brake to be applied, which reengages its contacts 186 to short-circuit coil BK203, thus causing brake resistance relay BK to drop out. The separation of contacts H41 reinserts resistance section 35 in circuit with the elevator motor field winding, reducing the current therein to a "standing field" 75

value. The reengagement of contacts H270 short-circuits resistances 266 and 276 in the circuit connecting the generator field winding 255 to the generator armature. This increases the effect of armature 256 on field winding 255 substantially to destroy the residual flux of the generator field.

Up levelling direction switch LU, dropping out simultaneously with switch H, separates contacts LU175, LU181, and LU187. The separation of contacts LU175 and LU187 disconnects the generator auxiliary field winding 184 from the supply lines.

Thus, the brake being applied and the generator separately excited field windings being disconnected from the supply lines, the car is brought to rest with the car in exact alignment with the seventh floor landing. The reengagement of contacts H210 connects resistance 207 in parallel with resistance 213 across coil 214, softening the final application of the brake.

Should an overrun occur, circuits are completed to return the car to the seventh floor landing level. Assume that an overrun occurs into the slow speed levelling zone. This results in the engagement of levelling contacts 87 to complete a circuit for coils H95 and LD86 of the brake and field switch and down levelling direction switch respectively, levelling interlock contacts 90 now being in engagement. Switch H operates to effect the release of the brake, to remove the short-circuit for resistances 266 and 276, to strengthen the field of the elevator motor and to cause the shunt circuit for the generator series field winding to be broken. Switch LD engages contacts LD174, LD182 and LD190 and separates contacts LD80. Contacts LD80 are interlock contacts corresponding with contacts LU85. Contacts LD174 and LD190 connect the generator auxiliary field winding 184 to the supply lines. Due to the reversal of the flow of current through this winding from that during the levelling operation upon the car approaching the floor in the up direction, the car is caused to start in the down direction. As the car returns to the floor, it is stopped by the separation of levelling contacts 87 in a manner similar to that described for the approach of the car to the floor in the up direction.

If the overrun extends into the fast speed levelling zone, levelling contacts 77 as well as levelling contacts 87 are engaged. The engagement of contacts 77 causes the operation of levelling slow down relay LZ and of levelling fast speed switch LE which engages its contacts LE181 to short-circuit section 186 and a portion of section 185 of the control resistance for field winding 184. This increases the generator voltage, causing the elevator motor to run at a fast levelling speed. As the car returns to the slow speed levelling zone, switch LE is dropped out, reinserting a portion of resistance 185 in circuit with field winding 184. Owing to the fact that relay LZ is delayed in dropping out, the separation of contacts LE191 also removes the short-circuit for resistance section 186. At this time contacts LD182 as well as contacts PL180 are in engagement so that a resistance 176 of relatively low value is connected in parallel with resistance 186. This compensates for the effects of hysteresis to cause field winding 184 to create a magnetizing force for the slow speed levelling operation in the slow speed zone which is sufficient to insure the continued return of the car to the floor. Contacts PL177 and LU181 serve a similar

purpose in case of an overrun during down car travel.

In the above described slow-down operation, it was assumed that the starting switch had been returned to off position. In the event that this switch is held in full running or intermediate position, the starting switch sequence relay OC insures the slowing down of the car and bringing it to a stop, and the opening of the gate and door. Assume in the above example where the car is brought to a stop at the seventh floor, that the starting switch is held in either full running or intermediate position during the slow-down operation. Upon the separation of contacts HG570, coils OB568 and OC569 of the starting switch sequence relays are not deenergized, owing to the fact that a circuit remains established for these coils through contacts OC576 and starting switch contacts 581. Thus, relay OC does not drop out, maintaining separated its contacts OC580 in the circuit for coil SM577 of the stop magnet. This prevents energization of coil SM577 by way of starting switch contacts 581 and therefore prevents the reoperation of the stop magnet. Also, contacts OC580 prevent the establishment of a circuit through starting switch contacts 581 for coil P575 of the door operating relay to prevent the latching of contacts P52 in engaged condition, which would prevent the opening of the door and gate. It is to be noted that with this arrangement, the starting switch must be returned to off position before the reclosing of the door and gate, and the restarting of the car, can be effected.

The steps of resistance in the circuit for the generator main field winding 255 are proportioned to suit the requirements of the particular installation, both as regards the time for bringing the car up to speed and the smoothness of the starting operation. For retardation, in order to cause the car to slow down in the desired time interval, which may be less than the time interval for acceleration, the short-circuit for resistance step 247 is removed by contacts Z231 of the notch-back switch, to permit a larger amount of resistance to be reinserted in the generator field winding circuit upon the separation of contacts G221.

The load switch Q, by means of its contacts Q232, assists in bringing the car to an accurate stop under different conditions of load.

The safety handle relay O is arranged to hold in until after the separation of contacts HG237 and HG254, being assisted by the action of generator field discharge resistance 240. This insures the deenergization of coil HG100 by selector switch 102.

Assume that the intending passenger at the seventh floor is taken into the car. Assume further that he desires to be taken to the tenth floor, and so informs the car attendant. The attendant presses the tenth floor car button 381 and moves the starting switch to full start position. This initiates the operation of the door operating mechanism to close the gate and door at the seventh floor. It also energizes the stop magnet SM to retract the pawls 1304 and 1305, and to cause the operation of relay A. Relay A separates its contacts A524 to extinguish the lighted hall lantern at the seventh floor and engages contacts A594 to cause the operation of the advance motor to advance the brushes.

The eighth floor car button 407 has also been pressed, under the assumed conditions, to cause a stop at the eighth floor for the passenger

who was taken into the car at the first floor. This button connects selector contact 408 to the negative supply line, rendering this contact "alive". Contact 408 is engaged by brush 507 5 as the advancer motor advances this brush in response to movement of the car starting switch to full operated position. This engagement completes a circuit for coil SM548 of the stop magnet, causing the release of the pawls and 10 the separation of contacts SM566 to deenergize relay A. Relay A separates contacts A594 to bring the advancer motor to a stop. Brush 523 is in engagement with contact 420 at this time so that the reengagement of contacts A524 15 completes a circuit for lamp 419 at the eighth floor, causing the up eighth floor hall lantern to be lighted. Owing to the fact that the car is started when the door and gate close, this arrangement causes the lighting of the hall lantern 20 to take place, under the conditions assumed, before the car is actually started from the seventh floor. In fact, the hall lantern is lighted almost immediately the starting switch is thrown to start position, thereby getting maximum duration of the advisory signal at the 25 eighth floor landing.

During the advance of the brushes, selector switches 102, 51, 121, and 131 are closed but selector switches 154 and 162 are set so as not 30 to be closed during a one-floor run in an installation operating at 1000 F. P. M. Thus, upon the reclosure of the gate and the seventh floor hatchway door, the car is started and speed switches D and E are operated to cut out steps 35 of generator field control resistance. The field boosting switch FB is also operated to engage its contacts FB233 which short-circuit an additional portion of the generator field control resistance. Coil FB144 of this switch is energized 40 by the momentary engagement of contacts B147 of relay B engaged as a result of the momentary operation of relay A. The field boosting switch remains operated after contacts B147 open, as a result of the engagement of the eighth floor 45 contact by the brush, by its holding contacts FB140. Thus the field of the generator is forced, under the conditions assumed, as well as under conditions where full brush advance is obtained during the starting operation.

50 As the car moves up the hatchway, up pawl 1305, which has been advanced along with brush 507, engages stopping lug 1306 for the eighth floor and, upon continued movement, causes the opening of selector switch 131. The third speed 55 relay FF is adjusted to operate just before selector switch 131 is opened. The operation of relay FF causes the dropping out of switch FB and the opening of switch 131 causes the dropping out of switch E. These switches reinstate 60 resistance in circuit with field winding 255, causing the car to slow down. The car is thereafter further slowed down and finally brought to a stop at the eighth floor landing, the car gate and hatchway door for that floor automatically opening as the car is brought to rest, as 65 previously described.

The above examples of operation show that when the brushes do not meet a live contact during their advance in response to movement 70 of the starting switch to full operated position, the advancer mechanism is brought to a stop by the engagement of the advancer carriage with one of its collars, the advancer motor being maintained energized, whereas when an "alive" 75 contact is engaged by a brush during the ad-

vance, the advancer motor is deenergized and the mechanism is brought to a stop at that point.

After the passenger has been discharged at the eighth floor, the attendant moves the starting switch to full start position. The lighted hall lantern at the eighth floor is extinguished during the starting operation as a result of the operation of relay A. Should the up hall button at the eighth floor be pressed after the starting switch has been operated, contacts AS547 10 insure that this button does not cause a stop at the ninth floor, these contacts remaining open until considerably after the disengagement of brush 514 from contact 413 for the eighth floor is assured. Assume that this button is not 15 pressed and only the tenth floor car button remains to be responded to. The brush advance motor is operated in response to operation of the starting switch and is brought to a stop upon engagement of brush 507 with contact 382 for 20 the tenth floor, this contact being independent of tenth floor car button 381, which serves to insure the car being brought to a stop at the upper terminal floor. Also, relay A reengages contacts A524 to complete the circuit through selector contact 390 for the hall lantern at the 25 tenth floor. Upon the closure of the car gate and eighth floor hatchway door, the car is re-started in the up direction.

The car is slowed down and stopped at the tenth floor by the action of the terminal stopping switches 156, 143, 126, 116, and 93. The selector switches are opened as a result of the engagement of brush 507 with contact 382. These terminal stopping switches are as a matter of safety set to act ahead of the selector switches, the latter being utilized to insure the slow down and stopping action. In case of the run from the eighth to the tenth floor in a 1000 F. P. M. installation, terminal stopping switch 156 is opened before the eighth floor is reached. 40

The opening of the door and gate at the upper terminal is effected in a manner similar to that previously described. Owing to the fact that the car is running very slowly during the latter part of the slow down operation at the upper terminal, due to the opening of the terminal stopping switches ahead of the selector switches, the short-circuit for coil P56 is maintained by the engagement of brush 64 with contact 63 until a certain point is reached, thereby avoiding premature opening of the door and gate. 45

As the car arrives at the upper terminal, brush 621 engages selector stationary contact 610. 55 Thus, upon the reengagement of contacts H615 and AS616 as the car is brought to a stop, a circuit is completed for restoring coil PU613 of the up direction switch and for operating coil PD612 of the down direction switch. This causes reset of the up direction switch and the latching of the down direction switch in operated condition. Upon the latching of the down direction switch being effected, contacts PD611 are separated, breaking the circuit. Switches PU and PD are preferably mechanically interlocked, as by a walking beam. This insures the reset of switch PU before latch contacts PD611 separate. Discharge resistance 609 in shunt to coils PD612 and PU613 acts to absorb any arc incident to the 60 separation of contacts PD611. 65

Upon the reset of the up direction switch PU, contacts PU92, PU195, PU216, PU281, and PU591 are separated and contacts PU128, PU134, PU150, and U164 are engaged. Upon the oper- 75

ation of down direction switch PD, contacts PD110, PD201, PD217, PD280, and PD592 are engaged and contacts PD115, PD125, PD142, and PD155 are separated.

5 The separation of contacts PD111 also breaks the circuit for auxiliary direction switch coils PA603 and PB604 and for auxiliary up direction switch coil AU608. Auxiliary direction switch PA, upon dropping out, separates its contacts 10 PA544 and reengages its contacts PA550. Auxiliary direction switch PB, upon dropping out, separates contacts PB526 and PB539 and reengages contacts PB525 and PB543. Auxiliary up direction switch AU, upon dropping out, separates its contacts AU371 and AU534.

Contacts PU92 and PD110 are for the purpose of insuring the dropping out of switch HG by the terminal stopping device switches at the terminals and permitting reoperation of switches 20 H and HG to effect starting of the car in the opposite direction. Contacts PD115 and PU123, PD125 and PU134, PD142, and PU160, and PD155 and PU164 serve a similar purpose in connection with the operation of speed switches 25 D, E, F, and G at the terminals. The separation of contacts PU195 and subsequent engagement of contacts PD201 causes the deenergization and subsequent energization of car button magnet 193. This releases all pressed car buttons to open circuit condition and renders the magnet effective to maintain subsequently pressed car buttons in operated condition. The separation of contacts PB526, PB509, and PA544 opens the circuits to brushes 523, 515, and 514 30 respectively while the simultaneous engagement of contacts PB525, PB543, and PA550 prepares the circuits to brushes 519, 511 and 510 respectively. Inasmuch as brush 519 is in engagement with selector stationary contacts 388 with the 40 car stopped at the upper terminal, the circuit for the down hall lantern at the tenth floor is transferred from up brush 523 to down brush 519 as a result of the operation of auxiliary direction switch PB.

45 It is to be noted that the circuit for the coils of the direction switches extends through contacts AS616 of the auxiliary speed relay. These contacts act to prevent the reversal of the direction of car travel if for any reason the advancer mechanism is in an advanced condition. Contacts AS579 of this relay act to prevent the starting of the car if the advancer mechanism is in an advanced condition.

The closing of the car gate and hatchway door 55 and the starting of the car from the upper terminal are effected in a manner similar to that described for starting the car in the up direction. Movement of the car starting switch to full running position causes the retraction of the pawls, 60 the operation of the advancer motor to advance the brushes, cam 598 and pawls and close selector switches 102, 57, 121, 131, 154, and 162, and the closing of the gate and door. The circuit for the brush advancer motor is through field winding 65 588, armature 589 and field winding 590 connected in parallel by contacts PD592. Thus, current is supplied to the advancer motor armature in a direction which is the reverse of the direction in which current was supplied thereto in starting 70 the car in the up direction, so that the brushes are advanced downwardly instead of upwardly. Upon engagement of gate contacts 103 and door contacts 104, the circuit for the coils of switches H and HG is completed. Switch H causes the brake 75 to be released and switch HG causes current to be

supplied to generator field winding 555. The current through the field winding is reversed as a result of the operation of the direction switches PU and PD to cause contacts PU216 and PU201 to be separated and contacts PD217 and PD280 to be in engagement so that the car is started in the down direction. Otherwise the operation of the system to start and accelerate the car is the same as that previously described, the circuits for the coils of the speed switches being through back contacts of up direction switch PU instead of through the back contacts of down direction switch PD, and through contacts 124, 138, 151, and 165 of the terminal stopping switch instead of contacts 116, 126, 143, and 158.

The circuits illustrated for the advancer motor are for providing constant speed of the motor during the advancing operation. The field windings 588 and 590 act cumulatively, one being connected across the armature so that any increase in load on the motor, due to misalignment of selector contacts or otherwise, tending to decrease the speed of the motor, would, by a lowering of the counterelectromotive force of the motor, weaken the field winding subject thereto. This would counteract the tendency to decrease the speed of the motor, maintaining the speed substantially constant. The point at which the motor armature is connected to resistance 598 may be changed so as to adjust for the desired speeds for the different directions of rotation of the motor. The portion of this resistance used for each direction is connected in parallel with the motor armature and field winding in series with the armature, and any change in the value of this resistance, in conjunction with resistance 588, alters the voltage applied to the motor. For example, for down car travel, a decrease in the value of the portion of resistance 598 connected in parallel to field winding 588 and armature 589 decreases the voltage applied to the motor and thus causes it to run at a slower speed.

Stopping in response to down push buttons at the landings during downward car travel is effected in a manner similar to that in which stops are made in response to up push buttons during upward travel. Assume that, with the car positioned at the upper terminal, the down sixth floor hall button 292 is pressed. This completes a circuit for operating coil 340 of the down sixth floor relay. This relay latches contacts 346 in engagement and contacts 363 in separated condition. The engagement of contacts 346 renders selector stationary contacts 439 and 440 "alive".

Upon the engagement of contact 439 by brush 510 as the brushes are advanced in the down direction incident to the operation of starting the car from the upper terminal, a circuit is completed for neutralizing coil SM548 of the stop magnet. Thus, the pawls are released to permit the down pawl to engage the stopping lug for the sixth floor and contacts SM566 open to break the circuit for coil A585 of the first auxiliary stop relay. This relay acts through its contacts A594 to bring the advancer motor to a stop, through its contacts A541 to cause sufficient voltage to be applied to reset coil 328 of the down sixth floor relay to cause this relay to be reset, and through its contacts A520 to complete the circuit for lamp 466, lighting the down lantern at the sixth floor.

As the car continues its downward motion, down pawl 1004 engages the lug for the sixth floor and cooperates therewith to cause the opening of the selector switches to slow down the car and finally bring it to a stop at the sixth floor. It is

believed that the operations involved will be readily understood, from previously described slow down and stopping operations in the up direction, and need not be described in detail.

5 Response is had to car buttons during downward travel of the car in a manner similar to that in which response is had to car buttons during upward travel. The pressing of any car button renders the corresponding selector stationary contact in the column including contact 403 "alive". The engagement of "alive" car button stationary contacts by brush 507 causes the car in its downward travel to be slowed down and finally brought to a stop at the floor corresponding to the button pressed.

The door and gate opening operation during stops in the down direction is effected in the same manner as described for stops in the up direction.

20 The car is slowed down and stopped at the lower terminal in its downward travel by the action of terminal stopping switches 166, 151, 128, 124, and 111. The selector switches, as in the case of a stop at the upper terminal floor, are utilized to insure the slow down and stopping 25 operation, selector contact 506 for the lower terminal being connected to the minus supply line. The opening of the door and gate at the first floor is effected in the same manner as this 30 operation was effected at the upper terminal floor. The short-circuit for coil P56 being maintained by the engagement of brush 84 with stationary contact 71 until the car arrives at the desired point in relation to the first floor.

35 As the car arrives at the lower terminal, brush 621 engages stationary contact 620. Thus, upon the reengagement of contacts H610 and AS616, as the car is brought to a stop, a circuit is completed for restoring coil PD619 of the down direction switch and for operating coil 40 PU618 of the up direction switch. This causes reset of the down direction switch and the latching of the up direction switch in operated condition. Resistance 622 acts to absorb any arc incident to the separation of contacts PU617. The 45 operation of switches PU and PD just described places the direction controlling circuits in the same condition as originally described, with the car positioned at the first floor. The car button magnet 193 is deenergized and reenergized by 50 the separation of contacts PD201 and the engagement of contacts PU195. This releases all pressed car push buttons and again renders the magnet effective to maintain subsequently pressed car buttons in operated condition.

55 The hall lantern 521 at the first floor is lighted upon the engagement of brush 519 with contact 520 and the dropping out of switch A. The operation of auxiliary direction switch PB incident to the change in the direction control circuits causes the circuit for this lamp to be transferred to contact 522 and brush 523 as the car arrives at the first floor by the separation of contacts PD525 and the engagement of contacts PD526.

65 Since the car buttons are maintained operated, once pressed, by car button magnet 193, the corresponding selector stationary contacts are maintained "alive" during this time. Thus, response is had to car buttons during travel of the 70 car in either direction, in the natural order of floors, regardless of the order in which the buttons are pressed. Also, response is had to each car button pressed during a run from one terminal to another, so long as brush 507 has not passed the selector stationary contact to which

the button is connected at the time that the button is pressed. The hall buttons, once pressed, cause the operation of corresponding floor relays. Since these relays are latched in operated condition, the corresponding selector stationary contacts are maintained "alive" until the relays are reset, i.e., until the call is answered. With this arrangement, stops are made in the natural order of floors regardless of the order in which the hall buttons are pressed. Also, the call is 10 answered upon the next approach of the car to the landing at which the button is located, traveling in the direction corresponding to the button pressed, so long as the selector brushes have not passed the corresponding selector stationary contacts for the floor at which the button is located at the time the button is pressed. As distinguished from car button operation, the selector stationary contacts controlled by the hall buttons are not rendered "dead" at the terminals, so that the call is ultimately responded to. 15 20

In the description up to this point, it has been assumed that the car ran to the terminals before reversing. The system is arranged, however, so that with service switch 373 closed and with the direction controlling mechanism set for up car travel, the direction of car travel is reversed automatically at any floor under conditions where, at the time circuits are set up which cause the car to be slowed down and brought to a stop at that floor, no push buttons are pressed which require further travel in the up direction. This also involves stopping the car in its upward travel in response to a down hall 30 button under conditions where no push buttons for floors above or the up push button at that floor are operated at the time the circuits are set up for causing the car to be slowed down and stopped at the floor at which the down button is located. 40

The highest operated push button may be a car button, an up hall button or a down hall button. While an up push button may be the highest one pressed, it also indicates that the prospective passenger desires to be carried in the up direction. Under such conditions the direction controlling mechanism remains set for up car travel in answering this button so that the car is started in the up direction after taking on the passenger who pressed the button. In case of a car button or down hall button, however, there is no indication for further travel in the up direction. The pressing of a down hall button indicates a desire to be carried in the down direction while the pressing of a car button indicates no further use of the car after the button has been answered. Therefore, in case the highest operated push button is a car button or a down hall button at the time the circuits are initially set up for answering the button, the direction controlling mechanism is operated automatically to change the direction of car travel to down when the car is brought to a stop. 50 55 60

In the arrangement of circuits illustrated, these operations are accomplished principally by the selector brush switches 395-494 and operating insulated cam 508, selector contacts 387-518 and cooperating brush 517, back contacts of the floor relays, and circuits and switches controlled thereby. The floor brush switches 395-494 are connected in series and are controlled individually by the car buttons to control the energization of topmost car call relay TC. The back contacts of the floor relays are also arranged in 70 75 80 85 90 95

series relation from the back contacts of the down second floor relay, through the back contacts of the up second floor relay, and likewise through those of the floor relays for each succeeding floor above in the same sequence, the back contacts of the upper terminal floor relay being connected to the negative line. Connections are taken off between the back contacts of the down and up floor relays for each floor and 10 led to a stationary contact on the selector for that floor in the column of contacts engaged by brush 517. This arrangement controls the energization of the topmost hall call relay TH.

The operation of the system to automatically reverse the direction of car travel at intermediate floors will now be described. Assume the car positioned at the ground floor with service switches 365 and 373 closed. While the car is standing at the ground floor switch AU is operated, causing its contacts AU377 and AU334 to be in engagement. If no hall push button is operated, all floor relay back contacts are in engagement so that contacts AU534 complete a circuit for coil TH533 of the topmost hall call relay. This circuit is through brush 517 and contact 516 of the selector and back contacts 365-372 of the floor relays. Relay TH, upon operation, separates its contacts TH378 so that the engagement of contacts AU377 only prepares the circuit for lamp 379. The engagement of contacts TH531 prepares the circuit for coil AR529 of the automatic reversal relay.

Assume now that the down seventh floor hall button 294 is pressed and that no other push buttons are operated. The pressing of this button completes the circuit for coil 312 of the down seventh floor relay, which latches its contacts 366 in engagement, and its contacts 366 in separated condition. The separation of contacts 366 breaks the circuit for coil TH536, which drops out to engage its contacts TH378, completing a circuit for lamp 379 in the elevator car. This lamp is for advising the attendant as to the direction of car travel. So long as the lamp stays lighted the car will start from any intermediate floor in the up direction.

The car is started as before by moving the starting switch in the car to full operated position. Selector switch 607 closes as a result of the operation of the advancer mechanism, this switch being operated by insulated cam 503 which operates the floor brush switches in the circuit for the coil of topmost car call relay TC. The switch is engaged by the cam causing the switch to be open while the car is idle at the first floor. As the advancer mechanism operates in starting, the cam is moved upwardly, disengaging the switch and permitting it to close. The closing of switch 607 completes the circuit for coil UL636 of the up indicator light relay. Relay UL engages contacts UL375 to by-pass contacts TH373 in the circuit for lamp 379. It also engages contacts UL333 in the circuit for coil AR529 of the automatic reversal relay.

When brush 517 engages selector stationary contact 429, a circuit is reestablished through back contacts 367-372 of the floor relays for coil TH536 of the topmost hall call relay. This relay engages contacts TH371, completing a circuit for coil AR529 of the automatic reversal relay. Relay AR, upon operation, engages contacts AR527 to establish a self-holding circuit and also engages contacts AR531 and AR514 and separates contacts AR602. The separation of contacts AR602 breaks the circuit for coils PA603 and PB604 of the auxiliary direction relays, these relays drop-

ping out to separate contacts PA544, PB539, and PB526 and to engage contacts PA550, PB543, and PB525. The engagement of contacts AR551 completes the circuit for neutralizing coil SM548 of the stop magnet, which causes the dropping out of first auxiliary stopping relay A and releases the pawls to permit the engagement of the stopping collar for the seventh floor by the up pawl 1305. Brush 517 is set sufficiently ahead of brushes 514 and 515 to insure the release of the pawls in time for the up pawl to engage the proper stopping collar.

Relay A, upon dropping out, separates contacts A594 to deenergize the brush advancer motor. It also engages contacts A541, completing a circuit through contacts PB543, brush 511, selector contact 426 and contacts 348 for reset coil 330 of the down seventh floor relay to restore the relay to reset condition. It also engages contacts A523, completing the circuit through contacts PB526 for lamp 432, lighting the down hall lantern at the seventh floor.

Continued movement of the car after the up pawl has engaged the seventh floor stopping collar causes the car to be slowed down and finally brought to a stop at the seventh floor landing. Owing to the engagement of contacts AR614, a circuit is established for the operating coil PD612 of the down direction switch and reset coil PU613 of the up direction switch, upon the reengagement of contacts H615 as the car comes to rest, to cause the operation of these switches to reverse the direction of car travel. The separation of contacts PD611 of the down direction switch, incident to the change in the direction controlled circuits, breaks the circuit for coil UL636 of the up indicator light relay. Relay UL separates its contacts UL323 to deenergize coil AR529, causing the automatic reversal relay to drop out. Relay UL also separates its contacts UL375, breaking the circuit for the direction indicating lamp 379 in the car. This advises the car attendant that the car is now set for travel in the down direction. The car is started in the down direction in response to movement of the starting switch in the car to full start position because contacts PD289 and PD217 are in engagement, causing the direction of current flow in field winding 255 to be such as to cause the car to run in the down direction.

Assume that the button pressed while the car is idle at the first floor is a car button instead of a down hall button; that is, assume, for example, that the seventh floor car button 422 is pressed and that no other push buttons are operated. With no hall push buttons operated, the topmost hall call relay TH is operated, engaging its contacts TH371 and separating its contacts TH373. Each of the car buttons is connected through its floor brush switch and the floor brush switches for floors above to the coil of topmost car call relay TC so that the pressing of car button 422 not only renders selector stationary contact 429 "alive" but also completes a circuit through selector switches 414, 416 and 395 for topmost car call relay coil TC533. This relay operates to engage contacts TC530 and separate contacts TC531. Contacts TC530 are in the circuit for coil AR529 of the automatic reversal relay, their separation preventing the energization of this coil as a result of the closing of selector switch 607 and contacts AS633 during the operation of the advancer mechanism in starting the car from the first floor. The engagement of contacts TC530 completes a circuit for lamp 379 in the

elevator car, advising the attendant of the direction of car travel.

- The car is started as before by moving the starting switch in the car to full operated position. Relay UL operates to establish a by-pass circuit for lamp 379. When insulated cam 508 engages and opens selector brush switch 424 for the seventh floor, the circuit for coil TC553 of the topmost car call relay is broken. This relay 5 drops out to reengage its contacts TC530. The topmost hall call relay TH is operated intermittently as brush 517 engages each of its cooperating stationary contacts during upward movement of the brush. Thus, this relay is operated to engage its contacts TH531 upon the engagement of brush 517 with seventh floor contact 429. This occurs at the same time that relay TC is dropped out so that the engagement of contacts TC530 completes a circuit for the coil of the automatic reversal relay AR. Relay AR operates as previously described to cause the dropping out of auxiliary direction relays PA and PB and the completion of the circuit for the neutralizing coil of stop magnet SM. The stop magnet acts to 10 drop out auxiliary stopping relay A and release the pawls. Relay A deenergizes the brush advancer motor and completes the circuit for lamp 432, lighting the down hall lantern at the seventh floor.
- Continued movement of the car after the engagement of up pawl 1305 with seventh floor stopping lug causes the car to be slowed down and finally brought to a stop at the seventh floor landing. Owing to the engagement of contacts 15 AR614 of the automatic reversal relay, the direction switches PU and PD are operated upon the reengagement of contacts H615 as the car comes to rest to reverse the direction of car travel. The direction indicating lamp 379 is extinguished by 20 the separation of contacts UL375 incident to the reversal of the direction of car travel, advising the car attendant that the direction controlling mechanism is now set for down car travel.

Assume the button pressed while the car is idle 25 at the first floor to be an up hall button instead of a car button or a down hall button. Assume that the up hall button 297 at the eighth floor is the one pressed and that no other push buttons are operated.

- The pressing of this button energizes coil 315 of the up eighth floor relay, which latches its contacts 351 in engagement and its contacts 369 in separated condition. The separation of contacts 369 breaks the circuit for coil TH536, which 30 completes the circuit for lamp 379 as before. When the car has been started in the up direction and brush 517 engages selector stationary contact 415 for the eighth floor, the circuit for coil TH536 of the topmost hall call relay is not 35 reestablished, owing to the fact that contacts 369 still maintain this circuit open. However, the engagement of brushes 514, 515, and 523 with contacts 413, 414 and 420 causes the up eighth floor hall lantern 419 to be lighted, the up eighth floor relay to be reset, and the car to be slowed down and brought to a stop at the eighth floor landing.

When the up eighth floor relay is reset, its contacts 369 reengage and complete a circuit for 40 coil TH536 of the topmost hall call relay. Relay TH engages its contacts TH531, but this does not complete the circuit for coil AR529 of the automatic reversal relay as the reset of the up eighth floor relay to cause the operation of relay 45 TH was effected by the dropping out of auxiliary

stopping relay A which, when it dropped out, separated its contacts A532 and thus prevented the energization of coil AR529 by the engagement of contacts TH531. The separation of contacts TH378 does not break the circuit for lamp 379 in the car as this lamp is maintained lighted by contacts UL375. Thus the car attendant is advised that the direction controlling mechanism is still set for travel in the up direction. 5

Assume that the intending passenger at the eighth floor who pressed the up eighth floor hall button is taken into the car and advises the car attendant that he desires to be carried to the ninth floor. The car attendant therefore presses the ninth floor car button 393, which causes the 15 energization of coil TC553 of the topmost car call relay. Relay TC engages contacts TC380 paralleling contacts UL375 in the circuit for lamp 379, and separates its contacts TC530 in the circuit for coil AR529 of the automatic reversal 20 relay.

Movement of the starting switch to full operated position causes operation of the brush advancer motor to advance the brushes and cam 508 in the up direction. The engagement of cam 25 508 with selector switch 395 breaks the circuit for coil TC553, which completes the circuit for coil AR529 of the automatic reversal relay. This relay operates, as previously described, to cause the dropping out of auxiliary direction relays PA 30 and PB and the completion of the circuit for the neutralizing coil of stop magnet SM. The stop magnet acts to drop out auxiliary stop relay A and release the pawls. Relay A deenergizes the brush advancer motor and completes a circuit for lamp 403, lighting the down hall lantern at the ninth floor. Up pawl 1305 being extended for cooperation with the ninth floor stopping collar, causes the car, after being started, to be slowed down and brought to a stop at the ninth 40 floor landing. When the car is brought to a stop, the direction switches are operated to reverse the direction of car travel. The direction indicating lamp 379 is extinguished by the operation of contacts UL375 incident to the reversal 45 of the direction of car travel, advising the car attendant that the direction controlling mechanism is now set for down car travel.

In case an up hall button is pressed at the highest floor for which a push button is operated, the direction controlling mechanism is maintained set for up car travel even though a car button or down hall button for that floor is also pressed. This is due to the fact that contacts A532 separate before contacts TH531 engage. However, the direction controlling mechanism is operated to reverse the direction of car travel when both the car button and the down hall button are pressed at a floor for which circuits have been set up to cause a stop to be made in case no push buttons are pressed for any floor above. Both contacts TC530 and TH531 must be in engagement at the same time in order for automatic reversal to take place and, in case of contacts TH531, they must be reengaged before contacts A532 separate. 50 55 60 65

It is believed that it will be seen from the above description that where several up hall buttons or car buttons or both have been pressed, the car will continue to travel in the up direction until all of these push buttons have been responded to and that, in case the push button pressed at the last floor at which a stop is made is an up push button, the car will remain set for up car travel 70 75

when it arrives at the floor at which the highest operated up hall button has been pressed.

There is a remote possibility that the person who presses the highest of the operated up hall buttons changes his mind, and does not desire to use the car. There is no way that this can be ascertained either by the car attendant or by the automatic mechanism which controls the operation of the elevator car. Therefore, the up hall lantern at the particular floor is lighted in the usual manner and the direction indicating light in the car remains lighted, advising the car attendant that the car is still set for up car travel. It is desirable that the car should leave the floor in the up direction under such conditions, since, as there is no way for the automatic controlling mechanism to register the change in intentions of the intending passenger, the car attendant would be unable to tell from the direction indicating light whether this light is lighted as a result of the registration of the call at that floor or as a result of the registration of a call for a floor above. With no calls above, however, the car is caused to slow down and stop at the next landing before its direction of travel is reversed.

In order that this may be more clearly understood, assume that the intending passenger who pressed the up eighth floor hall button in the example of operation previously assumed changes his mind and does not desire to use the car. Assume further that he has left the corridor so that there is no passenger to be taken into the car at the eighth floor when the stop is made. Confronted with this condition, the operator can only move the car switch to start position again to restart the car. The topmost hall call relay TH can be in operated condition only at a time that brush 517 is in engagement with one of its cooperating stationary contacts. The advance mechanism causes this brush to leave the stationary contact for the floor at which the car is stopped before the operation of auxiliary speed relay AS in the starting operation. This prevents the operation of automatic reversal relay AR before the engagement of brush 517 with the stationary contact for the next floor above. Thus, in the above example with the car stopped at the eighth floor, brush 517 leaves contact 415 before the engagement of contacts AS533, causing the dropping out of relay TH to separate contacts TH531 and thereby prevent the energization of coil AR529. Upon the engagement of brush 517 with the ninth floor contact 400, relay TH is again operated, completing a circuit for coil AR529. The automatic reversal relay thereupon operates to cause the lighting of the down hall lantern at the ninth floor, the slowing down and stopping of the car at the ninth floor and the reversal of the direction of car travel. Thus, under the abnormal conditions assumed, the car stops at the next possible floor and sets its direction controlling mechanism for the opposite direction of car travel.

In the case where a down hall button has been pressed, the car stops to answer up hall buttons at floors intervening the floor from which the car started and the one at which the down button is located, and to discharge passengers at such intervening floors in response to car buttons, but does not stop at such intervening floors in response to down hall buttons. A stop is made in response to a down hall button when no buttons for floors beyond have been pressed by the action of selector brush 517 and cooperating contacts and the floor relay back contacts above the

contacts of the floor relay for the operated down hall button in completing a circuit for the coil of topmost hall call relay TH. Should any hall button, for a floor above the one at which an operated down hall button is located, be operated or should the up hall button at the floor at which such down hall button is located be operated, the circuit for coil TH536 is not completed when brush 517 engages the selector stationary contact for that floor. In case a car button is pressed for a floor above, the topmost car call relay is operated, preventing the operation of relay AR in response to the engagement of contacts TH531, thereby preventing the slowing down and stopping of the car in response to the down hall button. All down hall buttons that are not responded to during up car travel are answered during down car travel as their floor relays are not reset and maintain their corresponding selector stationary contacts "alive" until the buttons are responded to.

Car button 381 for the upper terminal does not control the effectiveness of selector contact 392, being employed to maintain, when pressed, coil TC553 energized. It is to be noted that a car button, when pressed, not only renders the corresponding selector stationary contact "alive", but also renders other car button selector stationary contacts "alive" through selector switches 395-494. However, these other contacts, so rendered "alive", do not cause stopping of the car upon being engaged by brush 507. Assume, for example, that the car is positioned at the lower terminal and that the sixth floor car button 436 is pressed. This renders not only selector contact 437 "alive" but also the selector contacts for the second, third, fourth, fifth, seventh, eighth and ninth floors "alive". As the advancer mechanism advances the brushes, it also advances cam 509, which engages and opens selector switch 494 before the engagement of brush 507 with stationary contact 493 occurs, and maintains this switch open so long as brush 507 is in engagement with this contact. Thus, contact 493 is "dead" while engaged by brush 507, so that no false operation is obtained. The same operation is had with respect to selector car button stationary contacts for the third, fourth and fifth floors, switches 438, 466, and 452 being engaged by cam 508 before the engagement of the corresponding stationary contacts by brush 507 occurs. The opening of selector switch 438, however, has no effect on stationary contact 437, under the assumed conditions, so that the car is caused to slow down and stop at the sixth floor in response to the sixth floor car button 436. Cam 508 is of such length and is so positioned as to maintain the floor brush switch for any floor open until after brush 507, during upward travel, has left the stationary contact for the floor above. This prevents, for example under the assumed conditions, the rendering of selector contacts 423, 403, and 393 "alive" by the sixth floor car button 436 at the time that they are engaged by brush 507. Switch 438 being held open until after brush 507 disengages contact 423, renders this contact "dead" while engaged by the brush, thereby preventing a false stop. Contacts 403 and 394 are rendered "dead" in a like manner by switches 424 and 410 respectively.

Floor brush switch 607 is positioned so as to be opened by insulated cam 509 when the car is at the main floor and also so that the cam passes off the switch to permit it to reclose during the advance of the cam by the advancer mechanism,

as pointed out hereinbefore. The point at which the cam leaves the switch is selected so as to permit the energization of the automatic reversal relay at the proper time to effect slow down and stop of the car at the second floor and reversal of its direction of travel when conditions exist for effecting reversal at the second floor. The purpose of switch 607 and up indicator light relay UL controlled thereby is principally to prevent the operation of the automatic reversal relay to cause the direction controlling mechanism to operate to change the direction of car travel as the car comes from the basement to the main floor. Relay UL also serves to maintain the pilot light 379 in the car lighted after the reset of the floor relay in answering a highest up call.

Referring now also to Figure 25, the operation of a group of elevators will be described. The power and control circuits for the additional elevators are not illustrated as they may be identical with those illustrated and described for one elevator.

The hall buttons and their floor relays are common to all the elevators. The circuits through the making contacts of the floor relays are illustrated as leading to bus bars from where they are taken off in branch circuits to the selector machines of the various elevators. These bus bars have been characterized generally in accordance with the floor which is involved. For example, UH7 indicates that the bar is in the up hall button floor relay circuit for the seventh floor. The breaking contacts of the floor relays are also illustrated as connected to bus bars, the connections being taken off the series circuit containing these back contacts between the back contacts of the up and down floor relays for each floor. The bus bars to which these connections extend are designated numerically as to floors and by the letter R to indicate that they are in the automatic reversal circuits. All bus bars are common to all of the elevators of the group. Each elevator has one up and one down hall lantern at each intermediate floor, a down hall lantern at the top floor and an up hall lantern at the first floor. The car buttons are individual to their respective elevator cars and operate independently of the car buttons in any other car. Also, each car is provided with a starting switch.

It is believed that unnecessary duplication will be avoided and that the principles of operation will be readily understood from the illustration of the circuits for the selector machines for two elevators. It is to be understood, however, that the principles of the invention are applicable to any number of elevators. The selector machine circuits for the second elevator, hereinafter referred to as No. 2, may be identical with the selector machine circuits for the elevator previously described, hereinafter referred to as No. 1, and will not be described in detail except as set forth in the description of operation. In describing elevator No. 2, the same reference characters will be employed for the corresponding parts as have already been employed in describing elevator No. 1, with the exception that the letter "a" will be affixed to the designating character, as a means of differentiation. The travelling brushes of the selector machines for the two elevators are positioned on the wiring diagrams for both cars at the lower terminal.

Assume that the up eighth floor hall button 297 is pressed. This causes contacts 351 to be latched in engagement and thus contacts 413 and 414 of the selector machine for elevator No. 1 and

413a and 414a of the selector machine for elevator No. 2 to be rendered "alive". The manner in which this button is answered by car No. 1, resulting in the car being brought to rest at the eighth floor, has already been described. However, assume that the brushes of car No. 2 are first to engage selector stationary contacts for the eighth floor during upward travel. Upon the engagement of brush 514a with contact 413a a circuit is completed for the neutralizing coil 10 SM648a of elevator No. 2 stop magnet. The No. 2 selector pawls are thus released and the first auxiliary stopping relay for elevator No. 2 is de-energized to reengage its contacts A561a which causes sufficient current to be supplied to restoring coil 333 of the up eighth floor relay through selector contact 414a and brush 515a to cause the up eighth floor relay to be reset. Elevator No. 2 first auxiliary stopping relay also reengages its contacts A524a to complete a circuit through 20 potential switch contacts C376a, auxiliary direction switch contacts PB526a, brush 523a, selector contact 420a and contacts NS392a for lamp 419a, causing the lighting of the up hall lantern at the eighth floor for the No. 2 elevator. Continued 25 movement of car No. 2 results in the car being slowed down and brought to a stop at the eighth floor landing through the coaction of the up pawl and eighth floor stopping collar of its selector. It is believed that further description of the response of the No. 2 elevator to the up eighth floor hall button is unnecessary in view of the fact that the operations involved have already been described in detail for elevator No. 1. The car gate and eighth floor hatchway door for elevator No. 2 35 are opened as the car is brought to rest. Upon the car being restarted, the up hall lantern at the eighth floor for elevator No. 2 is extinguished as in the manner previously described in connection with elevator No. 1.

The reset of the up eighth floor relay at the time that brushes 514a and 515a engage selector contacts 413a and 414a which selected the No. 2 elevator to be the one to answer the up eighth floor hall button rendered not only selector contacts 413a and 414a of the No. 2 selector "dead" but also contacts 413 and 414 of the selector for elevator No. 1. Assume that car No. 1 is travelling upwardly to discharge a passenger at the ninth floor. The later engagement of contacts 413 and 414 by brushes 514 and 515 of the selector machine of elevator No. 1 does not cause car No. 1 to be slowed down and stopped at the eighth floor, nor does it cause the lighting of the up hall lantern at the eighth floor for the No. 1 elevator.

If the up hall button at the eighth floor had been pressed too late to be answered by elevator No. 2, the contacts of the various selector machines controlled by this push button are maintained "alive" so that the call is answered by the next car, travelling in the up direction, whose brushes 514 and 515 engage contacts 413 and 414. Thus, it is seen that a push button, once pressed, is sure to be responded to.

It is believed unnecessary to describe the operation of elevator No. 2 in answering hall buttons during downward travel, inasmuch as this operation is effected in the same manner as has already been described for elevator No. 1. The operation of elevator No. 2 in case of car buttons is also the same as that described for elevator No. 1. The car button circuits for each elevator are independent, so that only the car in which the car buttons are located is caused to slow down and

stop at floors in response to the operation of those buttons.

- The circuits for No. 2 elevator are also arranged to provide automatic reversal during up car travel at any floor, determined by the buttons pressed. The car buttons in the No. 2 car control the operation of the topmost car call relay TC of elevator No. 2 through floor brush switches in the same manner that relay TC of elevator No. 1 is controlled. The back contacts of the floor relays are connected through the reversal bus bars designated "R" to the contacts on the No. 2 selector corresponding to those on the No. 1 selector so that, with service switch 373 closed, the energization of the topmost hall call relay TH of elevator No. 2 is dependent upon the hall buttons pressed in the same manner as relay TH of elevator No. 1. Thus, with the direction controlling mechanism for elevator No. 2 set for up car travel, when the advancer mechanism moves the brushes and cam 508a to a position engaging stationary contacts and floor brush switch for a floor, for floors above which no push buttons are operated, the direction of travel of car No. 2 is reversed as the car arrives at that floor, provided the push button pressed for the floor is a down hall button or a car button. In case the up push button for that floor is pressed, the back contacts of the corresponding up floor relay prevent the energization of elevator No. 2 topmost hall call relay to engage its contacts TH531a until after the separation of contacts A532a, thereby preventing the reversal of the direction of car travel at that floor. Therefore, as in the case of car No. 1, the direction of travel of car No. 2 is reversed at any floor when, at the time the circuits are set up which cause the car to be slowed down and stopped at that floor, no push buttons are pressed which require further travel of the car in the up direction.
- The pilot light 379a in car No. 2 is controlled in the same way as the pilot lamp in car No. 1, i. e., the lamp stays lighted during up car travel until the reversal point is reached, whereupon the lamp is extinguished as the direction controlling mechanism is operating to change the direction of car travel to down. The up hall lanterns of elevator No. 2 are lighted in advance of the arrival of the car to indicate travel of the car in the up direction at all floors at which car No. 2 is stopped during its upward travel until the reversal point is reached. When circuits are set up on No. 2 selector which cause the car thereafter to be slowed down and stopped at a floor under conditions where no push buttons are pressed requiring further travel of the car in the up direction, the down hall lantern at that floor for car No. 2 is lighted an advance light distance of the car from the floor to indicate that the car will leave the floor in the down direction.
- When the circuits have been set up to cause an up car to be slowed down and stopped at a floor and the direction of travel reversed and a hall button for a floor above is pressed after the operation of the automatic reversal relay AR for that car to establish its self-holding circuit, this does not alter the operation of the car. Its direction of travel is reversed upon arrival of the car at the floor for which the circuits were set up and, upon being started, the car leaves the floor in the down direction. It is not desirable to have the operation of the car changed once the down lantern at the floor is lighted to indicate that that car is to leave the floor in the down direction, as this would result in confusion to intending passengers. Also, in case the stop is made in response

to a down hall button, to permit the car to continue in the up direction after making the stop would be in effect making a false stop in response to the down button and a false cancellation of the call. The call registered for the floor above is maintained registered, however, so that it will be responded to.

Assume that the highest call registered is a down call at the sixth floor. Assume further that car No. 1 is the one selected to respond to this call, i. e., its brush 517 engages stationary contact 443 before such engagement occurs for other up cars. Assume also that the up eighth floor hall button 297 is pressed after the engagement of brush 517 and contact 443 occurs. The engagement of brush 517 and contact 443 completes a circuit for coil TH536 of the topmost hall call relay of elevator No. 1, which engages its contacts TH531, establishing a circuit for coil AR529 for elevator No. 1 automatic reversal relay. This relay operates to establish a self-holding circuit and cause the down sixth floor hall lantern for car No. 1 to be lighted, the car to be slowed down and stopped at the sixth floor, and the direction controlling mechanism set for down car travel when the car is brought to rest. The pressing of the up eighth floor hall button does not affect this operation so long as it was not pressed before the automatic reversal relay established its self-holding circuit. Should it be pressed in time to prevent the operation of topmost hall call relay TH of elevator No. 1 or to cause contacts TH531 of this relay to drop out before the automatic reversal relay had time to establish its self-holding circuit, the car would not respond to the down sixth floor hall button. Instead, elevator No. 1 would continue to function to cause response to be given to the up eighth floor hall button.

The same operation is had regardless of the hall button pressed for a floor above the one at which circuits are set up to respond to a down hall button. Also, the same operation is had in the event that the up hall button at the same floor as the down hall button is pressed after the operation of the automatic reversal relay occurs.

If the car were responding to a car button instead of a down hall button as the highest button pressed, the same operation is had in the event of the late pressing of the up hall button for that floor or any hall button for a floor above. When the brush switch for the floor for which the car button switch is provided is opened by the insulated cam to break the circuit for the topmost car call relay and thus effect the reengagement of contacts TC530, brush 517 engages the stationary contact for that floor, causing the operation of the topmost hall call relay TH to engage contacts TH531. This causes the operation of the automatic reversal relay and if this relay establishes its self-holding circuit before the up hall button for that floor or any hall button for a floor above is pressed, the car is not only slowed down and stopped at that floor but also has its direction of travel reversed when the car is brought to rest.

The floor relay for the late pressed hall button is maintained operated so that this call will be answered. Assume that car No. 1 is the one which has its direction of travel reversed without responding to the late pressed hall button and that brush 517a of elevator No. 2, with elevator No. 2 set for up travel, engages the stationary contact corresponding to the late pressed hall button before corresponding engagement occurs for other elevators. Under such conditions,

car No. 2 is caused to slow down and stop at the floor at which the late pressed button is located, regardless of whether the late pressed button be an up hall button or a down hall button, provided 5 no higher call exists at the time this engagement occurs, and that no car button in car No. 2 for a higher floor is pressed. If the late pressed hall button be a down hall button, the direction of travel of car No. 2 is reversed as it arrives at the 10 floor, while if it be an up hall button, elevator No. 2 remains set for up car travel.

If the car is responding to a car button as the highest button pressed and the down hall button for the same floor is pressed after the circuits 15 have been set up to cause the car to respond to the car button, the down floor relay is reset. This is due to the fact that the reset brush 511 for the down hall button is in contact with the stationary contact for the floor for which the late 20 pressed down hall button is provided during the answering of the car button for that floor. Inasmuch as the answering of the car button involves the operation of the automatic reversal relay to deenergize the auxiliary direction relays 25 as well as to reverse the direction of car travel, contacts PB543 are engaged to complete the circuit for the reset coil of the down floor relay, so that the floor relay is restored to reset condition as soon as the late pressed down button is released. 30

A late pressed up hall button is reset under conditions where response is being had to a car button for the same floor, provided the car button does not represent the highest call which is registered. Reset brush 515 is in contact with the selector stationary contact for which the late 35 pressed up button is provided during the answering of the car button so that the corresponding up floor relay is reset under the conditions assumed. The system remains effective to reset late pressed push buttons as above set forth until the car switch has been moved to operated position to cause the operation of relay A to separate its contacts 541. This arrangement takes care of 40 the reoperation of floor relays as a result of the passenger becoming impatient and repressing the buttons after the relays have been reset and circuits have been set up to respond thereto.

Two or more cars may be set for travel in the 50 up direction with only one hall call above and no car calls. If the call is a down call, the car whose brush 517 is the first to engage the stationary contact for the floor at which the hall button is located, in other words the up car 55 which is in effect the first to reach the up car selecting point for that floor, is caused to light its down hall lantern at that floor, slow down and stop at the floor, and reverse its direction of travel as the floor is reached. If the call is an up 60 call, the car whose brushes 514 and 515 are first to engage their stationary contacts for the floor at which the button is located, i. e., in effect the car first to reach the up car selecting point for that floor, is caused to light its up hall lantern 65 at that floor and slow down and stop at the floor but does not reverse its direction of car travel. However, the reset of the floor relay, either up or down, incident to the selection of the car to 70 answer the call, by the engagement of its back contacts, prepares a common circuit for the coils of the topmost hall call relays of the other elevators. Thus, upon the next engagement of brush 517 of each of the other elevators set for up car travel with one of its stationary contacts, 75 circuits are set up to cause this car to be slowed

down and stopped at the floor for which the stationary contact is provided. Assume that a down hall call existed at the ninth floor and that it was answered by car No. 2. Assume, also, that car No. 1 is set for up car travel at this time and that its brush 517 is between contacts 457 and 448 at the time the down floor relay at the ninth floor is reset. Upon the engagement of back contacts 370 of the down ninth floor relay, contact 443 is rendered "alive" so that its engagement by brush 10 517 completes a circuit for coil TH536 of elevator No. 1 topmost hall call relay, causing car No. 1 to be slowed down and stopped at the sixth floor and its direction of travel reversed as the floor landing is reached. 15

Should there be a hall button pressed for a floor intervening the one for which circuits have been set up for the leading car to answer a call registered for that floor and another car which is set for up car travel, in other words if there be a call 20 for a floor in effect between these two cars, this other car is caused to travel in the up direction to answer this button. As in the previous example, assume that a down hall call existed at the ninth floor, that it was answered by car No. 2, 25 and that car No. 1 is set for up car travel at this time with its brush 517 between contacts 457 and 448 at the time the down floor relay at the ninth floor is reset. If a call is registered at the seventh or eighth floor, the engagement of back contacts 370 of the down ninth floor relay does not render 30 contact 443 at the sixth floor "alive", so that the engagement of this contact by brush 517 does not complete a circuit for the topmost hall call relay for elevator No. 1. Assume that the seventh floor up button 295 is the one pressed. The up seventh floor relay is therefore in operated condition, separating its back contacts 367, rendering not only selector contact 443 but also selector contact 429 "dead." Upon the engagement of brush 514 40 with selector stationary contact 427, rendered "alive" by the forward contacts 349 of the up seventh floor relay, a circuit is set up which causes car No. 1 to be slowed down and brought to a stop at the seventh floor. As contacts A532 separate before contacts TH531 reengage as a result of the reset of the up seventh floor relay, the automatic reversal relay AR of elevator No. 1 is not operated, 45 so that the direction controlling mechanism is maintained set for up car travel. 50

Should there be no call between the point at which the brushes of car No. 1 are positioned and the floor at which the highest call exists at the time circuits are set up to cause this call to be answered by car No. 2, car No. 1 will still respond 55 to a call above provided it is registered before the automatic reversal relay AR of elevator No. 1 is operated. Also, should no call be registered and car No. 1 be slowed down, stopped and its direction of travel reversed, say at the sixth floor, still a 60 call existing between the highest call and the position of brush 517 for another car set for up car travel, say at the fourth floor, would cause this latter car to continue in the up direction and answer this call. In other words, any car which is 65 set for up car travel is maintained in that condition so long as a call exists which is in effect above it, i. e., which may be answered by that car, until circuits are set up for some car to answer the call.

A pressed car button in car No. 1 for a floor intervening car No. 1 and the floor for which the highest call existed and for which car No. 2 has had circuits set up to cause it to slow down and come to a stop, is likewise effective to cause car No. 1 to travel in the up direction until response 70 75

is had thereto. This is due to the fact that the pressed car button maintains the topmost car call relay of elevator No. 1 operated to separate its contacts **TC530** until the floor brush switch for the floor for which the car button is provided is opened by insulated cam **508**, thereby preventing the operation of the automatic reversal relay **AR** of elevator No. 1 until the engagement of this floor brush switch by the insulated cam occurs.

10 The elevators may be arranged to cause the cars always to travel in the up direction to a certain floor before automatic reversal can take place. This may be done by providing a switch in the circuit containing the back contacts of the floor

15 relays immediately below the back contacts of the down floor relay for the floor at which it is desired to have cars travel before reversing. Such a switch, designated **365**, has been illustrated and is arranged immediately below back contacts **366** of

20 the down floor relay for the seventh floor. The opening of this switch acts the same as the opening of the back contacts of the down seventh floor relay in that it prevents the operation of the topmost hall call relay for any car before the engagement of brush **517** of that elevator with selector stationary contact **429** for the seventh floor. If at this time no button in the car is pressed for a floor above the seventh floor, no down hall button is pressed for a floor above the seventh floor, and

25 the up button for the seventh floor or the up button for any floor above is not pressed, the car is not only slowed down and brought to a stop at the seventh floor but its direction of travel is reversed at that point. However, should a button in the

30 car or a hall button for any floor above the seventh floor be pressed at the time brush **517** engages contact **429**, reversal of the direction of car travel at the seventh floor is not effected and the car is not slowed down and stopped at the

35 seventh floor unless the car button or up hall button for the seventh floor has been operated. The position of service switch **365** in the series circuit for the back contacts of the floor relays would be determined by the requirements of the

40 particular installation. This switch is preferably a snap switch located on the dispatcher's panel at the ground floor.

Switch **365**, being common to all the elevators, affects them all in the same way, i. e., causes all of them to travel upwardly to a predetermined floor before automatic reversal becomes effective. By by-passing the car buttons for the cars by manually operated switches or by providing buttons which may be mechanically locked in operated condition, the cars may be caused to travel to the same or different selected floors before automatic reversal is effective. For example, car No. 1 can be caused to always run to the seventh floor before automatic reversal becomes effective by shunting the car button **422**, connecting contact **423** to the negative line, while car No. 2 can be caused to always run to the eighth floor before automatic reversal becomes effective by shunting button **407a**, connecting contact **408a** to the negative line. If such arrangement be employed, each car is always stopped at the floor for which its car button is shunted.

Where some of the elevators of the group are arranged to serve additional floors above the upper terminal for the other elevators, to prevent the hall buttons for these additional floors affecting the operation of the other elevators, the floor relays of the hall buttons for the floors served by all the elevators of the group may be provided

with additional back contacts and these contacts connected in a separate series circuit along with the back contacts of the additional floor relays to control the automatic reversal mechanism for the elevators which serve these additional floors. Thus the elevators in this respect would be treated as two groups, the other floor relay back contacts being arranged in a separate series circuit and controlling only the elevators which do not serve the extra floors.

10 The automatic reversal feature may be cut out by opening service switch **373**. This opens the feed to the series circuit of floor relay back contacts and thereby prevents the operation of the topmost hall call relay **TH** for any car at any time. Inasmuch as the automatic reversal relay **AR** for each car cannot operate to reverse the direction of travel of the car until relay **TH** of that elevator is operated, each car cannot be reversed automatically except at terminals. Therefore, with service switch **373** open, each car, once started in the up direction from the ground floor, must make a complete trip to the upper terminal before reversal is automatically effected. The direction switches **PU** and **PD** may be manually controlled to reverse the direction of car travel at any floor, if desired. This may be obtained by switching means provided in the elevator car and diagrammatically illustrated as a throwover switch designated **623**. Service switch **373** is preferably a snap switch arranged on the dispatcher's panel.

Any car may be caused to run non-stop with respect to operated hall buttons by pressing either the non-stop switch **566** in the car or non-stop switch **567** at the dispatcher's station. For example, when car No. 1 becomes fully loaded and its attendant desires to prevent the taking on of more passengers until room is again provided in the car as a result of discharge of passengers, he may do so by opening the non-stop switch **566** in his car. This deenergizes coil **NS564** of the non-stop relay and coil **ANS565** of the auxiliary non-stop relay. Relay **NS** separates contacts **NS392**, **NS540** and **NS545** and relay **ANS** separates contacts **ANS535** and engages contacts **ANS537**. The separation of contacts **NS540** and **NS545** prevents the establishment of circuits by brushes **510**, **511**, **514**, and **515**, thereby preventing response of elevator No. 1 to hall buttons.

The separation of contacts **NS392** prevents the lighting of the hall lanterns of elevator No. 1. Although it is preferred to prevent the lighting of hall lanterns at floors under non-stop operation, it may be desirable to permit the lighting of these lanterns under conditions where the car under non-stop operation is stopped in response to a car button. This may be done by omitting contacts **NS392**. With contacts **NS392** omitted, the hall lantern for the floor at which a stop is made in response to a car button is lighted so that if any intending passengers are waiting to be carried in the direction in which the car is travelling, they may be taken on to replace the passengers discharged.

The purpose of the auxiliary non-stop relay **ANS** is served under conditions where service switch **373** is closed to render the automatic reversal mechanism effective. Contacts **ANS535** serve to prevent the intermittent operation of the topmost hall call relay **TH** during up car travel when no hall buttons are operated for floors above a point in the hatchway corresponding to the position of brush **517**. Contacts **75**

ANS537 serve to permit reversal of the car at the next floor whose floor brush switch is engaged by cam 508 under conditions where no car buttons for floors above that floor are pressed at the 5 time a non-stop switch for that car is operated. These contacts also serve to permit reversal of the car at the highest floor for which a car button is pressed under non-stop operating conditions.

10 The non-stop relays, upon dropping out, do not prevent response of the car to the car buttons. Slow-downs are made in response to these buttons in the manner previously described. Furthermore, in the case of hall buttons, the 15 selector stationary contacts are maintained "alive" so that the call is ultimately responded to.

The system of control above described is adapted for any installation in which attendants are provided in the elevator cars. The automatic reversal feature is particularly useful for installations in hotels, those in department stores, wherein the traffic is mostly between a lower group of floors, and for night service. It is also useful for office buildings, particularly under 25 certain conditions. Any elevator of a group which is arranged for automatic reversal may be used for night service. It is preferred, for night service, to arrange the system so that an audible signal is given whenever a hall button is pressed.

30 A night bell relay has been shown for this purpose, its coil NB282 being illustrated as in a circuit common to the hall buttons. Thus, when any hall button is pressed, this relay is operated and completes the circuit to a suitable form of 35 audible signal, advising the night operator that service is required. The pilot light 379 serves during night operation to advise the operator upon return of the car to the ground floor whether calls are registered which have not been 40 responded to. For department store operation, car buttons and hall buttons for certain of the lowermost floors might be omitted and the car button selector contacts connected directly to the negative supply line. This would cause the car 45 always to stop at these selected lowermost floors.

An indicator may be provided in each car which shows not only the position of the car in the hatchway but also the floors for which car buttons have been pressed. Circuits for such an 50 arrangement are illustrated in Figure 26. The position indicator comprises a series of lamps 636-673, one for each floor. These are preferably low voltage lamps and are connected directly to one side of a low voltage source. The 55 other side of each lamp is connected to a stationary contact on the selector machine. These contacts 635-672 are arranged according to floors in a vertical column to be engaged by a travelling brush 671. The brush is connected 60 through a cut out switch 632 to the other side of the source. The arrangement is such that when the car is at a floor the brush engages the contact for that floor to complete a circuit for the 65 lamp connected thereto. Thus the position indicator is illuminated to indicate that the car is at that particular floor in the hatchway.

The car call indicator also comprises a series of lamps 634-670. These lamps are controlled 70 by additional contacts on the car push buttons. For this purpose, an additional push button is provided in the car for the ground floor. These push button contacts 633-669, upon being pressed, cause current to be supplied to the corresponding lamps from the low voltage source.

The car call indicator can be cut out by opening switch 631.

The combination of car call and car position indicator is of advantage in that it enables a passenger, upon entering the car and announcing his destination, to ascertain whether the car push button for that floor is registered. It also enables him to tell when the car is about to stop at his destination so that he may prepare to alight.

10 The system of control may be arranged so that an up car is not affected by calls registered by hall buttons at floors in effect ahead of any other up car which is in effect above such car. As before, by "in effect" is meant that the position- 15 ing is determined by the positions of the brushes for the cars with respect to the floor contacts, rather than the actual positions of the cars. With such arrangement, the direction in which any following car is set for travel is automatical- 20 ly changed at any floor at which it is brought to a stop during upward travel under conditions where, at the same time that circuits are set up which cause the car to be slowed down and brought to a stop at such floor, no push button, of 25 those for that floor or for any floor between that floor and the next highest floor for which the selector stationary contact is engaged or is the next to be engaged by the automatic reversal brush for another up car, is pressed which re- 30 quires further travel of the following car in the up direction. This involves causing an up travelling following car to be slowed down and stopped at a floor in response to the down hall button for that floor, provided no car button in the car is 35 pressed for a floor above and provided, further, the up hall button at that floor is not pressed and no hall button is pressed for any floor above that floor and up to the floor next below the next floor whose stationary contact is engaged or 40 is next to be engaged by the automatic reversal brush for another up travelling car.

Such arrangement of control is shown in Figure 27. Only enough of the circuits for two elevators are illustrated to show the manner in which the 45 system differs from the arrangement of Figures 24b and 25 and to illustrate the principles involved. The circuits not shown are in accordance with those of Figures 24 and 25. In the arrangement shown, devices, which permit a flow 50 of current in one direction but not in the other, are provided in the circuit connecting the back contacts of the floor relays in series relation. For this purpose rectifiers may be used. These rectifiers are arranged to permit the flow of effective 55 current in the circuit toward back contacts of floor relays for higher floors but not in the reverse direction. An elongated additional brush 816 is provided on each selector for engaging the automatic reversal contacts. This brush is effective 60 only doing up car travel. It is positioned to follow the automatic reversal brush 807 and so as to engage each selector contact immediately after brush 807, in its upward movement, leaves the contact. Brush 816 is made long enough to span 65 two adjacent contacts but should be no larger than required to bridge contacts for the adjacent floors which are farthest apart. This arrangement renders the topmost hall call relay TH for any following car subject only to floor relays for 70 floors between the point corresponding to the position of brush 807 for this car and the point corresponding to the position of brush 807 next above for another car.

To provide a maximum effectiveness of the 75

control, the back contacts of the up floor relays are connected in circuit below (to the left of) the point of connection of the reversal bus bar for the corresponding floor to this series circuit. To prevent automatic reversal with this arrangement when a car is responding to an up hall button as the highest call for that car, an arrangement is provided which renders the automatic reversal mechanism ineffective under these conditions. 10 This involves delaying the separation of contacts AR874 upon the operation of the automatic reversal relay, until after the reset brushes engage their stationary contacts for the floor at which the stop is to be made. If the up floor relay for 15 that floor is operated, the engagement of the up reset brush with its contact for that floor completes a circuit for coil RC869 of the reversal control relay, which operates to break the circuit for the automatic reversal relay AR. This prevents 20 the separation of contacts AR874, thereby preventing the dropping out of auxiliary direction relays PA and PB. If no up floor relay is operated, the automatic reversal operation takes place in the manner set forth in describing the system 25 of Figures 24 and 25, auxiliary direction relay PB, upon dropping out as a result of the separation of contacts AR874, completing the circuit to reset the down floor relay in case it is operated. Additional contacts AR854 are provided on the 30 automatic reversal relay for each car which, together with the delayed action of relay PB for that car, slightly delays the lighting of the hall lantern for that car at a floor under conditions where the car is responding to its highest effective call.

In order that the operation may be clearly understood, assume that car No. 1 is being stopped at the seventh floor, as indicated by the position of its up hall button reset brush 806 and its automatic reversal brush 807, and that the only call existing between car No. 2, which is positioned at the ground floor, and the seventh floor, is one registered at the fourth floor by the down fourth floor button 687. Thus the down fourth floor 15 relay back contacts 761 are separated, preventing the energization of coil TH865a of elevator No. 2 topmost hall call relay. Assume further that elevator No. 2 starting switch is moved to start position and that brush 807a is moved into engagement with No. 2 selector fourth floor stationary contact 829a as a result thereof while elevator No. 1 brush is in contact with stationary contact 808. As brush 816 is in engagement with contact 817 while brush 807 is contacting with contact 803, the engagement of brush 807a with contact 829a completes a circuit for coil TH865a of elevator No. 2 topmost hall call relay, assuming no car button in car No. 2 for a floor above the fourth floor is pressed. This circuit is established regardless of whether there are any hall buttons pressed for floors above the sixth floor or not, since the circuit is independent of the back contacts of the floor relays for floors above the seventh floor. The circuit extends from the positive supply line subject to the elevator No. 2 potential switch contacts, through resistance 867a, coil TH865a, contacts ANS864a, contacts AU863a, brush 807a, contact 829a, fourth floor reversal bus bar R4, back contacts 764 and 765 of the fifth floor relays, rectifier 766, back contacts 767 and 768 of the sixth floor relays, rectifier 769, reversal bus bar R6, elevator No. 1 selector contact 841, elongated brush 816, direction relay contacts PA781, auxiliary non-stop switch contacts 75 ANS179, bus bar R10, service switch 754, to the

negative supply line. Elevator No. 2 topmost hall call relay TH, upon operation, engages contacts TH860a to complete the circuit for coil AR858a of the automatic reversal relay of elevator No. 2. The separation of contacts AR874a of the automatic reversal relay is delayed to prevent the deenergization of coils PA875a and PB876a of elevator No. 2 auxiliary direction relays until brush 806a engages contact 828a. Also, the automatic reversal relay separates contacts AR854a to prevent the lighting of the up hall lantern 832a for the fourth floor. Otherwise, the automatic reversal relay functions in the manner set forth in describing the system illustrated by Figures 24 and 25. Upon the deenergization 10 of the auxiliary direction relays of elevator No. 2, contacts PB851a engage and contacts PB852a separate. The engagement of contacts PB851a establishes a circuit for elevator No. 2 down hall lantern 831a of the fourth floor. Auxiliary direction relay PB, upon dropping out, also causes the reset of the down fourth floor relay in accordance with the circuits shown in Figure 24b. The car is caused to slow down and stop at the fourth floor as a result of the operation of the 15 automatic reversal relay to effect the electromagnetic neutralization of the operating coil of the stop magnet, and as the car is brought to a stop, a circuit for the direction switches is established 20 through contacts of the automatic reversal relay 25 for the reverse direction of car travel.

If a car button in car No. 2 has been pressed for a floor above the fourth floor, contacts TC859a of the topmost car call relay of that elevator would have been separated, preventing the establishment of a circuit for coil AR858a of elevator No. 2 automatic reversal relay upon the engagement of brush 807a with stationary contact 829a. If either the up or the down push button at the fifth or sixth floor had been pressed, the 30 engagement of brush 807a with contact 829a would not have established a circuit for coil AR858a due to the back contacts of this floor relay being separated. If the up hall button at the fourth floor is pressed, car No. 2 is caused 35 to slow down and stop at the fourth floor but its direction of travel is not reversed, regardless of whether the down hall button at the fourth floor or car button for that floor is pressed or not. This is due to the fact that the engagement of 40 elevator No. 2 up reset brush 806a with the up fourth floor stationary contact establishes a circuit for coil RC869a of elevator No. 2 reversal control relay in effecting the reset of the up fourth floor relay. The reversal control relay 45 operates to separate its contacts RC855a in the holding circuit for coil AR858a of the automatic reversal relay, causing the automatic reversal relay to drop out (contacts AR854a being separated at the time contacts RC855a open). The 50 separation of contacts AR874a being delayed until after the establishment of the circuit for coil RC858a, elevator No. 2 auxiliary direction relays PA and PB do not drop out, so that the circuit is established through contacts AR854a 55 and PB852a for the up hall lantern 832a at the fourth floor. The down fourth floor relay, if operated, is not reset because relay PB is not deenergized. As its automatic reversal relay AR is not in operated condition as car No. 2 comes 60 to a stop at the fourth floor, elevator No. 2 direction controlling mechanism is not operated to reverse the direction of car travel. Thus, when the intending passenger who pressed the up fourth floor hall button has been taken into car 65

No. 2 and the starting switch moved to start position, the car is started in the up direction.

It makes no difference in the above described operations whether the brushes of elevator No. 1 are in motion at the time elevator No. 2 brush 807a engages contact 829a, as elongated brush 816 of elevator No. 1 provides a feed for brush 807a, by-passing the back contacts of all floor relays for floors above the stationary contact or 10 contacts engaged by brush 816. The rectifiers prevent the establishment of unwanted circuits. For example, if effective current were permitted to flow in either direction in the circuit in which the back contacts of the floor relays are arranged 15 in series relation, a feed would be established for brush 807 by brush 816, causing the operation of relay TH regardless of whether calls existed for floors above the position of brush 807 or not. With brush 807 in contact with stationary contact 20 808, this circuit would be from the positive supply line through coil TH865 to brush 807, contact 808, bus bar R1, contacts 711 and 710 (the rectifiers not being provided under the assumption), bus bar R6, contact 817, brush 816, 25 contacts PA781, contacts ANS779, service switch 754, to the negative supply line. The rectifiers prevent such operation. Other means than rectifiers may be employed to restrict the direction of current flow in the floor relay back contacts circuits.

When an up car which is in effect ahead of another up car picks up its highest call, if the up floor relay for the floor for which circuits are set up is not operated, as soon as the mechanism 35 registers this fact by deenergizing the auxiliary direction relays for that car, the resultant separation of contacts PA781 renders brush 816 of that elevator ineffective to provide a feed for a lower brush 807. Thus, hall buttons for floors 40 in effect above such car ahead become immediately effective to control the operation of the car which is in effect next below. If no brush 807 for any other up car is ahead of brush 807 for the car for which circuits are set up to answer 45 its highest effective call (either car button or down hall button) at the time these circuits are established, all floor relays for floors above brush 816 for that car are effective to control the up car whose brush 807 is next below the one 50 for the car which is answering its highest call. If there is such brush ahead, then only floor relays for floors below the position of that brush are so effective. If the non-stop button for a car is pressed, additional contacts ANS779 on the 55 non-stop relay for that car are separated, rendering brush 816 ineffective to provide a feed for any lower brush 807 and thus rendering that car ineffective to control the effectiveness of the hall buttons as regards other cars so long as the 60 button is pressed.

The system of control may also be arranged so that an up car will continue its travel in the up direction only so long as car buttons remain to be responded to or up hall buttons for floors between the effective position of the car and that of the up travelling car in effect next above. In other words, an up car is not affected by down hall buttons unless it is in effect the leading car. With this control, all hall calls answerable by a 65 car which is in effect above all other cars, regardless of whether such car be set for up or down travel, do not affect any of the other cars which are set for up car travel. As soon as a 70 call is registered which is not answerable by such 75 car above, one of the other cars, which is in

effect behind such car in its round trip to the highest call and back, is caused to answer the call. Such arrangement of control is shown in Figure 28, in which only enough of the circuits for two elevators are illustrated to show the manner in which the system differs from the arrangement of Figure 27. The control circuits for several of the intermediate floors are omitted to further simplify the drawings.

In the arrangement shown, the series circuit 10 for the back contacts of the floor relays is divided, one circuit containing the back contacts of up floor relays and the other circuit containing the back contacts of the down floor relays. Rectifiers are provided in both circuits. As before, 15 these rectifiers permit the flow of effective current in the circuit toward the back contacts of floor relays for higher floors but not in a reverse direction. Separate automatic reversal contacts are provided on the selector for the up 20 hall calls and the down hall calls as distinguished from the previous arrangement in which only one automatic reversal contact is provided for each floor for both the up and the down hall button. The reversal contacts for up hall calls and 25 those for down hall calls are arranged in separate columns to be engaged by separate brushes. The contacts are connected to bus bars which are connected to the series circuits above the floor relay back contacts corresponding thereto. An 30 elongated brush is provided for engaging the selector brush contacts of each column. Each brush is arranged to follow the automatic reversal brush as in the case of Figure 27. The 35 elongated brushes are effective only during up car travel.

Each automatic reversal brush controls a separate topmost hall call relay, these relays being designated THU and THD to indicate that one is for the topmost up hall call and the other is for 40 the topmost down hall call. The contacts of these relays are arranged in series relation in circuit for the coil of the automatic reversal relay AR to replace the contacts of the single topmost hall call relay previously provided. Back 45 contacts of these relays are arranged in parallel relation in the circuit controlling the pilot light, these contacts replacing the back contacts of the single topmost hall call relay of the previous arrangements.

With the above described arrangement, both up hall calls and down hall calls above the car which is in effect the leading one are effective to control this car, whereas, as regards up hall calls, only those which are in effect between the up car which is in effect the leading one and the car which is in effect the next up car are effective to control this next up car. Thus, any following up car is not affected by up calls which are answerable by an up car ahead.

To prevent any down hall call from affecting any up car when there is a car in effect above, either set for up travel or down travel, which is in position to answer such call, an arrangement is provided which, in conjunction with the apparatus of Figure 27 above described, cuts out the control of all such up cars by down hall buttons. A series of relays are provided which may be of a small, low voltage type, one relay for each car for each floor above the ground floor. The operation of these relays is controlled by cam operated throw-over switches, preferably on the selector machine of the elevator for which the relays are provided. Each selector is provided with one of these switches for each floor above 70 75

the ground floor and a cam carried by the cross-head to close each switch during up car travel as the up brushes engage the stationary contacts for the floor for which the switch is provided and to open each switch immediately the down brushes leave their contacts for the corresponding floor during down car travel. The closing of a throw-over switch causes the operation of the corresponding relay which is thereafter maintained operated so long as the switch is closed. These relays will be termed selective relays and designated generally by the letter S preceded by the number of the floor for which the relay is provided. These relays are provided with forward contacts which are arranged to short-circuit the back contacts of the corresponding down floor relays.

In describing the operation of the control arrangement of Figure 28, car buttons will not be considered as each car answers its car buttons as set forth in describing Figures 24 and 25, i. e., each car proceeds in the up direction until its highest car button pressed is answered, regardless of the hall buttons pressed. Assume that car No. 1 is being stopped at the seventh floor as indicated by the position of its automatic reversal brushes 964 and 965, and that car No. 2 is positioned at the ground floor. As elevator No. 1 brushes were moved in the up direction, cam 974, moved therewith, caused the closing of throw-over switches 988-981 and 970 in sequence, throw-over switch 970 being closed as brush 964 engaged contact 963 for the seventh floor. The closing of these switches causes the operation of selective relays 2S, 3S, 4S, 5S, 6S, and 7S, which engage contacts 2S908-6S910 and 7S911 to short-circuit the back contacts 916-918 and 921 of the down floor relays for the second to seventh floors inclusive, respective. As elongated brush 973 of No. 1 selector engaged stationary contact 993 for the first floor, a circuit was established for coil THD995a of elevator No. 2 down topmost hall call relay. The circuit is from supply line Ca+ through contacts ANS1000a, contacts AU998a, coil THD995a, brush 965a, contact 993a, bus bar 1RD, contact 993, brush 973, contacts PA941, contacts ANS940, contacts CD938 of elevator No. 1 car delay relay (to be referred to later), switch 901, to the negative supply line. This circuit is maintained through the contacts of the selective relays of elevator No. 1 operated by the throw-over switches as elongated brush 973 leaves its stationary contacts for the corresponding floors in its upward movement. That is, as brush 973 leaves contact 993 for the first floor, which occurs after brush 965 has left contact 985 for the second floor, the circuit for coil THD995a is maintained through contacts 2S908 of elevator No. 1 second floor selective relay 2S. Thus, elevator No. 2 down topmost hall call relay is maintained operated while car No. 1 is being slowed down and stopped at the seventh floor, regardless of whether any down call exists for the second, third, fourth, fifth or sixth floor as the back contacts of an operated down floor relay for any of these floors are by-passed by contacts of elevator No. 1 selective relay for that floor. Elevator No. 2 up topmost hall call relay THU is also operated from the time that elevator No. 1 elongated brush 972 engages contact 992 for the first floor, which establishes a circuit for coil THU994a of this relay from supply line Ca+, contacts ANS1000a, contacts AU998a, coil THU994a, brush 964a, contact 992a, bus bar 1RU, contact 992, brush 972, to the negative supply

line. This circuit is maintained through the back contacts of the up floor relays as brush 972 continues its upward movement.

Assume that the up hall button at the sixth floor is pressed after elevator No. 1 up brushes have left their cooperating sixth floor selector contacts. The up sixth floor relay operates to separate its back contacts 892. Since with elevator No. 1 being slowed down and stopped at the seventh floor brush 972 has passed off the fifth floor contact into engagement with sixth floor contact 977, the separation of contacts 892 breaks the circuit for coil THU994a of elevator No. 2 up topmost hall call relay. This relay, upon dropping out, engages its contacts THU993a to complete the circuit for the pilot light 936a in car No. 2, advising the car attendant that the service of his car is required.

Assuming that the starting switch in car No. 2 has been moved to start position, upon the engagement of the elevator No. 2 selector sixth floor up stationary contact 977a by brush 964a, a circuit is reestablished for coil THU994a of elevator No. 2 up topmost hall call relay, this circuit extending from supply line Ca+, through contacts ANS1000a, contacts AU993a, coil THU994a, brush 964a, contact 977a, bus bar 1RU, contact 937, elongated brush 972, contacts PA941, contacts ANS940, service switch 901, to the negative supply line. Since brush 972 and its connection to the negative supply line by-pass the back contacts of all up floor relays for floors above the sixth floor, this circuit is established regardless of whether there are any hall buttons pressed for floors above the sixth floor or not.

Elevator No. 2 up topmost hall call relay, upon operation, engages contacts THU1006a which, owing to the fact that elevator No. 2 down topmost hall call relay is operated and its contacts THD1007a are in engagement, completes the circuit for elevator No. 2 automatic reversal relay AR. Upon the engagement of brushes 514 and 515 with contacts 441 and 442 (see Figure 24b), circuits are established to cause the lighting of the elevator No. 2 up hall lantern at the sixth floor and the slow down and stopping of car No. 2 at the sixth floor. The reversal of the direction of travel of car No. 2, as it is brought to a stop, is prevented by the action of reversal control relay RC which, as described in connection with Figure 27, deenergizes the automatic reversal relay as soon as the up floor relay is reset, the call being an up one signifying that the intending passenger desires to be carried in the up direction.

If the down hall button at the sixth floor had been pressed instead of the up button, this would not have affected car No. 2, as the circuit for coil THD995a would be maintained upon the separation of contacts 919 of the down sixth floor relay through contacts 6S910 of elevator No. 2 sixth floor selective relay. Thus, the pressing of this button, if car No. 2 were at the ground floor, would not cause the lighting of elevator No. 2 pilot light and, if the car was about to stop at a floor below to discharge a passenger with no up push buttons operated between this floor and the seventh floor and no car buttons operated for floors above the one at which the stop was being made, the engagement of contacts TC1005a incident to stopping the car in response to the car button for this floor below would cause the completion of the circuit for the automatic reversal relay so that the direction of travel of car No. 2 would be reversed as the car was brought to a stop.

Car No. 1, which is the leading up car, will answer all up calls ahead of it and also a down call provided it is the highest call. However, as soon as circuits are set up to make a reversal stop, 5 contacts PA941 separate, rendering the next effective up car subject to all up hall buttons for floors above the effective position of that car. This is due to the fact that elevator No. 1 elongated brush 972 is no longer effective to by-pass 10 up hall calls above car No. 1. For a like reason, the next effective up car is rendered subject to all down hall buttons for floors above car No. 1 but not below car No. 1. The rendering of the 15 next car subject to down hall calls above car No. 1 is due to the fact that elevator No. 1 elongated brush 973 is no longer effective to by-pass down hall calls above car No. 1. Down hall calls below car No. 1 still cannot affect up cars below car No. 1 because the back contacts of the floor relays 20 for floors below car No. 1 are by-passed by elevator No. 1 selective relay contacts for the respective floors, preventing the deenergization of the down topmost hall call relays THD for all 25 up cars below car No. 1.

Should a following up car in effect pass the leading up car, the car which passes, in becoming the leading car, renders the previously leading car subject only to up hall calls for floors between the effective positions of the two cars, 30 elongated brushes for the now leading car bypassing the back contacts of the floor relays for floors above the now leading car and the selective relays for such intervening floors for the now leading car bypassing the back contacts of the 35 down floor relays for such floors. The now leading car, in passing the previously leading one, becomes immediately subject to all up calls above and a down call above, when it is the highest call, in place of the previously leading car. When 40 any up following car is reversed, it will answer down hall buttons for floors in effect below the car during its subsequent downward travel. The connection of the contacts of the selective relays directly across the back contacts of the floor 45 relays renders the circuits through the contacts of the selective relays subject to the rectifiers, thereby avoiding unwanted circuits through contacts of the selective relays. If the non-stop button for a car is pressed, additional contacts ANS940 and ANS997 on the non-stop relay are separated, 50 not only rendering brush 972 ineffective to provide a feed for any lower up reversal brush but also preventing the operation of the selective relays S for that car, thereby rendering that car ineffective to control the effectiveness of the hall 55 buttons as regards other cars so long as the car is operating non-stop.

Thus, with the control arrangement of Figure 28, no up car is subject to any hall call which 60 is answerable by a car ahead.

The control arrangement of Figure 28 may be arranged so as to cause the cars, once started in the up direction, to travel to a predetermined intermediate floor before reversing. Such arrangement is illustrated in which service switches are provided in the wires connecting the stationary contacts arranged to be engaged by brushes 964 and 964a to the bus bars RU and RD. To make the cars always travel to a predetermined landing before they can be reversed, all 65 of these service switches for floors below that floor are opened. To illustrate the principles involved, these service switches are shown in the connecting wires only as high as those for the 70 sixth floor.

If it is desired to make the cars always travel to the seventh floor as the predetermined floor before they can be reversed, the service switches in all the connecting lines for floors below the seventh floor, namely, switches 991 and 991a for the first floor, 983 and 983a for the second floor, similarly located switches (not shown) for the third, fourth and fifth floors, and switches 971 and 971a for the sixth floor, are opened. The 5 opening of these switches prevents the energization of the coil of the up topmost hall call relay THU for any up travelling car before the car in effect reaches the seventh floor, thereby preventing the reversal of the direction of car travel of any up travelling car at any floor below the 10 seventh floor.

If it is desired to change the floor to which the cars must travel in the up direction before they can be reversed, this may be done by manipulation of the service switches. For example, if it is desired to have the cars always run to the sixth floor instead of the seventh floor before they can be reversed, service switches 971 and 971a are closed and the service switches for floors 15 below are left in open condition.

The cars in the control arrangement of Figure 27 may likewise be caused to always travel in the up direction to a predetermined floor before they can be reversed by providing service switches in the wires connecting the stationary 20 contacts engaged by brushes 807 and 807a to the bus bars R and manipulating these switches in the same manner as those of Figure 28 to select the intermediate floor to which it is desired to have the cars travel.

Instead of the arrangement employing service switches 971, 983, and 991, the car buttons in the respective cars for the selected floors may be locked in or by-passed by service switches to cause the cars always to travel upwardly to 30 a predetermined floor before reversing. In the latter arrangement, this floor can be made different for different cars.

The car delay relay CD of the control arrangement of Figure 28 is provided to insure that there will be no unwarranted delay in servicing floors above any up car. The coil CD1012 of the car delay relay for each elevator is subject to contacts H1013 of the brake and field switch for that elevator so as to cause the relay 40 to operate as soon as the car starts and to maintain the coil of the relay energized until the car is brought to a stop. Each relay is provided with two pairs of forward contacts, one pair, CD938, being arranged in the feed line to elongated brushes 972 and 973 and the other pair, CD990, being arranged in the feed line to the coils of the selective relays S. These contacts 50 are timed in opening, as by a dashpot, so as to prevent the opening of the circuits in which the contacts are arranged until a predetermined time interval after the separation of contacts H1013 to deenergize the relay coil.

The time interval of the relay may be adjusted to suit the requirements of any particular installation. For example, in an installation for handling passenger traffic alone, the time interval of the relay may be set for say fifteen 60 seconds, which would be more than the time required to make an average stop. Thus, should more than fifteen seconds be consumed by an up travelling car in making a stop, contacts CD938 and CD990 of the car delay relay open. The separation of contacts CD990 deenergizes the 70 75

coils of the selective relays for that car, removing the by-passes affected by the selective relays for the back contacts of the down floor relays. The separation of contacts CD938 breaks the feed to elongated brushes 972 and 973 for that car. Thus, the separation of these contacts renders the coils of the topmost hall call relays, both up and down, for the next up car, subject to the back contacts of all floor relays for floors above the car whose car delay relay contacts have separated to which that car is subject and, if that car is the leading up car, to the back contacts of all floor relays, both up and down, for floors above such next up car. This arrangement in effect acts to cut a car out of service whenever it stops at a landing longer than a predetermined interval of time and transfers to the following car all calls to which it is subject at the time the time interval expires.

20 The car delay relays may also be employed in the control arrangement of Figure 27 if desired. These relays may also be employed in the arrangement of Figure 29 about to be described to take care of unnecessarily long stops 25 at the selected intermediate landing. The car delay relays and the control mechanism therefor may be omitted if desired.

The elevator cars may also be controlled as regards hall calls so as to cause a car to travel 30 in the up direction above a selected floor when there exists a hall call for a floor above and no other cars are in effect above the selected floor or, if there are in effect one or more cars above, 35 provided the call is in effect behind such cars above the selected floor. If the selected floor be an intermediate floor, a car is caused to travel above that floor also if it is the one which answers an up hall call at that floor when such call has been registered. The arrangement also involves 40 lighting the pilot light in each car as it arrives at the selected floor under conditions where the car is to travel in the up direction from that floor. Once a car is started from this selected 45 floor, it is caused to continue in the up direction until circuits have been set up to answer the highest call then existing. Even then the car is caused to continue in the up direction if the highest call is answered by another car, provided a call exists between this car and the other car. Otherwise, the car is slowed down and 50 stopped at the next floor at which a normal stop can be made unless a call above is registered before circuits are set up for such next floor. In this way, when a car is serving floors above the 55 selected floor and conditions arise to cause another car to travel in the up direction from the selected floor, this other car is caused to give the first car a maximum amount of help without always travelling to the upper terminal.

50 Such arrangement of control is shown in Figure 29, in which only enough of the circuits for two elevators are illustrated to show the manner in which the system differs from the arrangement of Figures 24b and 25 and to illustrate the principles involved. The control circuits for several intermediate floors are again omitted to simplify the drawings.

In the arrangement shown, the series arrangement of back contacts of the floor relays, the reversal contacts and brushes on the selectors and the control of the topmost car call relay TC by the car buttons is the same as that of Figures 24 and 25. In addition to this, mechanism is provided for selecting the cars to travel above the

selected floor. This mechanism comprises the following relays for each elevator:

CS—Car selecting relay
CB—Car behind relay
SR—Selective reset relay

The car selecting relay CS and selective reset relay SR for each car are controlled by an additional column of contacts and cooperating brush on its corresponding selector and service switches common to the cars for determining the selected floor. Each call behind relay CB is controlled by two additional columns of contacts, one for up and one for down, and cooperating elongated brushes on each selector, in conjunction with additional back contacts common to all cars on each floor relay and service switches common to all cars operable in conjunction with the service switches for the car selecting relay to determine the selected floor.

In describing the operation of the control arrangement of Figure 29, car buttons will be considered only to the extent that they affect apparatus shown in this figure, as each car answers its car buttons as set forth in describing Figures 24 and 25, i. e., each car proceeds in the up direction until its highest car button pressed is answered, regardless of whether this button is for a floor above or below the selected floor and regardless of the hall buttons pressed. Assume that it is desired to have the seventh floor the selected floor. Service switches 1091 and 1113 are closed and service switch 1082 is opened. These switches may be blades of a manually operable multipole switch which, when operated, closes switches 1091 and 1113 and opens switch 1082. The service switches for the other floors likewise may be blades of multipole switches, all of which are not operated with the seventh floor the selected one, i. e., for example, eighth floor switches 1092 and 1114 are open and 1083 is closed.

The closing of switch 1113 renders contacts 1153 and 1153a "alive", thus preparing the circuits for causing the operation of the selecting relay CS for each up car upon the engagement of contact 1153 for that car by its brush 1177, provided conditions are such that such car is required to travel above the seventh floor. The closing of switch 1091 renders contacts 1152 and 1152a "alive", insuring the operation of the call behind relay CB for each up car upon engagement of contact 1152 for that car by its brush 1184. The opening of switch 1082 prevents the operation of the topmost hall call relay for each up car before the engagement of reversal contact 1150 for that car by its brush 1182. The brushes are set so that brush 1182 engages its contact for the selected floor before brush 1177 engages its contact, which occurs before the engagement of brushes 514 and 515 (Figure 24b) with their contacts for that floor.

Assume that car No. 1 is started in the up direction from the ground floor. Upon the engagement of elongated brush 1184 with seventh floor up contact 1152 a circuit is completed for coil CB1201, causing the operation of elevator No. 1 call behind relay, if this relay is not already operated. This circuit may be traced from elevator No. 1 positive supply line through coil CB1201, additional contacts PA1200 on auxiliary direction switch PA, brush 1184, contact 1152, call behind bus bar CBU1, service switches 1091 and 1066 to the negative supply line.

Assume further that there is no call to be

answered by car No. 1 at or above the seventh floor. Therefore elevator No. 1 topmost car call relay TC is not in operated condition at the time that cam 1181 opens seventh floor brush switch 5 1149 so that contacts TC1194 and TC1212 are in engagement and contacts TC1197 are separated. Also coil TH1223 of elevator No. 1 topmost hall call relay is energized upon the engagement of brush 1182 with seventh floor reversal contact 10 1150 to by-pass open service switch 1082, causing the engagement of contacts TH1209 and the separation of contacts TH1190. The engagement of contacts TC1212 and TH1209 causes the operation of elevator No. 1 automatic reversal relay AR. 15 This relay operates, in turn, to cause the car to be slowed down and stopped at the seventh floor and to be set for the opposite direction of travel as it comes to rest.

Elevator No. 1 selective reset relay SR is operated upon the engagement of brush 1177 with 20 seventh floor contact 1153. The purpose of relay SR will be explained later. Elevator No. 1 car selecting relay CS is not operated as a result of the engagement of brush 1177 with contact 1153 25 because both contacts TC1197 and TH1190 are separated. Therefore the car selecting relay does not influence the car under the conditions assumed. Thus, contacts CS1120 remain separated, so that pilot light 1123 is not lighted. This advises the attendant that his car is not to run above 30 the selected floor.

Assume now that the up eighth floor hall button had been pushed so that back contacts 1074 of the up eighth floor relay are separated as brush 35 1182 engages seventh floor contact 1150. Therefore, the topmost hall call relay is not operated so that contacts TH1209 are separated, preventing the operation of automatic reversal relay AR to cause the car to be slowed down, stopped and 40 reversed at the seventh floor. Also, contacts TH1190 are engaged so that the engagement of brush 1177 with seventh floor contact 1153 establishes a circuit for coil CS1196 of elevator No. 1 car selecting relay. This circuit extends from 45 the positive line through back contacts CS1206a, and CS1205 of the car selecting relays in series, contacts SR1192, contacts TH1190, contacts CS1191, contacts TC1194, coil CS1196, additional contacts PU1188 on the up direction switch, contacts CS1186, brush 1177, contact 1153, floor selecting bus bar FS7, service switches 1113 and 1066, to the negative supply line. The car selecting relay, upon operation, engages its contacts CS1187 and CS1198, establishing a self-holding 50 circuit which extends from elevator No. 1 positive supply line C through contacts CS1198, coil CS1196, contacts CS1187, additional contacts PA1185 of the auxiliary direction relay PA, to the negative supply line. Relay CS also separates 55 contacts CS1186 and CS1191 in the initial energizing circuit and contacts CS1217 in a circuit for coil AR1208 of the automatic reversal relay. Contacts CS1191 and TC1194 are provided in the initial energizing circuit for coil CS1196 to prevent 60 unwanted circuits. It also separates contacts CS1206 in the common feed to the hall call initial energizing circuits for the car selecting relays. Inasmuch as contacts CB1216 of elevator No. 1 call behind relay are also separated, no 65 car selecting relay for any other up car arriving at the seventh floor can be operated so long as the assumed condition exists unless as a result of a car button pressed in that car for a floor above the seventh. The purpose of this will be shown 70 later. Relay CS also engages contacts CS1120. 75

This completes the circuit for lamp 1123 which lights, advising the car attendant that his car is to travel above the seventh floor.

Circuits are not set up to cause car No. 1 to be slowed down until brush 514 engages contact 413 5 for the eighth floor (Figure 24b). When this occurs, the up eighth floor hall lantern is lighted and the car is caused to slow down and is brought to a stop at the eighth floor, the car gate and hatchway door opening automatically as the car 10 comes to rest.

If the up seventh floor hall button had been operated instead of the eighth, the action would have been the same to the extent that, due to back contacts 1072 of the up seventh floor relay being separated, coil TH1223 is not energized upon the engagement of brush 1182 with contact 1150 so that elevator No. 1 car selecting relay CS is operated upon the engagement of brush 1177 with contact 1153. The car is thus selected to serve 15 above the seventh floor inasmuch as the pressing of the up button at the seventh floor indicates a passenger to be carried therefrom in the up direction. The car is caused to slow down and stop at the seventh floor as a result of the engagement of brush 514 with seventh floor contact 427 (Figure 24b) but relay AR is not operated to reverse the direction of travel as contacts TH1209 and CS1211 20 are separated.

If a car button in car No. 1 for a floor above 30 the seventh floor, say for the eighth floor, had been the button pressed, coil TC1222 would remain energized upon the opening of seventh floor brush switch 1149 by cam 1181 so that contacts TC1194 are separated and contacts TC1197 35 are engaged at the time that brush 1177 engages contact 1153. Thus a circuit is established for coil CS1196 through contacts TC1197 when this engagement occurs, selecting the car to run above the seventh floor. However, should the car button pressed have been the seventh floor car button, coil TC is deenergized by the opening of switch 1149 by cam 1181 so that contacts TC1197 40 are not in engagement. Thus, if coil TH is energized and its contacts TH1190 separated at the 45 time that brush 1177 engages contact 1153, coil CS1196 is not energized and car No. 1 is slowed down, stopped and reversed at the seventh floor.

If the down hall button at the seventh floor had been the one pressed, coil TH1223 would be 50 energized upon the engagement of brush 1182 with contact 1150 so that contacts TH1190 would be separated at the time brush 1177 engaged contact 1153. Thus, relay CS would not be operated and the car would be caused to slow down, stop and reverse at the seventh floor. If the down button pressed had been for a floor above the seventh floor, coil TH would be deenergized and contacts TH1190 engaged at the time brush 1177 55 engaged seventh floor contact 1153 so that car 60 No. 1 would be caused to travel above the seventh floor.

A car once selected to travel above the seventh floor operates in the same manner as described 65 in connection with the control of Figures 24 and 25, i. e., stops and reverses at the highest car or down hall call. When a reversal stop is made, lamp 1123 is extinguished by the separation of contacts AU1122, advising the car attendant that his car will travel in the down direction from the 70 floor at which the stop is made.

Upon circuits being set up to cause a reversal stop to be made at a floor above the seventh floor, contacts PA1185 separate and contacts PA1195 75

engage, relay PA being arranged to engage contacts PA1195 before separating contacts PA1185 so as to maintain the holding circuit for coil CS1196. The holding circuit for coil CS1196 is now subject to contacts SR1193 of the selective reset relay. This relay, as pointed out before, is operated during upward movement of the carriage upon the engagement of brush 1177 with seventh floor contact 1153. If the car is selected to run above the seventh floor, the operation of the car selecting relay in separating contacts CS1186 prevents the establishment of a holding circuit for coil SR1178 so that the selective reset relay is dropped out upon the disengagement of brush 1177 from contact 1153 as a result of further upward movement of the brush. Upon the reengagement of contact 1153 by brush 1177 during downward movement of the brush, a circuit is again established for the coil of the selective reset relay which operates to separate its contacts SR1193, breaking the holding circuit for the coil of the car selecting relay CS. Thus, the car selecting relay, if operated, is maintained operated so long as the car is in effect at or above 25 the selected floor. Once the car in effect moves out of this zone in its downward operation, the car selecting relay is dropped out.

Auxiliary direction relay PA also operates, upon circuits being set up to cause reversal, to engage contacts PA1202 before separating contacts PA1200. This maintains the call behind relay CB operated, if it be operated. As brush 1184 moves upwardly from contact 1152 it successively disengages contacts for floors above the seventh floor so as to become subject to contacts of up floor relays for the floors, the contacts for which are disengaged by the brush. Before brush 1184 disengages one of these contacts it engages the contact next above so that when the disengagement occurs, the circuit for coil CB1201 must pass through back contacts of the corresponding up floor relay. That is, as brush 1184 leaves seventh floor contact 1152 the circuit for coil CB1201 must pass through up seventh floor relay contacts 1098. Similarly, as brush 1184 moves upwardly off contacts 1144 and 1137, the circuit for coil CB1201 must pass through up eighth and ninth floor relay contacts 1099 and 1100. Upon reversal circuits being established, the circuit for coil CB1201 is transferred by the operation of relay PA to brush 1183. Inasmuch as the controlling circuit for coil CB1201 through the floor relay back contacts from the operated service switch is in the order of back contacts 1098, 1099, 1100, 1107, 1106, 1105, and 1104 of the up seventh, eighth and ninth, tenth, and down ninth, eighth and seventh floor relays respectively, as soon as the circuit for coil CB1201 is transferred it is subjected to back contacts of all up floor relays and to back contacts of all down floor relays for floors above the floor at which reversal is to take place. Assuming that reversal is to take place at the eighth floor, immediately relay PA operates to transfer the circuit for coil CB1201, this coil becomes subject to back contacts 1099, 1100, 1107, and 1106 of the up eighth, up ninth, tenth and down ninth floor relays respectively in addition to up seventh floor relay contacts 1098. As brush 1183 moves downwardly off contact 1143, coil CB1201 becomes subject to back contacts 1105 of the down eighth floor relay. In other words, relay CB is subject to all calls unanswerable by the car for which the relay is provided, i. e., to calls behind the car.

Upon a call behind the car being registered, the separation of the back contacts of the operated floor relay breaks the circuit for the coil of relay CB which drops out.

Assume that car No. 1 has been caused to travel above the seventh floor so that its car selecting relay CS is operated, and while this relay is operated car No. 2, set for up travel, engages its brush 1177a with contact 1153a. Assuming further that no calls exist above the seventh floor, which cannot be answered by car No. 1, that the up hall button at the seventh floor is not operated and that no car button in car No. 2 is operated for a floor above the seventh floor, the circuit for coil CS1196a of elevator No. 2 car selecting relay cannot be established owing to the fact that elevator No. 1 call behind contacts CB1216 and elevator No. 1 car selecting relay contacts CS1206 are separated. Elevator No. 2 selective reset relay SR, however, is operated and engages its contacts SR1218a so that, even though elevator No. 2 topmost hall call relay TH is not operated due to the fact that an unanswered call exists above the seventh floor, a circuit is established through contacts CS1217a by the engagement of contacts SR1218a for coil AR1208a of elevator No. 2 automatic reversal relay, causing car No. 2 to be slowed down and stopped at the seventh floor and its direction of travel changed to down. Thus, under conditions where a hall call exists at or above the selected floor which requires travel above the selected floor but which can be answered by a car already selected to travel above the selected floor, another up car subsequently arriving in effect at the selected floor is not caused to travel above this floor in response to such hall calls.

Should a car button in car No. 2 for a floor above the seventh floor have been pressed, the engagement of brush 1177a with contact 1153a would have established a circuit for the coil of elevator No. 2 car selecting relay CS to select car No. 2 to also travel above the seventh floor, the circuit for coil CS1196a extending through contacts TC1197a, which circuit is independent of contacts CB1218 and CS1206.

When an up hall call exists at the selected floor or a hall call exists above the selected floor which cannot be answered by a car already selected to travel above the selected floor, due to the position of its brushes, the next up car in effect to arrive at the seventh floor is selected to travel above the selected floor. Assume, for example, that after car No. 1 has been selected to travel above the seventh floor and its brush 1177 has passed off contact 1153 for the seventh floor, that the up seventh floor hall button is pressed. Assume further that with car No. 2 set for up car travel, its brush 1177a engages contact 1153a while the brushes of car No. 1 are still within the zone above the seventh floor. Owing to the fact that the button pressed is an up button, car No. 2 will be caused to slow down and stop at the seventh floor in the same manner as described in connection with Figures 24 and 25. However, owing to the disengagement of elevator No. 1 elongated brush 1184 from seventh floor contact 1152 as brush 1177 left seventh floor contact 1153, the separation of contacts 1098 of the up seventh floor relay broke the circuit for coil CB1201 of elevator No. 1 call behind relay. Thus, contacts CB1216 are in engagement and the engagement of elevator No. 2 brush 1177a with contact 1153a establishes a circuit through contact CB1216 for elevator No. 2 car selecting relay. Thus, car No. 2 is also sectioned to travel above the selected floor.

- under the conditions assumed. Owing to the fact that under such conditions elevator No. 2 topmost hall call relay TH is not operated, its contacts TH1209a are separated, preventing the establishment of a circuit for the coil AR1208a of elevator No. 2 automatic reversal relay. Contacts SR1218a of elevator No. 2 selecting reset relay, which is operated at the same time elevator No. 2 car selecting relay is operated, are timed sufficiently to permit the separation of contacts CS1217a, preventing the establishment of a circuit for coil AR1208a through contacts CS1217a and SR1218a and thereby preventing the reversal of the direction of travel of car No. 2 as it is brought to a stop at the seventh floor. Contacts SR1192a of the selective reset relay act to prevent the operation of relay CS once relay SR is operated, contacts SR1192a being timed along with contacts SR1218a.
- 20 A following car is caused to travel above the selected floor when another car has already been selected to travel above that floor so long as there exists a hall call which cannot be answered by the previously selected car, i. e., a call behind this car, regardless of whether it be an up hall call or a down hall call. For example, assuming car No. 1 to have already been selected to travel above the seventh floor and that it has answered the highest call, reversed its direction of travel 30 and has moved its brushes downwardly past the eighth floor selector contacts at the time the eighth floor down hall button is pressed. As soon as the down eighth floor relay separates its contacts 1105, the circuit for elevator No. 1 call behind relay CB1201 is interrupted, thus preparing the initial hall call energizing circuit for the car selecting relays of the other elevators. Therefore, the subsequent engagement of brush 1177a in its upward movement with contact 1153a 40 of the No. 2 selector establishes a circuit for coil CS1196a of elevator No. 2 car selecting relay, selecting this car to travel above the seventh floor under the conditions assumed.
- When the car in the zone above the seventh floor in effect moves down out of the zone, i. e., its brush 1177 moves downwardly off seventh floor contact 1153, the dropping out of its relay CS by the action of relay SR renders the common hall call initial energizing circuit for the coils of all CS relays effective, regardless of the condition of contacts CB1216 of the call behind relay so that the next car in effect to arrive at the seventh floor is caused to travel above this floor when conditions require it.
- 55 If an additional car has been selected to travel above the selected floor, it will operate to give the maximum amount of help to a car or cars already selected to travel above the floor, without traveling to the upper terminal floor unless a call exists for that floor which should be answered by this car. Whenever a condition exists that both contacts TC1212 and TH1209 become in engagement, a circuit is completed for the automatic reversal relay for the subsequently selected car to cause 65 its direction of travel to be reversed as it is brought to a stop. This condition may exist as a result of this car answering its highest operated car button, the highest down hall call, or the answering of the highest hall call by a car 70 in effect ahead under conditions where no calls exist between the effective positions of the car ahead and this following car. Should hall calls exist between these cars, the following car is caused to continue its upward travel until such 75 calls are answered. In other words, the cars oper-

ate above the selected floor in the same manner as the cars in accordance with the control system of Figures 24 and 25.

If it is desired to make some floor other than the seventh floor the selected floor, this may be accomplished by opening the seventh floor multi-pole service switch and operating the multi-pole service switch for the other floor. By operating the first floor service switch 1110, the car may be caused to operate from the first floor as the selected floor. Additional service switches 1199 and 1199a are provided for the first floor and in conjunction with switch 1110 form a multi-pole switch. Service switches 1199 and 1199a, when closed, short-circuit contacts SR1192 and SR1192a in the initial hall call energizing circuits for car selecting relays CS.

With the first floor selected, the car selecting relays operate as the cars in effect arrive at the first floor during their downward operation, provided hall calls exist above the first floor which cannot be answered by cars above that floor in their normal operation. The short-circuiting of the back contacts of the selective reset relays SR permits the operation of the car selecting relay for a car already at the first floor at the time a call is registered which is unanswerable by any car above the first floor in its normal operation.

Assume that the first floor is the selected floor and that car No. 2 is operating above this floor as car No. 1 arrives at the floor. Upon the engagement of brush 1177 with contact 1176, selective reset relay SR is operated to break the holding circuit for elevator No. 1 car selecting relay CS which drops out. As the car reaches the first floor level, its direction of travel is reversed as a result of the engagement of brush 621 with contact 620 (Figure 24c). The resultant engagement of contacts PA1200 of the auxiliary direction relay establishes a circuit for elevator No. 1 call behind relay CB through elongated brush 1184, contact 1175 and switch 1088. If a hall call exists above the first floor the engagement of contacts AU1220 does not establish a circuit for coil TH1223 so that contacts TH1190 are in engagement. If this hall call is unanswerable by car No. 2, elevator No. 2 call behind relay contacts CB1216a are in engagement, so that the engagement of contacts PU1188 establishes a circuit for elevator No. 1 car selecting relay CS. This causes the lighting of the pilot light 1123 advising the attendant that his car is required for calls above the first floor. If no hall call exists which car No. 2 cannot answer, contacts CB1216a are separated, preventing the establishment of a circuit for coil CS1196 by the engagement of contacts PU1188 through the hall call energizing circuit. Thus, relay CS is not operated and pilot light 1123 is not illuminated, so that the attendant is advised that no calls exist above the first floor which cannot be handled by some other car. Contacts UL1207 are separated with the car at the first floor, preventing the establishment of a circuit for coil AR1208 as a result of both contacts CS1217 and SR1218 being in engagement.

Should a passenger enter car No. 1 at the ground floor and a car button in car No. 1 be pressed for a floor above the first floor, the resultant engagement of contacts TC1197 establishes a circuit for coil CS1196 through the car button energizing circuit. This causes the operation of the car selecting relay, which establishes its self-holding circuit through contacts PA1185 of the auxiliary direction relay. If, instead of the car button, a hall button is pressed which is not

answerable by car No. 2, elevator No. 2 call behind relay CB is deenergized, engaging contacts CB1210a to establish a circuit for coil CS1138. The engagement of contacts CS1120 in either case establishes a circuit for pilot light 1123, advising the car attendant that the car should leave the first floor.

The air gaps of the car selecting relays CS may be adjusted so that only one of them operates in the event that more than one car is in position to be selected at the time that the common circuit to the coils of these relays is completed. Thus, for example, if two cars are at the first floor at the time a call unanswered by a car above is registered, only one of these cars will be selected to operate above the first floor in response to this call.

Each car selected to operate above the selected floor may be caused to continue its upward travel to the upper terminal floor if desired. An arrangement for providing this operation is illustrated, which comprises a multi-pole service switch having blades 1124 and 1124a which, when closed, renders the topmost car call relay for each car subject to contacts of the car selecting relay for that car. With this service switch closed, upon operation of the car selecting relay for car No. 1, for example, its contacts CS1121 engage, establishing a circuit through switch 1124 for coil TC1222. Inasmuch as car selecting relay CS, once operated, is maintained operated until the car passes back out of the zone above the selected floor, the topmost car call relay is maintained operated by contacts CS1121 over the same period, preventing the reversal of the direction of car travel for the car until the upper terminal floor is reached.

The elevator cars may also be controlled, as regards hall calls above a selected floor, to cause the car to travel above the selected floor when one or more other cars are in effect already above that floor only in the event that a hall call exists which is in effect behind such cars above the selected floor or when the demand for service above the selected floor reaches a certain amount. When a car is caused to travel above the selected floor, owing to the increased demands for service, it is caused to continue in the up direction to provide a maximum amount of help without always travelling to the upper terminal.

Such arrangement of control is also shown in Figure 29, where it is subject to service switch 1052. The additional mechanism comprises the following switches:

FCC—First call counting relay
SCC—Second call counting relay
DS—Demand for service switch
FA—First arrival relay
SA—Second arrival relay

There may be the same number of car arrival relays as there are cars in the group operating under this arrangement of control and there may be one less call counting relay than the number of such cars. The forward contacts of the floor relays, in addition to controlling the connection of the reset coils of the floor relays to the negative supply line also connect, in this arrangement, resistances 1037—1048 in parallel in a circuit for the call counting relays. Only one floor relay reset coil, designated 1038, is shown to illustrate the connections. For purposes of changing the selected floor, a series of service switches is provided between the resistances controlled by the floor relays for each floor. These switches are

preferably blades on the multi-pole switches previously referred to, i. e., switch 1055 for the seventh floor would be arranged on the same multi-pole switch as switches 1082, 1081, and 1113 for that floor. This additional control mechanism is rendered effective by the closing of service switch 1052.

With switch 1052 closed, assume that the sixth floor is selected as the one above which cars are operated only if conditions require it. Therefore switches 1055 and 1081 are open and switches 1080 and 1112 are closed. The opening of switch 1055 renders the call counting relays subject only to the counting resistances controlled by the up-and-down floor relays at the seventh, eighth and ninth floors and the floor relay at the tenth floor. Assume further that car No. 2 is the one first in effect to arrive at the sixth floor in its upward travel and that, due to hall calls existing above the sixth floor, it is selected to travel above this floor. Upon the engagement of brush 1117a with contact 1161a, a circuit is established for the coil of elevator No. 2 car selecting relay CS, which engages its contacts CS1060a, establishing a circuit for the coils FA1065 and FA1062 of the car arrival relays through resistance 1068. These relays are designed so that the inclusion of only one of the resistances 1061 and 1064 in the circuit for these coils causes the operation of the first arrival relay FA but not the second arrival relay SA, while the inclusion of both resistances operates both relays. In other words, this arrangement counts cars which are selected to run above the selected floor so that when one car is selected the first arrival relay FA operates, when two cars are selected the second arrival relay SA operates and when three cars are selected the third arrival relay operates, and so on.

The first arrival relay FA, upon operation, engages contacts FA1032 to complete a circuit for coil FCC1051 of the first call counting relay through adjusting resistance 1080, contacts SA1033 of the second arrival relay, service switch 1052 and the resistances connected in parallel in the circuit by contacts of operated floor relays for floors above the sixth floor. If car No. 2 had been selected to run above the sixth floor as a result of an operated car button in car No. 2 for a floor above the sixth floor under conditions where no hall calls were registered above this floor, the engagement of contacts FA1032 simply prepares the circuit for coil FCC1051. The operation of elevator No. 2 car selecting relay not only separates contacts CS1206a in the hall call initial energizing circuit common to the car selecting relays but also engages contacts CS1203a in a by-pass circuit for contacts CS1206a, subject to the engagement of contacts DS1218 of the demand for service switch.

When the unanswered hall calls above the sixth floor reach a predetermined number, say four, four resistances are connected in parallel in the circuit for coil FCC1051. Thus, sufficient voltage is applied to the coil of the first call counting relay FCC to cause this relay to operate. Upon operation, the relay engages contacts FCC1058, completing a circuit for coil DS1080 of the demand for service switch. This switch operates to engage contacts DS1218 and DS1219, contacts DS1218 by-passing contacts CS1206a in the hall call initial energizing circuit common to the car selecting relays, so that the car selecting relay for the next up car in effect to arrive at the sixth floor will be completed.

gardless of whether contacts **CB1216a** are closed or open.

Assume that car No. 1 is the next up car whose brush **1177** engages contact **1161** for the sixth floor. As this engagement takes place, a circuit is completed for the coil of elevator No. 1 car selecting relay **CS** through contacts **CS1205a** and **DS1219**, assuming all calls above the sixth floor are ahead of car No. 2; if not, also through contacts **CB1216a**. Thus car No. 1 is also selected to run above the sixth floor to help out car No. 2.

Elevator No. 1 car selecting relay, upon operation, engages contacts **CS1060** which connects **resistance 1061** in parallel with resistance **1064**, causing sufficient voltage to be applied to coil **SA1062** of the second arrival relay to operate this relay. This relay engages contacts **SA1018** and separates contacts **SA1033**. This deenergizes **coil FCC1051** of the first call counting relay and energizes coil **SCC1017** of the second call counting relay through adjusting resistance **1016**. Relay **FCC** separates contacts **FCC1086**, deenergizing coil **DS1080** of the demand for service switch. This switch separates its contacts **DS1215** and **DS1219**, removing the by-pass for contacts **CS1206a**. The second call counting relay **SCC** is designed to require a higher voltage to effect its operation, i. e., a greater number of parallel resistances connected in its circuit and therefore a larger number of unanswered hall calls registered. Should the required number of unanswered hall calls above the selected floor be registered, the second call counting relay operates and engages contacts **SCC1078**, causing the reoperation of the demand for service switch **DS** to engage its contacts **DS1219** and **DS1215**, thus by-passing not only contacts **CS1206a** of elevator No. 2 car selecting relay but also contacts **CS1206** of elevator No. 1 car selecting relay through contacts **CS1205**. This again prepares the hall button initiating circuit common to the car selecting relays so that the next up car in effect to arrive at the sixth floor has its car selecting relay operated and is caused to travel above that floor to help out the other two cars.

Even though insufficient unanswered calls exist to cause the operation of a call counting relay when a car is above the selected floor, the existence of an unanswered hall call behind that car deenergizes the call behind relay for that car, thereby preparing the hall button circuit common to the car selecting relays. Thus, upon the next up car in effect arriving at the sixth floor, its car selecting relay is operated. Likewise, the car selecting relay for an up car is operated upon its arrival in effect at the sixth floor under conditions where a car button in that car for a floor above the sixth floor is operated. Thus, when no other car is in effect above the selected floor, a car is caused to travel above that floor when it has a passenger for a floor above, when an up hall call exists at that floor and when any hall call exists for a floor above that floor. When a car has been selected to travel above that floor, another car is caused to travel above that floor when a car button in that car is pressed for a floor above, when a hall call requiring travel above that floor exists behind the car already selected, and when the number of unanswered hall calls above that floor and ahead of the car already selected reaches a predetermined amount.

Regardless of the condition which causes a

car to be selected to travel above the selected floor, when the first car is selected, the first arrival relay **FA** is operated so that as regards hall calls above the selected floor ahead of the car already selected, a certain number must be registered before another car is selected to travel above the selected floor due to the demands for service. Likewise, regardless of the condition which causes a second car to be selected to travel above the selected floor, when the second car is selected, the second arrival relay **SA** is operated, so that as regards hall calls above the selected floor ahead of that one of the cars already selected which is in effect behind the other selected car, a certain number must be registered before a third car is selected to travel above the selected floor due to the demands for service.

The arrangement of the car counting relays permits their operation at selected numbers of calls, which may be varied by means of the adjusting resistances **1016** and **1050**, if desired, for example, upon changing the selected floor. To change the selected floor, the service switches are operated as before. For example, to change from the 6th to the 7th floor, service switch **1056** is opened and service switch **1055** is closed, this operation occurring at the same time the service switches for the other circuits are operated as a result of having them parts of the same multi-pole switches. With the first floor as the selected floor, all the service switches **1053**—**1058** are closed so as to render the call counting relays subject to all resistances.

If desired, a car can be caused to run above a selected floor as regards hall calls above this floor only in the event that with another car already selected to travel above the selected floor, a predetermined number of unanswered calls are registered. In other words, the feature of having the car travel above the selected floor when a hall call is registered which is unanswerable by the car already selected could be omitted. This may be done by means of a service switch **1204** in series with contacts **CB1216** of each call behind relay, these switches being open when it is desired to cut out the call behind feature.

By closing service switches **1124** each car can be caused to always travel to the upper terminal floor, once selected to travel above the selected floor, as was the case without the demand for service control. To cut out the demand for service control, service switch **1052** is opened. By opening service switch **1066** all cars can be caused always to travel to the upper terminal floor, once started from the lower terminal, regardless of conditions, the same as in the control of Figures 24 and 25.

In reviewing the operation of the control system according to Figures 24 and 25, passengers upon entering the car call out their desired destinations, which are registered by the car attendant by pressing car buttons for the floors announced. The attendant closes the door and gate and starts the car by moving the starting switch to the start position. The advance mechanism starts the advancing operation immediately, which is completed preferably before the door and gate reach closed positions. When the door and gate are closed, the car starts, the starting switch being released after the car attains a certain speed.

The car is caused to slow down and stop at the first floor for which the advance car button brush engages an "alive" selector contact or the advance hall button brush for the direction of car

travel engages an "alive" selector contact. This may occur while the car is stationary or in motion. Upon the arrival of the car a certain distance from such floor, the car is caused to slow down and is thereafter brought to a stop at the landing, the slow-down being controlled by the action of the selector switches. The car gate and hatchway door for that floor are opened automatically as the stop is made, permitting the passenger transfer to be made immediately the car comes to a stop. The hall lantern at that floor for that car and for the direction in which the car is travelling is lighted immediately the engagement of the brush with the "alive" contacts occurs, thus providing maximum duration of the period during which intending passengers at the floor are advised of the approach to and presence of the car at the floor, and its direction of travel.

Immediately the transfer of passengers has been completed, the attendant advances the starting switch. This causes the operation of the advancer mechanism and the closure of the car gate and hatchway door. Upon the door and gate reaching closed position, the car is started. The lighted hall lantern is extinguished immediately the starting switch is advanced, without waiting on the closure of the door and gate. This eliminates the attraction of intending passengers to the car after the starting switch has been operated.

Assuming that the car is set for up travel and that service switch 313 is open, the car continues its travel in the up direction after each stop until the upper terminal floor is reached. Car buttons for succeeding floors and up hall buttons for succeeding floors, if operated before the selector brushes disengage the corresponding stationary contacts, cause the car to be stopped, during the trip, at the floors for which the buttons are provided. The car gate and hatchway door at the floor open automatically upon each stop and the proper hall lantern is lighted as soon as the call is "picked up".

As the car nears the upper terminal, it is slowed down automatically and finally brought to a stop. The gate and hatchway door at the terminal floor open automatically and the terminal floor down hall lantern for that car is lighted. Also, the car is set for travel in the down direction so that, upon the starting switch being operated and the gate and door closed, the car is started in the down direction. Car buttons and unanswered down hall buttons are responded to during the trip of the car to the lower terminal floor.

The car buttons in each car control only that car. The hall buttons are common to all of the elevators in the group and a call registered by the pressing of a hall button may be answered by any one of the cars. The car which answers a call registered by a hall button is selected automatically in accordance with the effective positions of the cars, i. e., the relative positions of the advancer brushes of the different elevators, and the direction of travel of the cars. When the hall button is answered, the registration of another call by this button is prevented until after the starting switch has been operated to restart the car, preventing later false stops. This is due to the reset brush for the car which is answering the button remaining in contact with the selector contact, thereby maintaining the reset coil of the floor relay energized so long as the button is pressed. This prevents the latching of the relay in operated condition and

it falls out as soon as the button is released. The floors are served in their natural order, regardless of the order in which the buttons were pressed.

If a hall button is pressed after a car in effect has passed the floor at which the button is located, i. e., after the disengagement of the selector stationary contact controlled by the hall button by its brush, with the car set for a direction of travel corresponding to that of the button pressed, the call registered by the button is reserved for the next car set for the corresponding direction of car travel in effect to reach its slow down point for that floor, i. e., whose selector stationary contact controlled by the hall button is engaged by its brush. However, if circuits have been set up to cause the car to stop at a floor in response to its car button for that floor, the pressing of the hall button for that floor, for the direction of travel for which the car is set, after the circuits controlled by the car button for causing slow down have been established, does not register a call as conditions are such that a stop is being made which will satisfy this operation of the hall button. If the pressing of the hall button is delayed until after the attendant operates the starting switch, the reset coil of the floor relay is not energized and the call is registered and reserved for the next car set for the corresponding direction of car travel whose brush engages the stationary contact rendered "alive" by the floor relay.

The elevators may be changed from terminal-to-terminal operation to operation whereby the direction of travel of any car set for up car travel is reversed automatically when, at the time that circuits are set up to cause the car to be slowed down and brought to a stop at a floor, no push buttons are pressed which require or indicate further travel in the up direction from that floor. Under these conditions a car may stop in its upward travel in response to a down hall button at the floor at which the button is located, provided no buttons have been pressed requiring further travel of the car in the up direction. When circuits are set up to cause a car to respond to the highest call, each of the other cars set for up car travel is reversed at the next floor for which brush 517 therefor engages a stationary contact, provided no push button for a floor between the point corresponding to the position of the brush and the floor for which the highest call exists remains to be responded to at the time the engagement occurs. If such push button is pressed, all cars whose brushes 517 are below the selector stationary contacts for that button are caused to continue their upward travel until circuits are set up for one of them to answer the call. Each car will go to the highest floor for which a car button in the car is pressed, regardless of the hall buttons operated.

The elevators may be arranged so that, once started in the up direction, they will travel at least to a predetermined floor, which may be the same for all cars or different for different cars, before automatic reversal can take place, regardless of whether any buttons for such floor or floors intervening that floor and the ground floor are operated or not. If this floor be made the same for all elevators, a car may be controlled so that it is not stopped at that floor when a push button for a floor above has been pressed unless the car button in that car for that floor or the hall button for that floor for the direction in which the car is travelling has been pressed.

The control for the elevators may also be arranged, for example, as shown in Figure 27, so that as regards hall calls, an up car is not affected by any hall call which is in effect ahead of any other up car which is in effect above such car, but is affected only by unanswered up and down hall calls which are in effect between it and the car in effect next above. As regards such down hall calls, the car is caused to answer a down hall call when no higher car call exists for the car and no higher hall call exists between the effective position of the car and that of the car in effect next above. Its direction of travel is reversed incident to answering this call as it is in answering its highest car call under conditions where no hall call above is registered which is below the effective position of the car in effect next above.

The control may also be arranged, for example as shown in Figure 28, so that an up car is not affected by down hall calls unless it is in effect the leading car. In other words, no up car is subject to any hall call which is answerable by another up car which is in effect ahead. With such arrangement, the direction of travel of a following up car is reversed upon the car answering its highest car call.

The control for the elevators may be arranged, for example as shown in Figure 29, so that an up car is not caused to travel above a selected floor when a car is already in effect above such floor unless a car call exists therefor for a floor above this floor or a hall call exists requiring or indicating travel above such floor, which is in effect behind such car above. With such arrangement, a signal is given the car attendant upon his arrival at the selected floor advising him when his car is to travel above the selected floor. An up car may also be caused to travel above the selected floor when the unanswered hall calls for floors above the selected floor reach a predetermined number. Each car selected to operate above the selected floor continues in operation in the up direction until its highest car or down call is reached, whereupon its direction of travel is reversed. Any up car sent up above the selected floor to help out another car continues its upward travel so long as unanswered calls exist above it. If desired, any car selected to operate above the selected floor may be caused to travel to the upper terminal before reversing.

It is contemplated that many of the features of the invention disclosed may be used in connection with apparatus and circuits different from those specifically described and also in connection with other forms of elevator control.

Certain of the features are applicable to systems of control in which the starting as well as the stopping of the cars is controlled by the push buttons in the car and at the landings. Also, certain of the features are applicable to arrangements in which the stopping of the cars to discharge passengers is controlled by the attendants' start control switches in the cars or in which stops both to discharge and receive passengers are controlled in this manner.

The start control switch may be employed to effect the final stopping operation after the automatic slow down in response to a push button. This switch may be arranged so that it must be moved to one position to start the car in the up direction and to another position to start the car in the down direction, with the service conditions also exercising control over the direction in which the car can be started. Also, the direc-

tion of travel may be determined solely by the position to which the switch is moved, and the attendant may be advised as to the proper direction of travel as by signal. The operation of the doors may be controlled by a switch solely for that purpose. The doors may be manually operated if desired. In any event, the car will not start until the doors are closed.

The manner of controlling the operation of the hall lanterns may be varied. The cars may be express or local cars. If the cars are express cars, the predetermined landing to which the cars may be made to travel may be the first landing of the local zone.

Various alterations in the control of the hoisting motor may be made. The power supply may be either from direct current or alternating current supply mains. The manner in which the motor is accelerated or retarded may be varied. The operation of the advancer mechanism may be delayed so as to control the rate of acceleration by the selector switches 102, 51, 121, 131, 154, and 162 instead of electrically.

Other forms of control mechanism may be employed. This includes not only the selector machine but also the switches. For example, floor relays maintained operated electrically may be used instead of those mechanically held in operated condition or the hall buttons themselves may be automatically held in operated condition. The systems of control disclosed are very complex and admit of many variations in addition to those mentioned which do not depart from the spirit or scope of the invention. Many apparently widely different embodiments of the invention can be made within the scope of the invention. It is therefore intended that all matter contained in the above description or shown in the accompanying drawings shall be interpreted as illustrative and not in a limiting sense.

What is claimed is:

1. An electric elevator system comprising; an elevator car; a plurality of landings served by the car; car actuating and stopping mechanism; a plurality of controls, one for each of said landings; a plurality of additional controls, one for each of said landings; means responsive to the operation of the first named controls for causing said mechanism to slow down the car, during its travel in a certain direction as it nears each of the landings for which first named controls have been operated; responsive to the operation of said additional controls for causing said mechanism to slow down the car, during its travel in the opposite direction, as it nears each of the landings for which additional controls have been operated, and responsive to the operation of any one of said additional controls for causing said mechanism to slow down the car, during its travel in said certain direction, as it nears the landing for which the additional control is provided, under conditions where neither the first named control for such landing nor any of the controls for landings beyond is operated; means for causing said mechanism to bring the car to a stop at each of the landings for which slow down has been initiated; means for causing the operation of said mechanism to start the car after each stop; and direction control means for causing the direction in which the car is started after each stop to be the same so long as any control for landings beyond the one at which the stop is made remains to be responded to and, in the event that during travel of the car in said certain direction no

- control for landings beyond remains to be responded to, for causing the direction in which the car is started after such stop to be in the opposite direction when the slow down for such stop was made in response to the additional control for such landing but to be in said certain direction when the slow down for such stop was made in response to the first named control for such landing.
- 10 2. An electric elevator system comprising; an elevator car; a plurality of landings served by the car; a start control manually operable from within the car; means responsive to the operation of said start control for starting the car; a plurality of up controls, one for each of said landings; a plurality of down controls, one for each of said landings; mechanism responsive to the operation of said up controls for causing the car, during travel in the up direction, to slow down as it nears each of the landings for which up controls have been operated; mechanism responsive to the operation of said down controls for causing the car, during travel in the down direction, to slow down as it nears each of the landings for which down controls have been operated and also responsive to the operation of any one of said down controls for causing the car, during travel in the up direction, to slow down as it nears the landing for which the down control is provided, under conditions where neither the up control for such landing nor an up or a down control for any landing above is operated; stopping mechanism operable to bring the car to a stop at each of the landings for which slow down has been initiated; and means operable, incident to stopping the car during up car travel at a landing for which slow down has been initiated in response to the down control for that landing, to cause said starting means to start the car away from such landing in the down direction in response to the operation of said start control.
3. An electric elevator system comprising; an elevator car; a plurality of landings served by the car; a manually operable control switch in the car; means responsive to the operation of said control switch for starting the car; a plurality of up push button switches, one at each of said landings; a plurality of down push button switches, one at each of said landings; mechanism responsive to the operation of said up push button switches for causing the car, during travel in the up direction, to slow down as it nears each of the landings at which up push button switches have been operated, responsive to the operation of said down push button switches for causing the car, during travel in the down direction, to slow down as it nears each of the landings at which down push button switches have been operated, and responsive to the operation of any one of said down push button switches for causing the car, during travel in the up direction, to slow down as it nears the landing at which the switch is located, under conditions where neither the up push button switch at such landing nor any of the push button switches at landings above is operated, said mechanism including means for causing said push button switches to be responded to in the natural order of floors for the direction in which the car is travelling, regardless of the order in which the push button switches are operated; stopping mechanism operable to bring the car to a stop at each of the landings for which slow down has been initiated; direction control means for determining the direction in which said starting means starts the car in response to said control switch after each stop; and switching means controlled by said push button switches and operable, incident to answering a down push button switch during up car travel to set said direction controlling means for downward travel as the car is brought to a stop, thereby to cause said starting means to start the car away from such landing in the down direction in response to the operation of said control switch.
4. An electric elevator system comprising; an elevator car; a plurality of landings served by the car; car actuating and stopping mechanism; start control means operable from within the car to cause operation of said mechanism to start the car after each stop; a plurality of up controls, one at each of said landings; a plurality of down controls, one at each of said landings; a plurality of controls within the car, one for each of said landings; means responsive to the operation of said controls for causing said mechanism, during car travel in the up direction, to slow down the car as it nears each of the landings for which up controls or controls within the car have been operated and, during car travel in the down direction, to slow down the car as it nears each of the landings for which down controls or controls within the car have been operated; means responsive to the operation of any one of said down controls for causing the car, during travel in the up direction, to slow down as it nears the landing at which the control is located, under conditions where neither the up control at such landing nor any of the controls for landings above is operated; means for causing operation of said mechanism to bring the car to a stop at each of the landings for which slow down has been initiated; and means for causing said mechanism, once the car has been started in the up direction, to start the car in the up direction in response to the operation of said start control means after each stop so long as any control for landings above the one at which the stop is made remains to be responded to and, in the event that no control for such landings above remains to be responded to, for causing said mechanism to start the car in the down direction from the landing at which the stop is made when the slow down for such stop was made in response to the down control or the control within the car for such landing but to restart the car from such landing in the up direction when the slow down for such stop was made in response to the up control for such landing.
5. An electric elevator system comprising; an elevator car; a plurality of landings served by the car; car actuating and stopping mechanism; switching means manually controlled from within the car for causing operation of said mechanism to start the car; a plurality of up push button switches, one at each of said landings; a plurality of down push button switches, one at each of said landings; a plurality of push button switches within the car, one for each of said landings; means responsive to the operation of said push button switches for causing said mechanism, during car travel in the up direction, to slow down the car as it nears each of the landings for which up push button switches or push button switches within the car have been operated and, during car travel in the down direction, to slow down the car as it nears each of the landings for which down push button switches or push button switches within the car have been operated.

- been operated; means responsive to the operation of any one of said down push button switches for causing said mechanism, during car travel in the up direction, to slow down the car 5 as it nears the landing at which the down push button switch is located, under conditions where neither the up push button switch at such landing nor any of the push button switches for landings above is operated; means operable to cause 10 said mechanism to bring the car to a stop at each of the landings for which slow down has been initiated; and switching means controlled by said push button switches and operable, incident to answering a down push button switch or a push 15 button switch within the car during up car travel, under conditions where neither the up push button switch at the landing for which such down push button switch or push button switch within the car is provided nor any push 20 button switch for landings above is operated, to set the car for downward travel so that said mechanism starts the car away from such landing in the down direction in response to the operation of said manually operable switching 25 means.
6. An elevator system in which the elevator car serves a plurality of landings; means for each of said landings operable to register a call for the landing for which it is provided; a signal; 30 means operable as the car nears a certain one of said landings from a given direction for giving said signal when any call is registered which requires travel of the car beyond such certain landing; means for stopping the car at said landings; 35 means for starting the car; and means for causing the car to be started in the opposite direction from said certain landing when it is stopped thereat under conditions where said signal is not given as it arrives at that landing from said given 40 direction.
7. An electric elevator system comprising; an elevator car; a plurality of landings served by the car; car actuating and stopping mechanism; means operable from within the car after each 45 stop to cause operation of said mechanism to start the car; an up control at each of said landings; a down control at each of said landings; means responsive to the operation of said controls for causing said mechanism, during upward car travel, to slow down the car as it nears each 50 of the landings at which up controls are operated and, during downward car travel, to slow down the car as it nears each of the landings at which down controls are operated; additional 55 means for causing said mechanism, during upward car travel, to slow down the car as it nears a certain one of said landings; means for causing said mechanism, after slow down has been initiated, to bring the car to a stop at the landing at 60 which it is being slowed down; a signal; means for causing said signal to be given as the car, in its upward travel, arrives at said certain landing under conditions where the up control at that landing or any of said controls at landings above 65 are operated; and means for controlling the direction of car travel, said last named means being operable to cause said mechanism to start the car from said certain landing in the down direction in response to the operation of said starting 70 means when said signal is not given as the car arrives at that landing in the up direction.
8. An electric elevator system comprising; an elevator car; a plurality of landings served by the car; car actuating and stopping mechanism; 75 a start control operable from within the car after each stop to cause operation of said mechanism to start the car; an up control at each of said landings; a down control at each of said landings; a control in the car for each of said landings; means responsive to the operation of said controls for causing said mechanism, during upward car travel, to slow down and stop the car at each of the landings for which up controls and controls within the car are operated and, during downward car travel, to slow down and stop the car at each of the landings for which down controls and controls within the car are operated; a signal in the car; means for causing said signal to be given as the car, in its upward travel, arrives at a certain one of said landings under conditions where the up control at that landing or any of said controls for landings above are operated; and means for causing said mechanism, during upward car travel, to slow down and stop the car at said certain landing and to start the car from said certain landing in the down direction in response to the operation of said start control when said signal is not given as the car arrives at that landing in the up direction 10
9. An electric elevator system comprising; an elevator car; a plurality of landings served by the car; car actuating and stopping mechanism; a plurality of controls, one for each of said landings; means responsive to the operation of said controls for causing said mechanism, during car travel in a certain direction, to slow down and stop the car at each of the landings for which controls are operated; means operable from within the car to cause said mechanism to start the car after each stop; means for causing said mechanism, during car travel in said certain direction, to bring the car to and stop it at a selected one of said landings after a stop has been made at the farthest landing for which a control has been operated, provided the selected landing is beyond said farthest landing, and in the event said farthest landing is beyond said selected landing, for causing said mechanism to operate the car past said selected landing without stopping it thereat unless the control for said selected landing has been operated; and means for automatically reversing the direction in which said mechanism starts the car from said selected landing in response to said starting means when the car, during its travel in said certain direction, is brought to a stop at said selected landing under conditions where neither the control for said selected landing nor a control for any landing beyond is operated. 15
10. An electric elevator system comprising; an elevator car; a plurality of landings served by the car; car actuating and stopping mechanism; a plurality of up push button switches, one at each of said landings; a plurality of down push button switches, one at each of said landings; a plurality of push button switches within the car, one for each of said landings; means responsive to the operation of said push button switches for causing said mechanism, during car travel in the up direction, to slow down the car as it nears each of the landings for which up push button switches or push button switches within the car have been operated and, during car travel in the down direction, to slow down the car as it nears each of the landings for which down push button switches or push button switches within the car have been operated; means responsive to the operation of any one of said down push button switches for landings 20

above a certain selected landing for causing said mechanism, during car travel in the up direction, to slow down the car as it nears the landing at which such down push button switch is located, under conditions where neither the up push button switch at the landing at which the down push button switch is located nor any of the push button switches for landings above are operated; switching means within the car operable after each stop to cause the operation of said mechanism to start the car; means for causing said mechanism, once it has started the car in the up direction, to restart the car in that direction in response to said switching means after each stop and finally to slow down the car as it nears said selected landing, provided the selected landing is above the highest landing for which a push button switch has been operated and, in the event that a push button switch for a landing above the selected landing has been operated, for causing said mechanism to continue the car past said selected landing without slowing it down as it nears that landing unless the push button switch within the car for said selected landing or the up push button switch at the selected landing is operated; means for causing said mechanism, after it has initiated slow down of the car, to bring the car to a stop at the landing at which it has slowed down the car; and means for automatically reversing the direction in which said mechanism starts the car from said selected landing in response to said switching means when the car, during its upward travel, is brought to a stop at said selected landing under conditions where neither the up push button switch at the selected landing nor any push button switch for landings above is operated and, in the event that the car is caused to travel above said selected landing, for automatically reversing the direction in which said mechanism starts the car from a landing above said selected landing in response to said switching means when the car is slowed down at such landing above in response to the down push button switch or push button switch within the car for such landing under conditions where neither the up push button switch at the landing for which such down push button switch or push button switch within the car is provided nor any push button switch for any landing above is operated.

11. An electric elevator system comprising; an elevator car; a plurality of landings served by the car; car actuating and stopping mechanism; a plurality of up push button switches, one at each of said landings; a plurality of down push button switches, one at each of said landings; a plurality of push button switches within the car, one for each of said landings; means responsive to the operation of said push button switches for causing said mechanism, during car travel in the up direction, to slow down the car as it nears each of the landings for which up push button switches or push button switches within the car have been operated and, during car travel in the down direction, to slow down the car as it nears each of the landings for which down push button switches or push button switches within the car have been operated; means responsive to the operation of any one of said down push button switches for landings above a certain selected landing for causing said mechanism, during car travel in the up direction, to slow down the car as it nears the landing at which such down push button switch is located, under conditions where neither the up push button switch at the landing at which the down push button switch is operated nor any of the push button switches for landings above are operated; switching means within the car operable to cause the operation of said mechanism to start the car; means for causing said mechanism, once it has started the car in the up direction, to restart the car in that direction in response to said switching means after each stop and finally to slow down the car as it nears said selected landing, provided the selected landing is above the highest landing for which a push button

switch has been operated and, in the event that a push button switch for a landing above the selected landing has been operated, for causing said mechanism to continue the car past said selected landing without slowing it down as it nears that landing unless the push button switch within the car for said selected landing or the up push button switch at the selected landing is operated; means for causing said mechanism, after it has initiated slow down of the car, to bring the car to a stop at the landing at which it has slowed down the car; and means for automatically reversing the direction in which said mechanism starts the car from said selected landing in response to said switching means when the car, during its upward travel, is brought to a stop at said selected landing under conditions where neither the up push button switch at the selected landing nor any push button switch for landings above is operated and, in the event that the car is caused to travel above said selected landing, for automatically reversing the direction in which said mechanism starts the car from a landing above said selected landing in response to said switching means when the car is slowed down at such landing above in response to the down push button switch or push button switch within the car for such landing under conditions where neither the up push button switch at the landing for which such down push button switch or push button switch within the car is provided nor any push button switch for any landing above is operated.

12. An electric elevator system comprising; an elevator car; a plurality of landings served by the car; car actuating and stopping mechanism; a plurality of controls, one for each of said landings; means responsive to the operation of said controls for causing said mechanism, during car travel in a certain direction, to slow down and stop the car at each of the landings for which controls are operated; means operable from within the car to cause said mechanism to start the car after each stop; means for causing said mechanism, during car travel in said certain direction, to bring the car to and stop it at a selected one of said landings after a stop has been made at the farthest landing for which a control has been operated, provided the selected landing is beyond said farthest landing, and in the event said farthest landing is beyond said selected landing, for causing said mechanism to run the car past said selected landing without stopping it thereat unless the control for said selected landing has been operated; and means for automatically reversing the direction in which said mechanism starts the car from said selected landing in response to said starting means when the car, during its travel in said certain direction, is brought to a stop at said selected landing under conditions where neither the control for said selected landing nor a control for any landing beyond is operated and, in the event that the car is caused to travel beyond said selected landing, for automatically reversing the direction in which said mechanism starts the car from a landing beyond said selected landing in response to said starting means when the car is brought to a stop at such landing beyond in response to said control for that landing under conditions where no control for a landing beyond that landing is operated.

13. An electric elevator system comprising; an elevator car; a plurality of landings served by the car; car actuating and stopping mechanism; a

- plurality of controls, one for each of said landings; means responsive to the operation of said controls for causing said mechanism, during car travel in a certain direction, to slow down and stop 5 the car at each of the landings for which controls are operated; means operable from within the car to cause said mechanism to start the car after each stop; means for causing said mechanism, during car travel in said certain direction, 10 to bring the car to and stop it at a selected one of said landings after a stop has been made at the farthest landing for which a control has been operated, provided the selected landing is beyond said farthest landing, and in the event said farthest landing is beyond said selected landing, for 15 causing said mechanism to run the car past said selected landing without stopping it thereat unless the control for said selected landing has been operated; means for automatically reversing the 20 direction in which said mechanism starts the car from said selected landing in response to said starting means when the car, during its travel in said certain direction, is brought to a stop at said selected landing under conditions where neither 25 the control for said selected landing nor a control for any landing beyond is operated and, in the event that the car is caused to travel beyond said selected landing, for automatically reversing the direction in which said mechanism starts the car 30 from a landing beyond said selected landing in response to said starting means when the car is brought to a stop at such landing beyond in response to said control for that landing under conditions where no control for a landing beyond 35 that landing is operated; and means for changing the type of service so that the car, when started in the up direction, continues to travel in that direction after each stop until the upper terminal one of said landings is reached.
- 40 14. An electric elevator system comprising; an elevator car; a plurality of landings served by the car; car actuating and stopping mechanism; a plurality of up push button switches, one at each of said landings; a plurality of down push button switches, one at each of said landings; means responsive to the operation of said up push button switches for causing said mechanism, during car travel in the up direction, to slow down the car as it nears each of the landings at which up push 45 button switches have been operated, and responsive to the operation of said down push button switches for causing said mechanism, during car travel in the down direction, to slow down the car as it nears each of the landings at which down 50 push button switches have been operated; means responsive to the operation of any one of said down push button switches for causing said mechanism, during car travel in the up direction, to slow down the car as it nears the landing at which such down push button switch is located, under conditions where neither the up push button switch at the landing at which the down push button switch is located nor any of the push button switches for landings above are operated; 55 means for causing said mechanism, after slow down has been initiated, to bring the car to a stop at the landing at which the car is being slowed down; switching means within the car for causing the operation of said mechanism to start the car; and means for causing said mechanism, once it has started the car in the up direction, to restart the car in that direction in response to said switching means after each stop until the car has stopped at the highest landing at which a 60 push button switch has been operated and to

start the car away from such landing in the down direction in response to said switching means after such stop, in the event that slow down preparatory to stopping at such landing was in response to the down push button switch at such landing, and to start the car away from such landing in the up direction in response to said switching means after such stop, in the event that slow down preparatory to stopping at such landing was in response to the up push button switch at such landing. 5

15. In an elevator control system for an elevator car in which an up hall button and a down hall button are provided at each intermediate landing and a car button is provided for each intermediate 15 landing, in which means are provided for stopping the car at landings for which calls are registered by the pressing of hall buttons or car buttons, in which means are provided for starting the car after each stop and in which the car is 20 provided with a non-stop control operable to cause the car to run past hall calls without stopping in response thereto, characterized by the fact that means are provided for causing the car, upon being stopped in response to its highest car call, 25 to start from the landing at which such stop is made in the down direction in response to its starting means when no hall calls are registered for landings above the car and also when hall calls are registered for such landings under conditions where said non-stop control is operated. 30

16. In a control system for an elevator car serving a plurality of landings; a control relay having a coil; a source of current; a circuit for connecting said coil to said source; a pair of contacts for each of said landings, said contacts being arranged in series relation in said circuit for controlling the energization of said coil; and switching mechanism actuated in accordance with car movement for rendering the contacts for 40 landings below the car ineffective to control the energization of said coil. 35

17. In a control system for an elevator car serving a plurality of landings; a control relay having a coil; a circuit for said coil; an up control and a down control for each of said landings, each control having a pair of normally engaged contacts, said contacts being arranged in series relation in said circuit in the order of succession of said landings for upward car travel with the contacts of each down control preceding those of the up control for the same landing, each control, upon operation to separate its contacts, breaking the circuit for said coil; and switching mechanism actuated in accordance with movement of the car and operable during upward car travel to by-pass the contacts of all of said controls for landings below the landing at which the car is positioned and also to by-pass the contacts of at least the down control for such landing. 50 55 60

18. In a control system for an elevator car serving a plurality of landings; a control relay having a coil; a circuit for said coil; a control for each of said landings, each control having a pair of normally engaged contacts and said contacts being arranged in series relation in said circuit in the order of succession of said landings whereby each control, upon operation to separate its contacts, breaks the circuit for said coil; a plurality of stationary contacts, one for each of said landings; and a contact movable in accordance with movement of the car for successively engaging said stationary contacts, said stationary contacts and movable contact being connected in said circuit in such manner that the engagement 70 75 80 85 90 95

- of said movable contact with the stationary contact for any landing, during car travel in a given direction, by-passes the contacts of all the controls for landings to and including that landing.
- 5 19. In a control system for an elevator car serving a plurality of landings; a control relay having a coil; a circuit for said coil; an up control and a down control for each of said landings, each control having a pair of normally engaged contacts, 10 said contacts being arranged in series relation in said circuit in the order of succession of said landings in the up direction with the contacts of each down control preceding those of the up control for the same landing whereby each control, upon 15 operation to separate its contacts, breaks the circuit for said coil; a plurality of stationary contacts, one for each of said landings; and a contact movable in accordance with movement of the car for successively engaging said stationary contacts, 20 said stationary contacts and said movable contact being connected in said circuit in such manner that the engagement of said movable contact with any stationary contact during upward travel of the car by-passes the contacts of all of said controls for landings below the landing for which the stationary contact is provided and also by-passes the contacts of at least the down control for such landing.
20. An electric elevator system comprising; a plurality of elevator cars; a plurality of landings served by the cars; means for each car for starting that car; a plurality of controls, one for each of said landings; means responsive to said controls for causing any car, during its travel in a given 30 direction, to slow down and stop at landings for which controls are operated; means for preventing the slowing down of more than one car at a landing in response to an operated control for that landing; means for each car for causing that car, during its travel in said given direction, to slow down and stop at a predetermined landing; and means for each car for causing that car, after being brought to a stop at said predetermined landing, to be started in the opposite direction 40 from that landing in response to the operation of said starting means for that car, provided no control for a landing beyond said predetermined landing is operated.
- 50 21. An electric elevator system comprising; a plurality of elevator cars; a plurality of landings served by the cars; means for each car for starting that car; a plurality of controls, one for each of said landings; means responsive to said controls for causing any car, during its travel in a given 55 direction, to slow down and stop at landings for which controls are operated; means for preventing the slowing down of more than one car at a landing in response to an operated control for that landing; and means for each car for causing that car, during its travel in said given direction, to slow down and stop at a predetermined landing, provided no control for a landing beyond is operated, and for causing the car to be started from 60 said predetermined landing in the opposite direction in response to the operation of said starting means for that car after such stop.
- 70 22. An electric elevator system comprising; a plurality of elevator cars; a plurality of landings served by the cars; means for each car for starting that car; a plurality of controls, one for each of said landings; means responsive to said controls for causing any car, during its travel in a given direction, to slow down and stop at landings 75 for which controls are operated; means for pre-

venting the slowing down of more than one car at a landing in response to an operated control for that landing; and means for each car for causing that car, during its travel in said given direction, to slow down and stop when a condition is reached 5 where, due to the response to an operated control for a landing beyond that car by some other car, no operated control for a landing beyond the car remains to be responded to, and for causing the car to be started in the opposite direction in response to the operation of said starting means for that car after such stop.

23. An electric elevator system comprising; a plurality of elevator cars; a plurality of landings served by the cars; means for each car for starting that car; a plurality of controls, one for each of said landings; means responsive to said controls for causing any car, during its travel in a given direction, to slow down and stop at landings for which controls are operated; means for preventing the slowing down of more than one car at a landing in response to an operated control for that landing; and means for each car for causing that car, during its travel in said given direction, to slow down and stop at a selected 10 intermediate landing, provided no control for a landing beyond is operated, and for causing that car to be started from said selected landing in the opposite direction in response to the operation of said starting means for that car after such stop, and in the event one or more controls for landings beyond said selected landing are operated, for causing that car to slow down and stop at a landing beyond said selected landing for which said control is not operated when a condition is reached where, due to the response to an operated control for a landing beyond said selected landing by some other car, no operated control for a landing beyond that car remains to be responded to, and for causing that car to be started from such landing in the opposite direction in response to the operation of said starting means for that car after such stop.

24. An electric elevator system comprising; a plurality of elevator cars; a plurality of landings served by the cars; direction determining means for each car for controlling the direction of travel of that car; control means for each of said landings for one direction of travel of said cars; control means for each of said landings for the opposite direction of travel of said cars; means for each car for causing that car, during its travel in said one direction, to slow down and stop at any landing in response to operated control means for that direction for that landing and for causing that car, during its travel in the opposite direction, to slow down and stop at any landing in response to operated control means for said opposite direction for that landing; means for each car for causing that car, during its travel in said one direction, to slow down and stop at any landing in response to operated control means for said opposite direction for that landing, under conditions where no control means for landings beyond such landing is operated and for causing said direction determining means for that car to be set for the opposite direction of travel; means for preventing the response of more than one car to operated control means for each landing; means for each car for causing that car, during its travel in said one direction, to slow down and stop at a landing when, due to the response to operated control means for a landing beyond that car by said slow down and stopping means for some other car, no operated control 75

means for any landing beyond such landing remains to be responded to and for causing said direction determining means for that car to be set for the opposite direction of car travel; and 5 means for each car operable to cause the starting of that car after each stop in a direction determined by the setting of said direction determining means for that car.

25. An electric elevator system comprising; a 10 plurality of elevator cars; a plurality of landings served by the cars; up control means at each of said landings; down control means at each of said landings; means for each car for causing that car, during its upward travel, to slow down 15 and stop at any landing in response to up control means at that landing and for causing that car, during its downward travel, to slow down and stop at any landing in response to down control means at that landing; means for each car for 20 causing that car, during its upward travel, to slow down, stop and be set for downward travel at any landing in response to down control means at that landing, provided that, at the time such operation was initiated, up control means at the 25 landing at which such down control means is located is not operated and no control means at landings above such landings is operated; and means for each car for causing that car, during its travel in the up direction, to slow down, stop 30 and be set for downward travel at the first possible landing when a condition is reached where no operated control means at any landing above that car remains to be responded to.

26. An electric elevator system comprising; a 35 plurality of elevator cars; a plurality of landings served by the cars; actuating and stopping mechanism for each car; a plurality of up controls, one at each of said landings, each up control being common to all cars; a plurality of down 40 controls, one at each of said landings, each down control being common to all cars; means for causing said mechanism for any car to slow down that car in response to any operated up control as the car, during its travel in the up direction, 45 nears the landing at which such operated up control means is provided and to slow down that car in response to any operated down control as the car, during its travel in the down direction, nears the landing at which such operated down 50 control is provided; means for causing said mechanism for any car to slow down that car in response to any operated one of said down controls as the car, during its travel in the up direction, nears the landing at which such down control 55 is located, under conditions where neither the up control at the landing at which such operated down control is located is operated nor any of the controls at landings above such landing is operated; means for preventing the slowing down of more than one car at a landing in response to an operated control at that landing; means for each car for 60 causing said mechanism for that car, during travel of that car in the up direction, to slow down that car as it nears the first landing 65 above the car for which said mechanism is effective to do so when a condition is reached where, at the time such mechanism is rendered effective to slow down that car as it nears such landing, the up control at such landing is not operated and, due to the response to an operated control at a landing above that car by said mechanism for some other car, no operated control at a landing above that car, to which said mechanism for that car is effective to respond, remains 70 to be responded to; means for each car for causing 75

said mechanism for that car, after it has started to slow down the car, to bring it to a stop at the landing at which it is slowing down; means for each car operable from within that car to cause operation of said mechanism for that car to start 5 the car after each stop; and direction determining means for each car for causing said mechanism for that car, once said direction determining means for that car becomes set for up car travel, to start the car in the up direction after 10 each stop in response to said starting means for that car, until the car is brought to a stop at a landing at which slow down is initiated in response to the down control at that landing or at which slow down is initiated due to a condition being reached where, at the time said mechanism is rendered effective to slow down that car at such landing as it nears such landing, the up control at such landing is not operated, and, due to the response to an operated control at a 15 landing above that car by said mechanism for some other car, no operated control at a landing above that car, to which said mechanism for that car is effective to respond, remains to be responded to, said direction determining means there- 20 upon operating to cause said mechanism to start that car in the down direction from such landing in response to the operation of the starting means for that car.

27. An electric elevator system comprising; a 30 plurality of elevator cars; a plurality of landings served by the cars; actuating and stopping mechanism for each car; a plurality of up controls, one at each of said landings, each up control being common to all cars; a plurality of down controls, 35 one at each of said landings, each down control being common to all cars; means for causing said mechanism for any car to slow down that car in response to any operated up control as the car, during its travel in the up direction, nears the 40 landing at which such operated up control is located, to slow down that car in response to any operated down control as the car, during its travel in the down direction, nears the landing at which such operated down control is located, and to 45 slow down that car in response to any operated one of said down controls as the car, during its travel in the up direction, nears the landing at which such down control is located, under conditions where neither the up control at the landing at which such operated down control is located is operated nor any of the controls at landings above such landing is operated; means for preventing the slowing down of more than one car at a landing in response to an operated control at that landing; means for each car for 50 causing said mechanism for that car, during travel of that car in the up direction, to slow down that car as it nears any landing above the car for which said mechanism for that car can still do so, when a condition is reached where, at the time such mechanism is rendered effective to slow down that car at such landing as it nears such landing, the up control at such landing is not operated and, due to the response to an operated control at a landing above that car by said mechanism for some other car, no operated control at a landing above that car, to which said mechanism for that car is effective to respond, remains to be responded to; means for each car for 55 causing said mechanism for that car, after it has started to slow down the car, to bring the car to a stop at the landing at which it is slowing down; means for each car operable from within that car to cause operation of said mechanism 60 65 70 75 80 85 90 95

for that car to start the car; and means for each car for causing said mechanism for that car, once it has started that car in the up direction, to restart it in that direction in response to said starting means for that car after each stop until the car is brought to a stop at a landing at which said mechanism for that car slows down that car in response to the down control at that landing, and to start the car from such landing in the 10 down direction in response to said starting means for that car, or for causing said mechanism for that car, once it has started that car in the up direction, to restart the car in the up direction in response to said starting means for that car after 15 each stop until the car is brought to a stop at a landing above that car at which said mechanism for that car is caused to slow down the car, due to a condition being reached where, at the time said mechanism for that car is rendered effective to cause such slow down, the up control at that landing is not operated and, due to the response to an operated control at a landing above that car by said mechanism for some other car, no operated control at a landing above the car, to 20 which said mechanism for that car is effective to respond, remains to be responded to, and to start the car from such landing in the down direction in response to said starting means for that car.

28. An electric elevator system comprising; a plurality of elevator cars; a plurality of landings served by the cars; actuating and stopping mechanism for each car; up control means at each of said landings; down control means at each of said landings; means for each car for causing said mechanism for that car to slow down that car in response to operated up control means as the car, during its travel in the up direction, nears the landings at which such operated control means are located and to slow down that car in response to operated down control means as the car, during its travel in the down direction, nears the landings at which such operated control means are located; means for each car for causing said mechanism for that car to slow down that car in response to operated down control means as the car, during its travel in the up direction, nears the landing at which such down control means is located, under conditions where neither up control means at the landing at which such down control means is located nor any control means at landings above such landing is operated; means for preventing the slowing down of other cars at a landing, in response to operated control means at that landing, to which said mechanism for said one car is responding; means for each car for causing said mechanism for that car, during travel of that car in the up direction, to slow down that car as it nears the first landing above the car for which said mechanism is effective to do so, when a condition is reached where, at the time such mechanism is rendered effective to slow down that car at such landing as it nears such landing, no operated control means at any landing above that car, to which said mechanism for that car is effective to respond, remains to be responded to; means for each car for causing said mechanism for that car, after it has started to slow down that car, to bring the car to a stop at the landing at which it is slowing down; means for each car operable from within that car to cause operation of said mechanism for that car to start the car; and means for each car for causing said mechanism for that car, once it has started that car in the up direction, to restart it in that direction in response to said starting means for

that car after each stop until the car is brought to a stop at a landing at which said mechanism for that car slows down that car in response to down control means at that landing and to start the car from such landing in the down direction 5 in response to said starting means for that car, or for causing said mechanism for that car, once it has started that car in the up direction, to restart the car in the up direction in response to said starting means for that car after each stop 10 until the car is brought to a stop at a landing at which said mechanism for that car is caused to slow down the car, due to a condition being reached where, at the time said mechanism for that car is rendered effective to cause such slow down, no operated control means at any landing above the car, to which said mechanism for that car is effective to respond, remains to be responded to, and to start the car from such landing 15 in the down direction in response to said starting 20 means for that car.

29. An electric elevator system comprising; a plurality of elevator cars; a plurality of landings served by the cars; up control means at each of said landings; down control means at each of said landings; control means for each of said landings in each car; means for each car for causing that car, during its upward travel, to slow down and stop at any landing in response to up control means or control means within that car for that landing, and for causing that car, during its downward travel, to slow down and stop at any landing in response to down control means or control means within that car for that landing; means for each car for causing that car, during its upward travel, to slow down, stop and be set for downward travel at any landing in response to down control means at that landing or control means in that car for that landing, provided that, at the time such operation was initiated, up control means at the landing at which such down control means is located is not operated and no control means at landings above such landing or control means in that car for landings above such landing is operated; means for preventing the response of more than one car to operated control means at each landing; means for each car for causing that car, during its travel in the up direction, to slow down, stop and be set for downward travel at the first possible landing, when a condition is reached where no operated control means at any landing above that car remains to be responded to; and means for each car operable to cause the starting of that car after each stop. 40 45 50 55 60 65 70 75

30. An electric elevator system comprising; a plurality of elevator cars; a plurality of landings served by the cars; actuating and stopping mechanism for each car; means for each car operable from within that car after each stop to cause operation of said mechanism for that car to start the car; a plurality of up controls, one at each of said landings, each up control being common to all cars; a plurality of down controls, one at each of said landings, each down control being common to all cars; a plurality of controls, one for each of said landings, in each car; means for causing said mechanism for any car to slow down that car in response to any operated up control or control within that car as the car, during its travel in the up direction, nears the landing for which each operated control is provided, and to slow down that car in response to any operated down control or control within that car as the car, during its travel in the down direction, nears the landing 75 80 85 90 95

for which such operated control is provided; means for preventing the slowing down of more than one car at a landing in response to an operated control at that landing; means for 5 each car for causing said mechanism for that car, after it has started to slow down that car, to bring the car to a stop at the landing at which it is slowing down; means for each car for causing said mechanism for that car, during 10 travel of that car in the up direction, to slow down and stop that car at the first landing above the car for which said mechanism is effective to do so, when the up control at such landing is not operated, when no control in that car for 15 landings above such landing is operated and when, upon the response to an operated control at a landing above that car by said mechanism for some other car, no operated control at any landing above that car, to which said mechanism 20 for that car is effective to respond, remains to be responded to and for causing the direction of travel of that car to be reversed at such landing.

31. An electric elevator system comprising; a 25 plurality of elevator cars; a plurality of landings served by the cars; actuating and stopping mechanism for each car; a plurality of up controls, one at each of said landings, each up control being common to all cars; a plurality of 30 down controls, one at each of said landings, each down control being common to all cars; a plurality of controls, one for each of said landings, in each car; means for causing said mechanism for any car to slow down that car in response 35 to any operated up control or control within that car as the car, during its travel in the up direction, nears the landing for which such operated control is provided, to slow down that car in response to any operated down control or 40 control within that car as the car, during its travel in the down direction, nears the landing for which such operated control is provided; means for causing said mechanism for any car to slow down that car in response to any operated 45 one of said down controls as the car, during its travel in the up direction, nears the landing at which such down control is located, under conditions where neither the up control at the landing at which such operated down control is located is operated nor an operated control at 50 any landing above such landing or an operated control in that car for any landing above such landing remains to be responded to; means for preventing the slowing down of more than one 55 car at a landing in response to an operated control at that landing; means for each car for causing said mechanism for that car, during travel of that car in the up direction, to slow down that car as it nears the first landing above the car for which said mechanism is effective 60 to do so, when the up control at such landing is not operated, when no control in that car for a landing above such landing is operated and when, upon the response to an operated control 65 at a landing above that car by said mechanism for some other car, no operated control at a landing above that car, to which said mechanism for that car is effective to respond, remains to be responded to; means for each car for causing 70 said mechanism for that car, after it has started to slow down that car, to bring the car to a stop at the landing at which it is slowing down; means for each car operable from within that car to cause operation of said mechanism for that car to start the car; and means for 75

each car for causing said mechanism for that car, once it has started that car in the up direction, to restart it in that direction in response to said starting means for that car after each stop until the car is brought to a stop at a landing at which said mechanism for that car slows down that car in response to the down control at that landing or the control in the car for that landing, under conditions where no operated control at a landing above such landing or 10 operated control in that car for a landing above such landing remains to be responded to at the time said mechanism for that car is rendered effective to cause slow down of that car as it nears such landing, and to start the car from 15 such landing in the down direction in response to said starting means for that car after such stop, or for causing said mechanism for that car, once it has started the car in the up direction, to restart the car in that direction in response to said starting means for that car after each stop until the car is brought to a stop at a landing at which said mechanism for that car is caused to slow down the car, when a condition is reached where the up control at such 25 landing is not operated, where no control in that car for any landing above such landing is operated and where, upon the response to an operated control at a landing above that car by said mechanism for some other car, no operated 30 control at any landing above that car, to which said mechanism for that car is effective to respond, remains to be responded to, and to start the car from such landing in the down direction in response to said starting means for that 35 car after such stop.

32. An electric elevator system comprising; a plurality of elevator cars; a plurality of landings served by the cars; actuating and stopping mechanism for each car; a plurality of up controls, 40 one at each of said landings, each up control being common to all cars; a plurality of down controls, one at each of said landings, each down control being common to all cars; a plurality of controls, one for each of said landings, in each 45 car; means for causing said mechanism for any car to slow down that car in response to any operated up control or control within that car as the car, during its travel in the up direction, nears the landing for which such operated control is provided, and to slow down that car in response to any operated down control or control within that car as the car, during its travel in the down direction, nears the landing for which such operated control is provided; means for 50 causing said mechanism for any car to slow down that car in response to any operated one of said down controls as the car, during its travel in the up direction, nears the landing at which such down control is located, under conditions where neither the up control at the landing at which such operated down control is located is operated nor any of the controls at landings above such landing or of the controls in that car for landings above such landing is operated; means for 55 each car for causing said mechanism for that car, after it has started to slow down the car, to bring the car to a stop at the landing at which it is slowing down; means for each car operable from within that car to cause operation of 60 said mechanism for that car to start the car; and means for each car for causing said mechanism for that car, once it has started that car in the up direction, to restart it in that direction in response to said starting means for that car 65 70 75

- after each stop until the car is brought to a stop at a landing at which said mechanism for that car slows down that car in response either to the down control at that landing or to the control 5 in the car for that landing, under conditions where no operated control at a landing above such landing or operated control in that car for a landing above such landing remains to be responded to at the time said mechanism for that 10 car is rendered effective to cause slow down of that car as it nears such landing, and to start the car from such landing in the down direction in response to said starting means for that car after such stop.
- 15 33. An electric elevator system comprising; a plurality of elevator cars; a plurality of landings served by the cars; actuating and stopping mechanism for each car; a plurality of up controls, one at each of said landings, each up control 20 being common to all cars; a plurality of down controls, one at each of said landings, each down control being common to all cars; a plurality of controls, one for each of said landings, in each car; means for causing said mechanism for any 25 car to slow down that car in response to any operated up control or control within that car as the car, during its travel in the up direction, nears the landing for which such operated control is provided, and to slow down that car in 30 response to any operated down control or control within that car as the car, during its travel in the down direction, nears the landing for which such operated control is provided; means for causing said mechanism for any car to slow down 35 that car in response to any operated one of said down controls for landings above a selected intermediate one of said landings as the car, during its travel in the up direction, nears the landing at which such down control is located, under 40 conditions where neither the up control at the landing at which such operated down control is located is operated nor any of the controls at landings above such landing or of the controls in that car for landings above such landing is operated; means for preventing the slowing down 45 of more than one car at a landing in response to an operated control at that landing; means for each car for causing said mechanism for that car, during travel of that car in the up direction, 50 to slow down that car as it nears said selected intermediate landing, provided no operated control at any landing above said selected landing or operated control in that car for any landing above said selected landing remains to be responded to; means for each car for causing said mechanism for that car, after it has started to 55 slow down the car, to bring the car to a stop at the landing at which it is slowing down; means for each car operable from within that car to cause operation of said mechanism for that car to start the car; and means for each car for causing said mechanism for that car, once it has started that car in the up direction, to restart it in that direction in response to said starting means for that car, after each stop at least until said 60 selected intermediate landing is reached and, when it stops that car at said selected landing, to start the car therefrom in the down direction in response to said starting means for that car, 65 provided the slow down at said selected landing was not in response to the up control at that landing and no operated control at any landing above said selected landing or operated control in that car for any landing above said selected landing remained to be responded to at the time 70 75 said mechanism for that car was rendered effective to cause that car to slow down as it neared said selected landing.
34. An electric elevator system comprising; a plurality of elevator cars; a plurality of landings served by the cars; actuating and stopping mechanism for each car; a plurality of up controls, one at each of said landings, each up control being common to all cars; a plurality of down controls, one at each of said landings, each down control being common to all cars; a plurality of controls, one for each of said landings, in each car; means for causing said mechanism for any car to slow down that car in response to any operated up control or control within that car as the car, during its travel in the up direction, nears the landing for which such operated control is provided, to slow down that car in response to any operated down control or control within that car as the car, during its travel in the down direction, nears the landing for which such operated control is provided, and to slow down that car in response to any operated one of said down controls for landings above a selected intermediate one of said landings as the car, during its travel in the up direction, nears the landing at which such down control is located, under conditions where neither the up control at the landing at which such operated down control is located is operated nor an operated control at any landing above such landing or an operated control in that car for any landing above such landing remains to be responded to; means for preventing the slowing down of more than one car at a landing in response to an operated control at that landing; means for each car for causing said mechanism for that car, during travel of that car in the up direction, to slow down that car as it nears said selected intermediate landing, in the event the up control at said selected landing is not operated and regardless of whether the control in that car for said selected landing is operated or not, provided no operated control at any landing above said selected landing or operated control in that car for any landing above said selected landing remains to be responded to and, in the event the car is caused to travel above said selected landing, for causing said mechanism for that car to slow down that car as it nears any landing above said selected landing at which said mechanism for that car can still do so, when a condition is reached where, at the time said mechanism for that car is rendered effective to slow down that car at such landing as it nears such landing, the up control at such landing is not operated, no control in that car for a landing above such landing is operated and, due to the response to an operated control at a landing above said selected landing by said mechanism for some other car, no operated control at a landing above that car, to which said mechanism for that car is effective to respond, remains to be responded to; means for each car for causing said mechanism for that car, after it has started to slow down the car, to bring the car to a stop at the landing at which it is slowing down; means for each car operable from within that car to cause operation of said mechanism for that car to start the car; and means for each car for causing said mechanism for that car, once it has started that car in the up direction, to restart it in that direction in response to said starting means for that car, after each stop at least until said selected intermediate landing is reached and, when it stops that car at said selected landing, to start it therefrom in the 75

- down direction in response to said starting means for that car, provided the slow down at said selected landing was not in response to the up control at that landing and no operated control at 5 any landing above said selected landing or operated control in that car for any landing above said selected landing remained to be responded to at the time said mechanism for that car was rendered effective to cause that car to slow down 10 as it neared said selected landing and, in the event said mechanism for that car slowed down that car at said selected landing in response to the up control at that landing or there were one or more operated controls at landings above said selected landing or one or more operated controls in that car for landings above said selected landing to be responded to at the time said mechanism for that car was rendered effective to cause slow down of that car in 15 response to the control in that car for said selected landing as the car neared such landing, provided such control was operated, or would have been rendered effective to do so in response to such control if such control were operated, 20 for causing said mechanism for that car to restart that car in the up direction in response to said starting means for that car after each stop until the car is brought to a stop at a landing above said selected landing at which said mechanism for that car slows down that car in response either to the down control at that landing or to the control in the car for that landing, under conditions where no operated control at a landing above such landing or operated control in that 25 30 35 40 45 50 55 60 65 70 75 car for a landing above such landing remained to be responded to at the time said mechanism for that car was rendered effective to cause slow down of that car as it neared such landing, and to start the car from such landing in the down direction in response to said starting means for that car, or for causing said mechanism for that car to restart the car in the up direction in response to said starting means for that car after each stop until the car is brought to a stop at a landing above said selected landing at which said mechanism for that car is caused to slow down the car due to a condition being reached where, at the time said mechanism for that car is rendered effective to cause such slow down, the up control at such landing is not operated, no control in that car for any landing above such landing is operated and, due to the response to an operated control at a landing above that car by said mechanism for some other car, no operated control at any landing above that car, to which said mechanism for that car is effective to respond, remains to be responded to, and to start the car from such landing in the down direction in response to said starting means for that car.
35. An electric elevator system comprising; a plurality of elevator cars; a plurality of landings served by the cars; actuating and stopping mechanism for each of said cars; a start control in each car; a control for each of said landings; means for causing said mechanism for any car, during travel of that car in a given direction, to slow down and stop the car in response to the controls that are operated at the landings for which the operated controls are provided; means for preventing the response of said mechanism for more than one car to each operated control; means for each car for causing said mechanism for that car, during travel of that car in said given direction, to slow down and stop the car at a predetermined one of said landings and to

start it in the opposite direction from such landing in response to the operation of said start control for that car after such stop, provided no controls for landings beyond such landing are operated which require further travel of that car in said given direction; and means for each car for selecting any intermediate one of said landings as said predetermined landing for that car, regardless of which of the landings are selected for the other cars.

36. An electric elevator system comprising; a plurality of elevator cars; a plurality of landings served by the cars; a control for each of said landings; means for causing any car, during its travel in a given direction, to slow down and stop at any landing in response to the control for that landing; means for preventing the response of more than one car to the operated control for each landing; means for causing a car to travel beyond a predetermined one of said landings in said given direction of travel when a control for any landing beyond said predetermined landing is to be responded to, either under conditions where no other car has already been caused to travel beyond said landing or under conditions where any car which has already been caused to travel beyond said landing cannot respond to one or more operated controls for landings beyond said predetermined landing; and means for each car for causing that car, during its travel in said given direction, to slow down, stop and reverse its direction of travel at said predetermined landing in the event it is not selected for travel beyond said landing.

37. An electric elevator system comprising; a plurality of elevator cars; a plurality of landings served by the cars; means for each of said landings operable to register a call for the landing for which it is provided; a signal for each car; a circuit for each signal; and means operable as any car nears a certain one of said landings from a given direction for completing the circuit for the signal for that car when any call is registered for a landing beyond and for opening the circuits for the signals for the other cars.

38. An electric elevator system comprising; a plurality of elevator cars; a plurality of landings served by the cars; means for each of said landings operable to register a call for the landing for which it is provided; a signal for each car; a circuit for each signal; means operable as any car nears a certain one of said landings from a given direction for completing the circuit for the signal for that car when any call is registered for a landing beyond and for opening the circuits for the signals for the other cars; and means for completing the circuit for the signal for any of the other cars as it nears said certain landing where any car whose signal has already been given cannot answer one or more calls for landings beyond said certain landing.

39. An electric elevator system comprising; a plurality of elevator cars; a plurality of landings served by the cars; means for each of said landings operable to register a call for the landing for which it is provided; a signal for each car; a circuit for each signal; means operable as any car nears a certain one of said landings from a given direction for completing the circuit for the signal for that car when any call is registered for a landing beyond and for opening the circuits for the signals for the other cars; and means for completing the circuit for the signal for any of the other cars as it nears said certain landing

from said given direction under conditions where any car whose signal has already been given cannot answer one or more calls for landings beyond said certain landing or where the unanswered calls for such landings beyond reach a predetermined number.

40. An electric elevator system comprising; a plurality of elevator cars; a plurality of landings served by the cars; a control for each of said landings; means for causing any car, during its travel in a given direction, to slow down and stop at any landing in response to the control for that landing; means for preventing the response of more than one car to the operated control for each landing; means for causing each car, once started in a given direction, to continue to travel in that direction after each stop at least until a predetermined one of said landings is reached; means for causing a car to travel beyond said predetermined landing in said given direction of travel when a control for any landing beyond said predetermined landing is to be responded to, either under conditions where no other car has already been caused to travel beyond said landing or under conditions where any other car which has already been caused to travel beyond said landing cannot respond to one or more operated controls for landings beyond said predetermined landing; means for each car for causing that car, during its travel in said given direction, to slow down, stop and reverse its direction of travel at said predetermined landing in the event it is not selected for travel beyond said landing; a signal in each car; and means for causing the giving of the signal in any car when that car is selected to travel beyond said predetermined landing in said given direction.

41. An electric elevator system comprising; a plurality of elevator cars; a plurality of landings served by the cars; control means for each of said landings for one direction of travel; control means for each of said landings for the opposite direction of travel; means for causing any car, during its travel in said one direction, to slow down and stop at any landing in response to control means for that direction for that landing and, during its travel in the opposite direction, to slow down and stop at any landing in response to control means for said opposite direction for that landing; means for preventing the response of more than one car to each operated control means for each landing; means for determining which of the cars is to travel beyond a predetermined one of said landings in said one direction, such means acting automatically to select a car for such travel when control means for any landing beyond said predetermined landing is to be responded to, either under conditions where no other car has already been selected for such travel or under conditions where any other car previously selected for such travel cannot respond to operated control means for some landing beyond said predetermined landing; and means for each car for causing that car, during its travel in said one direction, to slow down, stop and reverse its direction of travel at said predetermined landing in the event that car is not selected for travel beyond said landing.

42. An electric elevator system comprising; a plurality of elevator cars; a plurality of landings served by the cars; means for each car for starting that car; control means for each of said landings for one direction of travel; control

means for each of said landings for the opposite direction of travel; means for causing any car, during its travel in said one direction, to slow down and stop at any landing in response to control means for that direction for that landing and, during its travel in the opposite direction, to slow down and stop at any landing in response to control means for said opposite direction for that landing; means for causing any car, during its travel in said one direction, to slow down and stop at any landing above a predetermined one of said landings in response to control means for said opposite direction for that landing and to start from that landing in the opposite direction upon operation of said starting means for that car after such stop, provided that control means for said one direction for that landing is not operated and no control means for any landing beyond such landing remains to be responded to; means for preventing the response of more than one car to each operated control means for each landing; means for determining which of the cars is to travel beyond said predetermined landing in said one direction, such means acting automatically to select a car for such travel when control means for any landing beyond said predetermined landing is to be responded to, either under conditions where no other car has already been selected for such travel or under conditions where any other car previously selected for such travel cannot respond to operated control means for some landing beyond said predetermined landing; and means for each car for causing that car, during its travel in said one direction, to slow down and stop at said predetermined landing and to start from that landing in the opposite direction upon operation of said starting means for that car after such stop, in the event that car is not selected for travel beyond said landing.

43. An electric elevator system comprising; a plurality of elevator cars; a plurality of landings served by the cars; start control means for each car controllable from within that car to cause the starting of that car after each stop; control means for each of said landings for one direction of travel; control means for each of said landings for the opposite direction of travel; means for causing any car, during its travel in said one direction, to slow down and stop at any landing in response to control means for said opposite direction for that landing; means for causing any car, during its travel in said one direction, to slow down and stop at any landing above a predetermined one of said landings in response to control means for said opposite direction for that landing and to start from that landing in the opposite direction in response to said start control means for that car after such stop, provided that control means for said one direction for that landing is not operated and no control means for any landing beyond such landing remains to be responded to; means for preventing the response of more than one car to each operated control means for each landing; means for determining which of the cars is to travel beyond said predetermined landing in said one direction, such means acting automatically to select a car for such travel when control means for any landing beyond said predetermined landing is to be responded to, either under conditions where no other car has already been selected for such travel

- or under conditions where any other car previously selected for such travel cannot respond to operated control means for some landing beyond said predetermined landing; and means for each 5 car for causing that car, in the event it is selected for such travel, to slow down and stop at a landing beyond said predetermined landing and to start from that landing in the opposite direction in response to said start control means for that car 10 after such stop, when control means for said one direction for such landing is not operated and when, upon the response to operated control means for a landing beyond said predetermined landing by some other car, no operated control 15 means for any landing beyond the car to which the car can respond, remains to be responded to.
44. An electric elevator system comprising; a plurality of elevator cars; a plurality of landings served by the cars; up control means at each of 20 said landings; down control means at each of said landings; control means for each of said landings in each car; means for causing any car, during its travel in the up direction, to slow down and stop at any landing in response to up control means at 25 that landing or control means within that car for that landing and, during its travel in the down direction, to slow down and stop at any landing in response to down control means at that landing or control means within that car for that landing; 30 means for causing any car, during its travel in the up direction, to slow down, stop and reverse its direction of travel at any landing above a predetermined one of said landings in response to down control means at that landing or to control 35 means in that car for that landing provided that, at the time such operation was initiated, up control means at that landing is not operated and no control means at any landing above such landing or control means in that car for any landing 40 above such landing remains to be responded to; means for preventing the response of more than one car to operated control means at each landing; a start control in each car manually operable to start the car; and means for preventing a car 45 travelling above said predetermined landing when no control means in that car for any landing above said predetermined landing is operated and no control means at any landing above said predetermined landing is to be responded to.
45. An electric elevator system comprising; a plurality of elevator cars; a plurality of landings served by the cars; a start control in each car operable to cause the starting of that car after 50 each stop; up control means at each of said landings; down control means at each of said landings; control means for each of said landings in each car; means for causing any car, during its travel in the up direction, to slow down and stop at any landing in response to up control means at 55 that landing or control means within that car for that landing; means for causing any car, during its travel in the up direction, to slow down and stop at any landing above a predetermined one of said landings in response to down control means at that landing or to control means in that 60 car for that landing and to start in the down direction from such landing in response to the operation of said start control in that car after such stop, provided that, at the time such means is rendered effective to cause slow down at that landing, up control means at that landing is not operated and no control means at any landing above such landing or control means in that car for any landing above such landing remains to be 65 responded to; means for preventing the response of more than one car to operated control means at each landing; means for determining which of the cars is to travel above said predetermined landing, such means acting automatically to select a car to travel above such landing when control means in that car for any landing above said predetermined landing is operated, and also when control means at any landing above said predetermined landing is to be responded to either under conditions where no other car has 70 been selected to travel above said predetermined landing or under conditions where any other car previously selected to travel above said predetermined landing cannot respond to operated control means at some landing above said prede- 75

no control means at any landing above such landing or control means in that car for any landing above such landing remains to be responded to; means for preventing the response of more than one car to operated control means at each landing; means for determining which of the cars is to travel above said predetermined landing, such means acting automatically to select a car to travel above such landing when control means in that car for any landing above said predetermined landing is operated, and also when control means at any landing above said predetermined landing is to be responded to under conditions where no other car has been selected to travel above said predetermined landing; and means for each car 10 for causing that car, in the event that car is selected to travel above said predetermined landing, to slow down and stop at a landing above said predetermined landing when up control means at such landing is not operated, no control means in that car for a landing above such landing is operated and, due to the response to operated control means at a landing above said predetermined landing by some other car, no operated control means at any landing above the car to 20 which the car can respond, remains to be responded to at the time such operation was initiated, and to start in the opposite direction from such landing in response to the operation of said start control in that car after such stop. 30

46. An electric elevator system comprising; a plurality of elevator cars; a plurality of landings served by the cars; a start control in each car operable to cause the starting of that car after each stop; up control means at each of said landings; down control means at each of said landings; control means for each of said landings in each car; means for causing any car, during its travel in the up direction, to slow down and stop at any landing in response to up control means at 35 that landing or control means within that car for that landing and, during its travel in the down direction, to slow down and stop at any landing in response to down control means at that landing or control means within that car for that landing; means for causing any car, during its travel in the up direction, to slow down and stop at any landing above a predetermined one of said landings in response to down control means at that landing or to control means in that 40 car for that landing and to start in the down direction from such landing in response to the operation of said start control in that car after such stop, provided that, at the time such means is rendered effective to cause slow down at that landing, up control means at that landing is not operated and no control means at any landing above such landing or control means in that car for any landing above such landing remains to be 45 responded to; means for preventing the response of more than one car to operated control means at each landing; means for determining which of the cars is to travel above said predetermined landing, such means acting automatically to select a car to travel above such landing when control means in that car for any landing above said predetermined landing is operated, and also when control means at any landing above said predetermined landing is to be responded to either under conditions where no other car has 50 been selected to travel above said predetermined landing or under conditions where any other car previously selected to travel above said predetermined landing cannot respond to operated control means at some landing above said prede- 55

terminated landing; means for each car for causing that car, during its upward travel, to slow down and stop at said predetermined landing and to start in the down direction from said predetermined landing in response to the operation of said start control in that car after such stop in the event that car is not selected to travel above said predetermined landing and, in the event it is selected to travel above said predetermined landing, to slow down and stop at a landing above said predetermined landing when up control means at such landing is not operated, no control means in that car for a landing above such landing is operated and, due to the response to operated control means at a landing above said predetermined landing by some other car, no operated control means at any landing above the car to which the car can respond, remains to be responded to at the time such operation was initiated and to start in the down direction from such landing in response to the operation of said start control in that car after such stop.

47. An electric elevator system comprising; a plurality of elevator cars; a plurality of landings served by the cars; up control means at each of said landings; down control means at each of said landings; means for causing any car, during its travel in the up direction, to slow down and stop at any landing in response to up control means at that landing and, during its travel in the down direction, to slow down and stop at any landing in response to down control means at that landing; means for preventing the response of more than one car to operated control means at each landing; means for determining which of the cars is to travel above a predetermined one of said landings, such means acting automatically to select a car to travel above such landing when control means at any landing above said predetermined landing is to be responded to, either under conditions where no other car has been selected to travel above said predetermined landing or under conditions where any other car previously selected to travel above said predetermined landing cannot respond to operated control means at some landing above said predetermined landing.

48. An electric elevator system comprising; a plurality of elevator cars; a terminal landing and a plurality of intermediate landings served by the cars; means for each car operable to cause the starting of that car after each stop; up control means at each of said intermediate landings; down control means at each of said intermediate landings; control means for each of said intermediate landings in each car; means for causing any car, during its travel in the up direction, to slow down and stop at any of said intermediate landings in response to up control means at that landing or control means within that car for that landing and, during its travel in the down direction, to slow down and stop at any of said intermediate landings in response to down control means at that landing or control means within that car for that landing; means for causing any car, during its travel in the up direction, to slow down and stop at any landing above a predetermined one of said landings in response to down control means at that landing or

to control means in that car for that landing and to start in the down direction from that landing in response to said starting means for that car provided that, at the time such operation was initiated, up control means at that landing is not operated and no control means at any landing above such landing or control means in that car for any landing above such landing remains to be responded to; means for preventing the response of more than one car to operated control means at each landing; and means for picking out a car for travel above said predetermined landing, such means acting automatically to do so when control means in that car for any landing above said predetermined landing is operated or control means at any landing above said predetermined landing is to be responded to, either under conditions where no other car has been picked out for travel above said predetermined landing or under conditions where any other car previously picked out for travel above said predetermined landing cannot respond to operated control means at some landing above said predetermined landing.

49. An electric elevator system comprising; a plurality of elevator cars; a lower terminal landing and a plurality of intermediate landings served by the cars; a start control in each car; up control means at each of said intermediate landings; down control means at each of said intermediate landings; control means for each of said intermediate landings in each car; means for causing any car, during its travel in the up direction, to slow down and stop at any landing in response to up control means at that landing or control means within that car for that landing and, during its travel in the down direction, to slow down and stop at any landing in response to down control means at that landing or control means within that car for that landing; means for causing any car, during its travel in the up direction, to slow down and stop at any landing in response to down control means at that landing or control means within that car for that landing; means for causing any car, during its travel in the up direction, to slow down and stop at any landing in response to down control means at that landing or control means within that car for that landing and to start from such landing in the down direction in response to said start control in that car after such stop, provided that up control means at that landing is not operated and no control means at any landing above that landing or control means in that car for any landing above that landing remains to be responded to; means for selecting a car to be started from said lower terminal landing in the up direction, such means acting automatically to do so if control means in that car for any landing above said lower terminal landing is operated or if control means at any landing above said lower terminal landing is to be responded to either under conditions where no other car has been selected to travel above the lower terminal landing or under conditions where any other car previously selected to travel above the lower terminal landing cannot respond to operated control means at some landing above the lower terminal landing; and means for each car for causing that car, during its upward travel, to slow down and stop at a landing above the lower terminal landing and to start from such landing in the down direction in response to said start control in that car after such stop, provided that up control means at such landing above is not operated, that no control means in that car for landing above such landing is operated and that, upon the response to operated control means at a landing above the lower terminal landing by some other car, no

operated control means at any landing above the car to which the car is effective to respond, remains to be responded to.

50. An electric elevator system comprising; a plurality of elevator cars; upper and lower terminal landings and a plurality of intermediate landings served by the cars; actuating and stopping mechanism for each car; a plurality of up controls, one at each of said intermediate landings, each up control being common to all cars; a plurality of down controls, one at each of said intermediate landings, each down control being common to all cars; a plurality of controls, one for each of said intermediate landings, in each car; means for causing said mechanism for any car to slow down that car in response to any operated up control or control within that car as the car, during its travel in the up direction, nears the landing for which such operated control is provided and to slow down that car in response to any operated down control or control within that car as the car, during its travel in the down direction, nears the landing for which such operated control is provided; means for preventing the slowing down of more than one car at a landing in response to an operated control at that landing; means for picking out a car for travel above a predetermined one of said landings, such means acting automatically to do so when one or more controls in that car for landings above said predetermined landing are operated or one or more operated controls at landings above said predetermined landing are to be responded to either under conditions where 35 no other car has been picked out for travel above said predetermined landing or under conditions where said mechanism for any other car already picked out for travel above said predetermined landing is no longer effective to respond to one 40 or more of the operated controls at landings above said predetermined landing during such travel of such other car in either the up or down direction; means for each car for causing said mechanism for that car, after it has started to 45 slow down the car, to bring the car to a stop at the landing at which it is slowing down; starting means for each car manually operable from within the car to cause operation of said mechanism for that car to start the car after each stop; 50 and means for each car for causing said mechanism for that car, in the event that car is picked out for travel above said predetermined landing, to restart the car in the up direction in response to said starting means for that car until 55 the upper terminal landing is reached.

51. An electric elevator system comprising; a plurality of elevator cars; a plurality of landings served by the cars; actuating and stopping mechanism for each car; a plurality of up controls, one at each of said landings, each up control being common to all cars; a plurality of down controls, one at each of said landings, each down control being common to all cars; a plurality of controls, one for each of said landings, in each car; means for causing said mechanism for any car to slow down that car in response to any operated up control or control within that car as the car, during its travel in the up direction, nears the landing for which such operated control is provided, and to slow down that car in response to any operated down control or control within that car as the car, during its travel in the down direction, nears the landing for which such operated control is provided; means for 70 causing said mechanism for any car to slow down that car in response to any operated one of said down controls for landings above a predetermined one of said landings as the car, during its travel in the up direction, nears the landing at which 75

down that car in response to any operated one of said down controls for landings above a predetermined one of said landings as the car, during its travel in the up direction, nears the landing at which such down control is located, under conditions where neither the up control at the landing at which such operated down control is located is operated nor an operated control at any landing above such landing or an operated control in that car for any landing above such landing remains to be responded to; means for preventing the slowing down of more than one car at a landing in response to an operated control at that landing; means for determining which of the cars is to travel above said predetermined landing, such means acting automatically to select a car to travel above such landing when one or more controls in that car for landings above said predetermined landing are operated and also when one or more operated controls at landings above said predetermined landing are to be responded to, either under conditions where no other car has been selected to travel above said predetermined landing or under conditions where said mechanism for any other car already selected to travel above said predetermined landing is no longer effective to respond to one or more of the operated controls at landings above said predetermined landing during such travel of such other car in either the up or the down direction; means for each car for causing said mechanism for that car, in the event that car is selected to travel above said predetermined landing, to slow down that car in its upward travel as it nears any landing above said predetermined landing at which said mechanism for that car can still do so, when a condition is reached where, at the time such means becomes effective, the up control at such landing is not operated, no control in that car for a landing above such landing is operated, and, upon the response to an operated control at a landing above said predetermined landing by said mechanism for some other car, no operated control at a landing above that car, to which said mechanism for that car is effective to respond, remains to be responded to; and means for each car for causing said mechanism for that car, after it has started to slow down the car, to bring the car to a stop at the landing at which it is slowing down.

52. An electric elevator system comprising; a plurality of elevator cars; a plurality of landings served by the cars; actuating and stopping mechanism for each car; a plurality of up controls, one at each of said landings, each up control being common to all cars; a plurality of down controls, one at each of said landings, each down control being common to all cars; a plurality of controls, one for each of said landings, in each car; means for causing said mechanism for any car to slow down that car in response to any operated up control or control within that car as the car, during its travel in the up direction, nears the landing for which such operated control is provided, and to slow down that car in response to any operated down control or control within that car as the car, during its travel in the down direction, nears the landing for which such operated control is provided; means for causing said mechanism for any car to slow down that car in response to any operated one of said down controls for landings above a predetermined one of said landings as the car, during its travel in the up direction, nears the landing at which 70

such down control is located, under conditions where neither the up control at the landing at which such operated down control is located is operated nor an operated control at any landing 5 above such landing or an operated control in that car for any landing above such landing remains to be responded to; means for preventing the slowing down of more than one car at a landing in response to an operated control at that 10 landing; means for automatically selecting a car to travel above such landing when one or more controls in that car for landings above said predetermined landing are operated or one or more operated controls at landings above said predetermined landing are to be responded to, either 15 under conditions where no other car has been selected to travel above said predetermined landing or under conditions where said mechanism for any other car previously selected to travel 20 above said predetermined landing is no longer effective to respond to one or more of the operated controls at landings above said predetermined landing during such travel of such other car in either the up or the down direction; means 25 for each car for causing said mechanism for that car, in the event that car is selected to travel above said predetermined landing, to slow down that car in its upward travel as it nears any landing above said predetermined landing at 30 which said mechanism for that car can still do so, when a condition is reached where, at the time such means becomes effective, the up control at such landing is not operated, no control in that car for a landing above such landing is 35 operated and, upon the response to an operated control at a landing above said predetermined landing by said mechanism for some other car, no operated control at a landing above that car, to which said mechanism for that car is effective 40 to respond, remains to be responded to; means for each car for causing said mechanism for that car, after it has started to slow down the car, to bring the car to a stop at the landing at which it is slowing down; means for each car operable 45 from within that car to cause the operation of said mechanism for that car to start the car; and means for each car for causing said mechanism for that car, once that car is selected to travel above said predetermined landing, to restart that 50 car in the up direction in response to said starting means for that car after each stop until said mechanism brings the car to a stop at a landing above said predetermined landing at which said mechanism slows down the car in response to 55 the down control at that landing or to the control in the car for that landing, under conditions where no operated control at a landing above such landing or operated control in that car for a landing above such landing remains to be re- 60 sponded to at the time said mechanism for that car is rendered effective to cause slow down of that car as it nears such landing, and to start the car from such landing in the down direction in response to said starting means for that car 65 after such stop, or for causing said mechanism for that car, once that car has been selected to travel above said predetermined landing, to restart the car in the up direction in response to said starting means for that car after each stop 70 until said mechanism brings the car to a stop at a landing above said predetermined landing at which said mechanism is caused to slow down the car under conditions where, at the time said mechanism is rendered effective to cause such slow down, the up control at such landing is not 75 operated, no operated control in that car for any landing above such landing is operated and, upon the response to an operated control at a landing above that car by said mechanism for some other car, no operated control at any landing above that car, to which said mechanism for that car is effective to respond, remains to be responded to, and to start the car from such landing in the down direction in response to said starting means for that car after such stop. 10

53. An electric elevator system comprising; a plurality of elevator cars; a plurality of landings served by the cars; actuating and stopping mechanism for each car; a plurality of up controls, one at each of said landings, each up control being 15 common to all cars; a plurality of down controls, one at each of said landings, each down control being common to all cars; a plurality of controls, one for each of said landings, in each car; means for causing said mechanism for any car to slow down that car in response to any operated up control or control within that car as the car, during its travel in the up direction, nears the landing for which such operated control is provided, and to slow down that car in response to any operated down control or control within that car as the car, during its travel in the down direction, nears the landing for which such operated control is provided; means for preventing the slowing down of more than one car at a landing in 20 response to an operated control at that landing; means for automatically selecting a car to travel above a predetermined one of said landings when one or more controls in that car for landings above said predetermined landing are operated or when one or more operated controls at landings above said predetermined landing are to be responded to under conditions where said mechanism for any other car previously selected to travel above said predetermined landing is no longer effective to respond to one or more of the operated controls at landings above said predetermined landing; means for each car for causing said mechanism for that car, in the event that car is selected to travel above said predetermined landing, to slow down that car in its upward travel as it nears any landing above said predetermined landing at which said mechanism for that car can still do so, when a condition is reached where, at the time such means becomes effective, the up control at such landing is not operated, no control in that car for a landing above such landing is operated and, upon the response to an operated control at a landing above said predetermined landing by said mechanism for some other car, no operated control at a landing above that car, to which said mechanism for that car is effective to respond, remains to be responded to; means for each car for causing said mechanism for that car, after it has started to slow down the car, to bring the car to a stop at the landing at which it is slowing down; means for each car operable from within that car to cause the operation of said mechanism for that car to start the car; and means for each car for causing said mechanism for that car, once that car is selected to travel above said predetermined landing, to restart that car in the up direction in response to said starting means for that car after each stop until it brings the car to a stop at a landing above said predetermined landing at which said mechanism for that car is caused to slow down the car under conditions where, at the time said mechanism is rendered effective to cause such slow down, the up control at such landing is not 30 35 40 45 50 55 60 65 70 75 80 85 90 95 100

trol at such landing is not operated, no operated control in that car for any landing above such landing is operated and, upon the response to an operated control at a landing above that car 5 by said mechanism for some other car, no operated control at any landing above that car, to which said mechanism for that car is effective to respond, remains to be responded to, and to start the car from such landing in the down 10 direction in response to said starting means for that car after such stop.

54. An electric elevator system comprising; a plurality of elevator cars; a plurality of landings served by the cars; actuating and stopping mechanism for each car; a plurality of up controls, one at each of said landings, each up control being common to all cars; a plurality of down controls, one at each of said landings, each down control being common to all cars; a plurality of controls, one for each of said landings, in each car; means for causing said mechanism for any car to slow down that car in response to any operated up control or control within that car as the car, during its travel in the up direction, nears the landing for which such operated control is provided, to slow down that car in response to any operated down control or control within that car as the car, during its travel in the down direction, nears the landing 30 for which such operated control is provided, and to slow down that car in response to any operated one of said down controls for landings above a predetermined intermediate one of said landings as the car, during its travel in the up direction, nears the landing at which such down control is located, under conditions where neither the up control at the landing at which such operated down control is located is operated nor an operated control at any landing 40 above such landing or an operated control in that car for any landing above such landing remains to be responded to; means for preventing the slowing down of more than one car at a landing in response to an operated control at that landing; means for each car for causing said mechanism for that car, during travel of that car in the up direction, to slow down that car as it nears said predetermined intermediate landing, in the event that the up control at said 50 predetermined landing is not operated and regardless of whether the control in that car for said predetermined landing is operated or not, provided no operated control at any landing above said predetermined landing or operated control in that car for any landing above said predetermined landing remains to be responded to or, if one or more operated controls at landings above said predetermined landing remain to be responded to, provided such control or controls can be responded to by said mechanism for another car already selected to travel above said predetermined landing during travel of such other car in the up direction and subsequent travel thereof in the down direction; means for 60 each car for causing said mechanism for that car, after it has started to slow down the car, to bring the car to a stop at the landing at which it is slowing down; and means for determining which of the up travelling cars is to travel above said predetermined intermediate landing, such means acting automatically to select an up travelling car to travel above such landing when said mechanism for that car causes the car to be slowed down at such landing in response to 70 the up control at such landing and when, at 75

the time said mechanism for that car is rendered effective to cause slow down of that car in response to the control in that car for such landing as the car nears such landing, provided such control is operated, or would be rendered effective to do so in response to such control if such control were operated, there are one or more operated controls in that car for landings above said predetermined landing to be responded to or there are one or more operated controls at 10 landings above said predetermined landing to be responded to, either under conditions where no other car has been selected to travel above said predetermined landing or under conditions where said mechanism for any other car already selected to travel above said predetermined landing is no longer effective to respond to one or more of the operated controls at landings above said predetermined landing during travel of such other car in the up direction or travel 20 thereof in the down direction.

55. An electric elevator system comprising; a plurality of elevator cars; a plurality of landings served by the cars; actuating and stopping mechanism for each car; a plurality of up controls, one at each of said landings, each up control being common to all cars; a plurality of down controls, one at each of said landings, each down control being common to all cars; a plurality of controls, one for each of said landings, in each car; means for causing said mechanism for any car to slow down that car in response to any operated up control or control within that car as the car, during its travel in the up direction, nears the landing for which such operated control is provided, to slow down that car in response to any operated down control or control within that car as the car, during its travel in the down direction, nears the landing for which such operated control is provided, and to slow down that car in response to any operated one of said down controls for landings above a predetermined intermediate one of said landings as the car, during its travel in the up direction, nears the landing at which such down control is located, under conditions where neither the up control at the landing at which such operated down control is located is operated nor an operated control at any landing above such landing or an operated control in that car for any landing above such landing remains to be responded to; means for preventing the slowing down of more than one car at a landing in response to an operated control at that landing; means for each car for causing said mechanism for that car, during travel of that car in the up direction, to slow down that car as it nears said predetermined intermediate landing, in the event that the up control at said predetermined landing is not operated and regardless of whether the control in that car for said predetermined landing is operated or not, provided no operated control at any landing above said predetermined landing or operated control in that car for any landing above said predetermined landing remains to be responded to or, if one or more operated controls at landings above said predetermined landing remain to be responded to, provided such control or controls can be responded to by said mechanism for another car, already selected to travel above said predetermined landing, during travel of such other car in the up direction and subsequent travel thereof in the down direction; means for each car for causing said mechanism for that car, in the event that car is selected to travel above said predetermined 70 75

landing, to slow down that car during its upward travel as it nears any landing above said predetermined landing at which said mechanism for that car can still do so, when a condition is 5 reached where, at the time such mechanism is rendered effective to slow down that car at such landing as it nears such landing, the up control at such landing is not operated, no control in that car for a landing above such landing is operated, 10 and, due to the response to an operated control at a landing above said predetermined landing by said mechanism for some other car, no operated control at a landing above that car, to which said mechanism for that car is effective to 15 respond, remains to be responded to; means for each car for causing said mechanism for that car, after it has started to slow down the car, to bring the car to a stop at the landing at which it is slowing down; means for determining which 20 of the up travelling cars is to travel above said predetermined intermediate landing, such means acting automatically to select an up travelling car to travel above such landing when said mechanism for that car causes the car to be slowed 25 down at such landing in response to the up control at such landing and when, at the time said mechanism for that car is rendered effective to cause slow down of that car in response to the control in that car for such landing as the car 30 nears such landing, provided such control is operated or would be rendered effective to do so in response to such control if such control were operated, there are one or more operated controls in that car for landings above said predetermined 35 landing to be responded to or there are one or more operated controls at landings above said predetermined landing to be responded to, either under conditions where no other car has been selected to travel above said predetermined land- 40 ing or under conditions where said mechanism for any other car already selected to travel above said predetermined landing is no longer effective to respond to one or more of the operated controls at landings above said predetermined land- 45 ing during travel of such other car in the up direction or travel thereof in the down direction; means for each car operable from within that car to cause said mechanism for that car to start the car; and means for each car for causing said 50 mechanism for that car, once it has started that car in the up direction, to restart it in that direction in response to said starting means for that car until it brings the car to a stop at said predetermined intermediate landing under conditions 55 where that car is not selected to travel above said predetermined intermediate landing and to start it from such landing in the down direction, and if that car is selected to travel above said predetermined landing, for causing said mecha- 60 nism for that car to restart that car in the up direction in response to said starting means for that car after each stop until it brings the car to a stop at a landing above said predetermined landing at which said mechanism for that car 65 slows down that car in response to the down control at that landing or to the control in the car for that landing, under conditions where no operated control at a landing above such landing or operated control in that car for a landing above 70 such landing remained to be responded to at the time said mechanism for that car was rendered effective to cause slow down of that car as it neared such landing, and to start the car from such landing in the down direction in response 75 to said starting means for that car, or for caus- ing said mechanism for that car to restart the car in the up direction in response to said starting means for that car after each stop until it brings the car to a stop at a landing above said predetermined landing at which said mechanism 5 for that car is caused to slow down the car under conditions where, at the time said mechanism is rendered effective to cause such slow down, the up control at such landing is not operated, no operated control in that car for any landing 10 above such landing is operated and, due to the response to an operated control at a landing above that car by said mechanism for some other car, no operated control at any landing above that car, to which said mechanism for that car 15 is effective to respond, remains to be responded to, and to start the car from such landing in the down direction in response to said starting means for that car. 20

56. An electric elevator system comprising; a plurality of elevator cars; a plurality of landings served by the cars; a plurality of controls, one for each of said landings, for one direction of travel; a plurality of controls, one for each of said landings, for the opposite direction of travel; means for causing any car, during its travel in said one direction, to slow down and stop at any landing in response to the control for that direction for that landing and for causing any car, during its travel in the opposite direction, to slow 25 down and stop at any landing in response to the control for that direction for that landing; means for determining which of the cars is to travel beyond a predetermined intermediate one of said landings in said one direction, such means acting automatically to select a car for such travel when the operated controls for landings beyond said predetermined landing in said one direction to be responded to reach a number determined by the number of cars already selected 30 for such travel; and means for causing any car, during its travel in said one direction, to slow down, stop and reverse its direction of travel at said predetermined landing in the event it is not selected for travel beyond such landing in said 35 one direction. 40

57. An electric elevator system comprising; a plurality of elevator cars; a plurality of landings served by the cars; actuating and stopping mechanism for each car; a plurality of controls, one for each of said landings, for one direction of travel; a plurality of controls, one for each of said landings, for the opposite direction of travel; means for causing said mechanism for any car, during travel of that car in said one direction, 55 to slow down and stop that car at any landing in response to the control for that direction for that landing and, during travel of that car in the opposite direction, to slow down and stop that car at any landing in response to the control for that direction for that landing; switching means for each car manually controllable from within that car to cause operation of said mechanism for that car to start the car after each stop; and means for determining which of the cars is to travel beyond a predetermined one of said landings in said one direction, such means acting automatically to select a car for such travel when there are one or more operated controls for landings beyond said predetermined landing in said 60 one direction to be responded to under conditions where no other car has been selected for such travel and, if one or more cars have already been selected for such travel, to select another car for such travel when the operated con- 65 70 75

5   58. An electric elevator system comprising; a plurality of elevator cars; a terminal landing and a plurality of intermediate landings served by the cars; actuating and stopping mechanism for each car; means for each car for causing said 10 mechanism for that car to start the car; a plurality of up controls, one at each of said intermediate landings, each up control being common to all cars; a plurality of down controls, one at each of said intermediate landings, each down 15 control being common to all cars; means for causing said mechanism for any car to slow down that car in response to any operated up control as the car, during its travel in the up direction, nears the landing at which such operated 20 control is located and to slow down that car in response to any operated down control as the car, during its travel in the down direction, nears the landing at which such operated control is located; means for each car for causing 25 said mechanism for that car, after it has started to slow down the car, to bring the car to a stop at the landing at which it is slowing down; and means for causing an up travelling car to travel above a predetermined one of said landings when 30 there are one or more operated controls at landings above said predetermined landing to be responded to under conditions either where no other car has been selected to travel above said predetermined landing or, if one or more of the 35 other cars have already been selected to travel above said predetermined landing, where said mechanisms for all of such cars are no longer effective to respond to one or more of the operated controls at landings above said predetermined landing during travel of such other car 40 in the up direction or travel thereof in the down direction or where the operated controls at landings above said predetermined landing reach a predetermined number determined by the number 45 of cars already selected to travel above said predetermined landing.

59. An electric elevator system comprising; a plurality of elevator cars; a plurality of landings served by the cars; actuating and stopping mechanism for each car; a plurality of up controls, one at each of said landings, each up control being common to all cars; a plurality of down controls, one at each of said landings, each down control being common to all cars; a plurality of 55 controls, one for each of said landings, in each car; means for causing said mechanism for any car to slow down that car in response to any operated up control or control within that car as the car, during its travel in the up direction, nears 60 the landing for which such operated control is provided and to slow down that car in response to any operated down control or control within that car as the car, during its travel in the down direction, nears the landing for which such operated control is provided; means for preventing the slowing down of more than one car at a landing in response to an operated control at that landing; means for each car for causing said mechanism for that car, after it has started to 65 slow down the car, to bring the car to a stop at the landing at which it is slowing down; means for determining which of the up travelling cars is to travel above a predetermined intermediate one of said landings, such means acting automatically to select an up travelling car to travel

above such landing when said mechanism for that car causes the car to be slowed down at such landing in response to the up control at such landing and when, at the time said mechanism for that car is rendered effective to cause slow down of that car in response to the control in that car for such landing as the car nears such landing, provided such control is operated, or would be rendered effective to do so in response to such control if such control were operated, there are one or more operated controls in that car for landings above said predetermined landing to be responded to or there are one or more operated controls at landings above said predetermined landing to be responded to under conditions either where no other car has been selected to travel above said predetermined landing or, if one or more of the other cars have already been selected to travel above said predetermined landing, where none of said mechanisms for such other selected cars remains effective to respond to one or more of the operated controls at landings above said predetermined landing during travel of such other car in the up direction or travel thereof in the down direction or where the operated controls at landings above said predetermined landing reach a predetermined number, determined by the number of cars already selected to travel above said predetermined landing; means for each car operable from within that car to cause the operation of said mechanism for that car to start the car after each stop; and means for causing said mechanism for any up travelling car to slow down and stop that car at said predetermined intermediate landing and to start the car in the down direction from such landing in response to said starting means for that car after such stop under conditions where that car is not selected to travel above such landing.

60. An electric elevator system comprising; a plurality of elevator cars; a plurality of landings served by the cars; actuating and stopping mechanism for each car; a plurality of up controls, one at each of said landings, each up control being common to all cars; a plurality of down controls, one at each of said landings, each down control being common to all cars; a plurality of controls, one for each of said landings, in each car; means for causing said mechanism for any car to slow down that car in response to any operated up control or control within that car as the car, during its travel in the up direction, nears the landing for which such operated control is provided, to slow down that car in response to any operated down control or control within that car as the car, during its travel in the down direction, nears the landing for which such operated control is provided, and to slow down that car in response to any operated one of said down controls for landings above a predetermined intermediate one of said landings as the car, during its travel in the up direction, nears the landing at which such down control is located, under conditions where neither the up control at the landing at which such operated down control is located is operated nor an operated control at any landing above such landing or an operated control in that car for any landing above such landing remains to be responded to; means for preventing the slowing down of more than one car at a landing in response to an operated control at that landing; means for causing said mechanism for each car, during travel of that car in the up direction, to slow down that car as it nears said predetermined intermediate landing; means for each car

for causing said mechanism for that car, after it has started to slow down the car, to bring the car to a stop at the landing at which it is slowing down; means for determining which of the up travelling cars is to travel above said predetermined intermediate landing, such means acting automatically to select an up travelling car to travel above such landing when said mechanism for that car causes the car to be slowed down at 5 such landing in response to the up control at such landing and when, at the time said mechanism for that car is rendered effective to cause slow down of that car in response to the control in that car for such landing as the car nears 10 such landing, provided such control is operated, or would be rendered effective to do so in response to such control if such control were operated, there are one or more operated controls in that car for landings above said predetermined landing 15 to be responded to or there are one or more operated controls at landings above said predetermined landing to be responded to under conditions, either where no other car has been selected to travel above said predetermined landing 20 or, if one or more of the other cars has already been selected to travel above said predetermined landing, provided one or more of the landings at which such control or controls are operated are in effect behind all such other cars or provided 25 the operated controls at landings above said predetermined landing reach a predetermined number, determined by the number of cars already selected to travel above said predetermined landing; means for each car operable from within 30 that car to cause the operation of said mechanism for that car to start the car; and means for each car for causing said mechanism for that car, once it has started that car in the up direction, to restart it in that direction in response to 35 said starting means for that car until it brings the car to a stop at said predetermined intermediate landing under conditions where that car is not selected to travel above said predetermined intermediate landing and if that car is selected 40 to travel above said predetermined landing, for causing said mechanism for that car to operate that car above said predetermined landing.

61. An electric elevator system comprising; a plurality of elevator cars; a plurality of landings 45 served by the cars; actuating and stopping mechanism for each car; a plurality of up controls, one at each of said landings, each up control being common to all cars; a plurality of down controls, one at each of said landings, each down control 50 being common to all cars; a plurality of controls, one for each of said landings, in each car; means for causing said mechanism for any car to slow down that car in response to any operated up control or control within that car as the car, during 55 its travel in the up direction, nears the landing for which such operated control is provided, to slow down that car in response to any operated down control or control within that car as the car, during 60 its travel in the down direction, nears the landing for which such operated control is provided, and to slow down that car in response to any operated one of said down controls for landings above a predetermined intermediate one of 65 said landings as the car, during its travel in the up direction, nears the landing at which such down control is located, under conditions where neither the up control at the landing at which such operated down control is located is operated nor an operated control at any landing above 70 such landing or an operated control in that 75

car for any landing above such landing remains to be responded to; means for preventing the slowing down of more than one car at a landing in response to an operated control at that landing; means for each car for causing said mechanism for that car, during travel of that car in the up direction, to slow down that car as it nears said predetermined intermediate landing, in the event that the up control at said predetermined landing is not operated and regardless of whether the control in that car for said predetermined landing is operated or not, provided no operated control at any landing above said predetermined landing or operated control in that car for any landing above said predetermined landing remains to be responded to or, if one or more operated controls at landings above said predetermined landing remain to be responded to, provided such operated controls do not exceed a predetermined number; means for each car for causing said mechanism for that car, in the event that car is selected to travel above said predetermined landing, to slow down that car during its upward travel as it nears any landing above said predetermined landing at which said mechanism for that car can still do so, when a condition is reached where, at the time such mechanism is rendered effective to slow down that car at such landing as it nears such landing, the up control at such landing is not operated, no control in that car for a landing above such landing is operated and, due to the response to an operated control at a landing above said predetermined landing by said mechanism for some other car, no operated control at a landing above that car, to which said mechanism for that car is effective to respond, remains to be responded to; means for each car for causing said mechanism for that car, after it has started to slow down the car, to bring the car to a stop at the landing at which it is slowing down; means for determining which of the up travelling cars is to travel above said predetermined intermediate landing, such means acting automatically to select an up travelling car to travel above such landing when said mechanism for that car causes the car to be slowed down at such landing in response to the up control at such landing and when, at the time said mechanism for that car is rendered effective to cause slow down of that car in response to the control in that car for such landing as the car nears such landing, provided such control is operated, or would be rendered effective to do so in response to such control if such control were operated, there are one or more operated controls in that car for landings above said predetermined landing to be responded to or there are a predetermined number of operated controls at landings above said predetermined landing to be responded to, determined by the number of cars already selected to travel above said predetermined landing; and means for each car operable from within that car to cause the operation of said mechanism for that car to start the car after each stop.

62. An electric elevator system comprising; a plurality of elevator cars; a plurality of landings served by the cars; actuating and stopping mechanism for each car; a plurality of up controls, one at each of said landings, each up control being common to all cars; a plurality of down controls, one at each of said landings, each down control being common to all cars; a plurality of controls, one for each of said landings, in each car; means for causing said mechanism for any car to slow down that car in response to any operated up control or control within that car as the car, during its travel in the up direction, nears the landing for which such operated control is provided, to slow down that car in response to any operated down control or control within that car as the car, during its travel in the down direction, nears the landing for which such operated control is provided, and to slow down that car in response to any operated one of said down controls for landings above a predetermined intermediate one of said landings as the car, during its travel in the up direction, nears the landing at which such down control is located, under conditions where neither the up control at the landing at which such operated down control is located is operated nor an operated control at any landing above such landing or an operated control in that

car to slow down that car in response to any operated up control or control within that car as the car, during its travel in the up direction, nears the landing for which such operated control 5 is provided, to slow down that car in response to any operated down control or control within that car as the car, during its travel in the down direction, nears the landing for which such operated control is provided, and to slow down that car in 10 response to any operated one of said down controls for landings above a predetermined intermediate one of said landings as the car, during its travel in the up direction, nears the landing at which such down control is located, under 15 conditions where neither the up control at the landing at which such operated down control is located is operated nor an operated control at any landing above such landing or an operated control in that car for any landing above such 20 landing remains to be responded to; means for preventing the slowing down of more than one car at a landing in response to an operated control at that landing; means for each car for causing said mechanism for that car, during travel 25 of that car in the up direction, to slow down that car as it nears said predetermined intermediate landing, in the event that the up control at said predetermined landing is not operated and regardless of whether the control in that car for 30 said predetermined landing is operated or not, provided no operated control at any landing above said predemined landing or operated controlin that car for any landing above said predetermined landing remains to be responded to or, 35 if one or more operated controls at landings above said predetermined landing remain to be responded to, provided such control or controls can be responded to by said mechanism for another car already selected to travel above said 40 predetermined landing during travel of such other car in the up direction and subsequent travel thereof in the down direction and provided further such operated controls do not exceed a predetermined number; means for each car for 45 causing said mechanism for that car, in the event that car is selected to travel above said predetermined landing, to slow down that car during its upward travel as it nears any landing above said predetermined landing at which said mechanism 50 for that car can still do so, when a condition is reached where, at the time such mechanism is rendered effective to slow down that car at such landing as it nears such landing, the up control at such landing is not operated, no control in that 55 car for a landing above such landing is operated and, due to the response to an operated control at a landing above said predetermined landing by said mechanism for some other car, no operated control at a landing above that car, to which said 60 mechanism for that car is effective to respond, remains to be responded to; means for each car for causing said mechanism for that car, after it has started to slow down the car, to bring the car to a stop at the landing at which it is slowing 65 down; means for determining which of the up travelling cars is to travel above said predetermined intermediate landing, such means acting automatically to select an up travelling car to travel above such landing when said mechanism for that car causes the car to be slowed down at such landing in response to the up control at such landing and when, at the time said mechanism for that car is rendered effective to cause slow down of that car in response to the 70 75 control in that car for such landing as the car

nears such landing, provided such control is operated or would be rendered effective to do so in response to such control if such control were operated, there are one or more operated controls in that car for landings above said predetermined landing to be responded to or there are one or more operated controls at landings above said predetermined landing to be responded to, either under conditions where no other car has been selected to travel above said predetermined landing or, if one or more of the other cars has already been selected to travel above said predetermined landing, provided none of said mechanisms for such other cars remains effective to respond to one or more of the operated controls 5 at landings above said predetermined landing during travel of such other car in the up direction or travel thereof in the down direction or provided the operated controls at landings above said predetermined landing reach a predetermined number, determined by the number of cars already selected to travel above said predetermined landing; means for each car operable from within that car to cause the operation of said mechanism for that car to start the car; and means for each car for causing said mechanism for that car, once it has started that car in the up direction, to restart it in that direction in response to said starting means for that car until it brings the car to a stop at said predetermined 10 intermediate landing under conditions where that car is not selected to travel above said predetermined intermediate landing and to start it from such landing in the down direction, and if that car is selected to travel above said predetermined landing, for causing said mechanism for that car to restart that car in the up direction in response to said starting means for that car after each stop until it brings the car to a stop at a landing above said predetermined landing at which said mechanism for that car slows down that car in response to the down control at that landing or to the control in the car for that landing, under conditions where no operated control at a landing above such landing or operated control in that car for a landing above such landing remained to be responded to at the time said mechanism for that car was rendered effective to cause slow down of that car as it neared such landing, and to start the car 15 from such landing in the down direction in response to said starting means for that car, or for causing said mechanism for that car to restart the car in the up direction in response to said starting means for that car after each stop until it brings the car to a stop at a landing above said predetermined landing at which said mechanism for that car is caused to slow down the car due to a condition being reached where, at the time said mechanism is rendered effective 20 to cause such slow down, the up control at such landing is not operated, no control in that car for any landing above such landing is operated and, due to the response to an operated control at a landing above that car by said mechanism for some other car, no operated control at any landing above that car, to which said mechanism for that car is effective to respond, remains to be responded to, and to start the car from such landing in the down direction in response to 25 said starting means for that car. 30

63. In an elevator control system for a plurality of cars in which an up hall button and a down hall button are provided at each intermediate landing and in which means are pro- 35 40 45 50 55 60 65 70 75

vided for each car for stopping the car, during its upward travel, at landings for which calls are registered by the pressing of up hall buttons and, during its downward travel, at landings for which calls are registered by the pressing of down hall buttons, characterized by the fact that means are provided for causing an up travelling car to stop at a landing in response to a down hall call at that landing and to be set for downward travel from that landing when no hall call is registered for any landing between such landing and the next up travelling car above that car.

64. In an elevator control system for a plurality of cars in which an up hall button and a down hall button are provided at each intermediate landing, in which each car is provided with a car button for each intermediate landing and in which means are provided for each car for stopping the car, during its up travel, at landings for which calls are registered by the pressing of up hall buttons or by the pressing of car buttons for that particular car and, during its down travel, at landings for which calls are registered by the pressing of down hall buttons or by the pressing of car buttons for that particular car, characterized by the fact that means are provided for causing an up travelling car to stop at a landing in response to a down hall call at that landing and to be set for downward travel from that landing after such stop when no car call for that car is registered for any landing above such landing, the up hall call at such landing is not registered and no hall call is registered at any landing between such landing and the next up travelling car above that car.

65. In an elevator control system for a plurality of cars in which an up hall button and a down hall button are provided at each intermediate landing, in which each car is provided with a car button for each intermediate landing and in which means are provided for each car for stopping the car at landings for which calls are registered by the pressing of hall buttons or by the pressing of car buttons for that particular car, characterized by the fact that means are provided for causing an up travelling car to be set for downward travel from the landing at which it is stopped in response to its highest car call when no hall calls exist for landings between such landing and the up travelling car next above that car.

66. An electric elevator system comprising: a plurality of elevator cars; a plurality of landings served by the cars; start control means for each car manually operable from within that car to start the car after each stop; a plurality of up controls, one for each of said landings; a plurality of down controls, one for each of said landings; means for causing any car, during its upward travel, to slow down and stop at any landing in response to the up control for that landing, and for causing any car, during its downward travel, to slow down and stop at any landing in response to the down control for that landing; and means for causing any car, during its upward travel, to slow down and stop at any landing in response to the down control for that landing and to start from such landing in the down direction in response to the start control means for that car after such stop, under conditions where the up control at such landing is not operated and where either no operated

control at any landing above such landing remains to be responded to or, if one or more controls at landings above such landing do remain to be responded to, provided there is another up travelling car above that car and below the landings at which such control or controls are located.

67. An electric elevator system comprising: a plurality of elevator cars; a plurality of landings served by the cars; actuating and stopping mechanism for each car; a plurality of up controls, one at each of said landings; a plurality of down controls, one at each of said landings; a plurality of controls in each car, one for each of said landings; means for causing said mechanism for any car to slow down that car in response to any operated up control or control within that car as the car, during its travel in the up direction, nears the landing for which such operated control is provided, and to slow down that car in response to any operated down control or control within that car as the car, during its travel in the down direction, nears the landing for which such operated control is provided; means for causing said mechanism for any car to slow down that car in response to any operated one of said down controls as the car, during its travel in the up direction, nears the landing at which such down control is located, under conditions where the up control at the landing at which such operated down control is located is not operated, where no control in that car for any landing above such landing is operated and where either no operated control at any landing above such landing remains to be responded to or, if one or more controls at landings above such landing do remain to be responded to, there is another up travelling car in effect above that car and in effect below the landings at which such control or controls are operated; and means for each car for causing said mechanism for that car, after it has started to slow down the car, to bring the car to a stop at the landing at which it is slowing down.

68. An electric elevator system comprising: a plurality of elevator cars; a plurality of landings served by the cars; actuating and stopping mechanism for each car; start control means for each car manually operable from within that car to cause the operation of said mechanism for that car to start the car after each stop; a plurality of up controls, one at each of said landings, each up control being common to all cars; a plurality of down controls, one at each of said landings, each down control being common to all cars; means for causing said mechanism for any car to slow down and stop that car in response to any operated up control as the car, during its travel in the up direction, arrives at the landing at which such operated control is located, and to slow down and stop that car in response to any operated down control as the car, during its travel in the down direction, arrives at the landing at which such operated control is located; means for causing said mechanism for any car to slow down and stop that car in response to any operated one of said down controls as the car, during its travel in the up direction, arrives at the landing at which such down control is located and to start that car from such landing in the down direction in response to said start control means for that car after such stop, under conditions where, at the time that said mechanism for that car is rendered effective to slow down the car as it nears such landing, the up control

at the landing at which such operated down control is located is not operated and either no operated control at any landing above such landing remains to be responded to or, if one or more controls at landings above such landing remain to be responded to, there is another up travelling car in effect above such car and in effect below the landings at which such control or controls are located; means for preventing the slowing down 10 and stopping of more than one car at a landing in response to an operated control at that landing; and means for each car for causing said mechanism for that car, during travel of that car in the up direction, to slow down and stop 15 that car as it arrives at any landing when a condition is reached where, at the time said mechanism for that car is rendered effective to slow down that car as it nears such landing, the up control at such landing is not operated and, upon 20 response to an operated down control at a landing above that car by a down car, either no operated control at any landing above the car remains to be responded to or if one or more controls at landings above the car remain to be responded to, there is another up travelling car in effect above that car and in effect below such landings, and for causing said mechanism for that car to start the car from that landing in the 25 down direction in response to said start control 30 means for that car after such stop.

69. An electric elevator system comprising; a plurality of elevator cars; a plurality of landings served by the cars; actuating and stopping mechanism for each car; means for each car operable from within that car to cause the operation of 35 said mechanism for that car to start the car, a plurality of up controls, one at each of said landings, each up control being common to all cars; a plurality of down controls, one at each of said 40 landings, each down control being common to all cars; a plurality of controls, one for each of said landings, in each car; means for causing said mechanism for any car to slow down that car in response to any operated up control or control 45 within that car as the car, during its travel in the up direction, nears the landing for which such operated control is provided, and to slow down that car in response to any operated down control or control within that car as the car, during 50 its travel in the down direction, nears the landing for which such operated control is provided; means for causing said mechanism for any car to slow down that car in response to any operated one of said down controls as the car, during 55 its travel in the up direction, nears the landing at which such down control is located, and to start that car from such landing in the down direction in response to said starting means for that car after such stop, under conditions where, at 60 the time that said mechanism for that car is rendered effective to slow down the car as it nears such landing, the up control at such landing is not operated, no control in that car for any landing above such landing is operated and either 65 no operated control at any landing above such landing remains to be responded to or, if one or more controls at landings above such landing do remain to be responded to, there is another up traveling car in effect above such car 70 and in effect below the landings at which such control or controls are located; means for preventing the slowing down of more than one car at a landing in response to an operated control at that landing; means for each car for 75 causing said mechanism for that car, after it

has started to slow down the car, to bring the car to a stop at the landing at which it is slowing down; and means for each car for causing said mechanism for that car, once it has started that car in the up direction, to restart it in that direction in response to said starting means for that car until it brings the car to a stop at a landing at which it slows down the car in response to the down control at that landing and to start the car from such landing in the down direction in response to said starting means for that car, or for causing said mechanism for that car to restart the car in the up direction in response to said starting means for that car after each stop until it brings the car to a stop at a landing at which it slows down the car in response to the control in that car for such landing and to start the car therefrom in the down direction in response to the starting means for that car under conditions where, at the time such mechanism is rendered effective to cause such slow down, the up control at such landing is not operated, no control in that car for any landing above such landing is operated and either no operated control at any landing above that car, to which said mechanism for that car is effective to respond, remains to be responded to, or, if one or more operated controls at landings above that car do remain to be responded to, provided there is another up travelling car in effect above such car and in effect below the landings at which such control or controls are located.

70. In an elevator control system for a plurality of cars in which an up hall button and a down hall button are provided at each intermediate landing, in which each car is provided with a car button for each intermediate landing and in which means are provided for each car for stopping the car at landings for which calls are registered by the pressing of hall buttons or by the 40 pressing of car buttons for that particular car, characterized by the fact that means are provided for causing an up travelling car to be set for downward travel from the landing at which it is stopped in response to its highest car call when 45 no hall calls are registered which cannot be answered by a car above that car as said car above completes its trip in the up direction and returns to the lower terminal.

71. In an elevator control system for a plurality of cars in which an up hall button and a down hall button are provided at each intermediate landing and each car is provided with a car button for each intermediate landing, in which means are provided for each car for stopping the 55 car at landings for which calls are registered by the pressing of hall buttons or by the pressing of car buttons for that particular car and in which each car is provided with a non-stop control operable to cause the car to run past hall 60 calls without stopping in response thereto, characterized by the fact that means are provided for causing an up following car to be set for downward travel from the landing at which it is stopped in response to its highest car call when 65 no hall calls are registered which cannot be answered by a car above that car and further by the fact that means are provided for causing said following car to continue its travel in the up direction, when said non-stop control in said car 70 above is operated, so long as hall calls are registered above such following car.

72. An electric elevator system comprising; a plurality of elevator cars; a plurality of landings served by the cars; a plurality of up controls, one 75

at each of said landings; a plurality of down controls, one at each of said landings; a plurality of controls, one for each of said landings, in each car; means for causing any car, during its upward travel, to stop at any landing in response to the up control at that landing or to the control within that car for that landing, and for causing any car, during its downward travel, to stop at any landing in response to the down control at that landing or to the control within that car for that landing; start control means for each car manually operable from within that car to start the car; and means for each car for causing that car, once it has started that car in the up direction, to restart in the up direction in response to its start control means after each stop until it stops at a landing in response to the control in that car for such landing and to start therefrom in the down direction in response to its start control means under conditions where the up control at such landing is not operated, no control in that car for any landing above such landing is operated and either no control at any landing above that car is operated or, if one or more operated controls at landings above that car remain to be responded to, there is another car in effect ahead of that car and in a position to respond to such controls.

73. In an elevator control system for a plurality of cars in which an up hall button and a down hall button are provided at each intermediate landing and each car is provided with a car button for each intermediate landing, in which means are provided for each car for stopping the car at landings for which calls are registered by the pressing of hall buttons or by the pressing of car buttons for that particular car and in which each car is provided with a non-stop control operable to cause the car to run past hall calls without stopping in response thereto, characterized by the fact that means are provided for causing an up following car to reverse its direction of travel at the landing at which it is stopped in response to its highest car call when no hall calls are registered for landings above that car which cannot be answered by a car above that car and further by the fact that means are provided for causing said following car to continue its travel in the up direction, when said non-stop control in said car above is operated, so long as hall calls are registered above such following car.

74. An electric elevator system comprising; a plurality of elevator cars; a plurality of landings served by the cars; actuating and stopping mechanism for each car; a plurality of up controls, one at each of said landings, each up control being common to all cars; a plurality of down controls, one at each of said landings, each down control being common to all cars; a plurality of controls, one for each of said landings, in each car; means for causing said mechanism for any car to slow down that car in response to any operated up control or control within that car as the car, during its travel in the up direction, nears the landing for which such operated control is provided, and to slow down that car in response to any operated down control or control within that car as the car, during its travel in the down direction, nears the landing for which such operated control is provided; means for preventing the slowing down of more than one car at a landing in response to an operated control at that landing; means for each car for causing said mechanism for that car, after it has started to slow down the car, to bring the car to a stop at the landing at which it is slowing down; means for each car operable from within that car to cause the operation of said mechanism for that car to start the car; and means for each car operable, once said mechanism for that car has started that car in the up direction, to cause that car to continue its travel in the up direction at least until said predetermined landing is reached and in the event that one or more controls in that car for landings above such landing are operated or there are one or more operated controls at landings above such landing to be responded to under conditions either where no other car is in effect above that car or where there

which it is slowing down; means for each car operable from within that car to cause the operation of said mechanism for that car to start the car; and means for each car for causing said mechanism for that car, once it has started that car in the up direction, to restart it in the up direction in response to said starting means for that car after each stop until it brings the car to a stop at a landing at which it slows down the car in response to the control in that car for such landing and to start the car therefrom in the down direction in response to the starting means for that car under conditions where, at the time such mechanism is rendered effective to cause such slow down, the up control at such landing is not operated, no control in that car for any landing above such landing is operated and either no operated control at any landing above that car to which said mechanism for that car is effective to respond remains to be responded to or, if one or more operated controls at landings above that car to which said mechanism is effective to respond remain to be responded to, such landings at which such control or controls are located are in effect ahead of any other car in effect above that car.

75. An electric elevator system comprising; a plurality of elevator cars; a plurality of landings served by the cars; actuating and stopping mechanism for each car; a plurality of up controls, one at each of said landings, each up control being common to all cars; a plurality of down controls, one at each of said landings, each down control being common to all cars; a plurality of controls, one for each of said landings, in each car; means for causing said mechanism for any car to slow down that car in response to any operated up control or control within that car as the car, during its travel in the up direction, nears the landing for which such operated control is provided; means for causing said mechanism for any car to slow down that car in response to any operated one of said down controls for landings above a predetermined one of said landings as the car, during its travel in the up direction, nears the landing at which such down control is located, under conditions where there is no other car in effect above that car, the up control at such landing is not operated, no control in that car for any landing above such landing is operated and no operated control at any landing above such landing remains to be responded to; means for preventing the slowing down of more than one car at a landing in response to an operated control at that landing; means for each car for causing said mechanism for that car, after it has started to slow down the car, to bring the car to a stop at the landing at which it is slowing down; means for each car operable from within that car to cause the operation of said mechanism for that car to start the car; and means for each car operable, once said mechanism for that car has started that car in the up direction, to cause that car to continue its travel in the up direction at least until said predetermined landing is reached and in the event that one or more controls in that car for landings above such landing are operated or there are one or more operated controls at landings above such landing to be responded to under conditions either where no other car is in effect above that car or where there

are one or more other cars in effect above that car but none of them is in position where its mechanism can respond to one or more of such operated controls, to cause that car to continue 5 its travel in the up direction until it is brought to a stop at a landing above said predetermined landing at which it is slowed down in response to the down control at that landing and to cause the car to be started by its mechanism from such 10 landing in the down direction in response to said starting means for that car after such stop, or to cause that car to continue its travel in the up direction until it is brought to a stop at a landing above said predetermined landing at which it is 15 slowed down in response to the control in that car for such landing under conditions where the up control at such landing is not operated, no control in that car for any landing above such landing is operated and either no control at any 20 landing above that car is operated or, if one or more operated controls at landings above that car remain to be responded to, there is another car in effect above that car and in position where its mechanism can respond to such control or 25 controls and to cause the car to be started by its mechanism from such landing in the down direction in response to the starting means for that car after such stop.

76. An electric elevator system comprising; a 30 plurality of elevator cars; a plurality of landings served by the cars; actuating and stopping mechanism for each car; a plurality of up controls, one at each of said landings, each up control being common to all cars; a plurality of down 35 controls, one at each of said landings, each down control being common to all cars; a plurality of controls, one for each of said landings, in each car; means for causing said mechanism for any car to slow down that car in response to any 40 operated up control or control within that car as the car, during its travel in the up direction, nears the landing for which such operated control is provided, and to slow down that car in response to any operated down control or control 45 within that car as the car, during its travel in the down direction, nears the landing for which such operated control is provided; means for causing said mechanism for any car to slow down that car in response to any operated one of said 50 down controls for landings above a predetermined intermediate one of said landings as the car, during its travel in the up direction, nears the landing at which such down control is located, under conditions where there is no other 55 car in effect above that car, the up control at such landing is not operated, no control in that car for any landing above such landing is operated and no operated control at any landing above such landing remains to be responded to; 60 means for preventing the slowing down of more than one car at a landing in response to an operated control at that landing; means for causing said intermediate landing to be different for different cars; means for each car for causing 65 said mechanism for that car, during travel of that car in the up direction, to slow down that car as it nears said predetermined intermediate landing for that car; means for each car for causing said mechanism for that car, after it has 70 started to slow down the car, to bring the car to a stop at the landing at which it is slowing down; means for each car operable from within that car to cause the operation of said mechanism for that car to start the car; and means for each 75 car for causing said mechanism for that car, once

it has started that car in the up direction, to restart it in that direction in response to said starting means for that car after each stop until it brings the car to a stop at said predetermined intermediate landing and to start it from such landing in the down direction in response to said starting means for that car after such stop, under conditions where the slow down at said predetermined landing was not in response to the up control at that landing and where at the time said mechanism for that car is rendered effective to cause the car to slow down as it nears said predetermined landing no control in that car for any landing above said predetermined landing is operated and either no control at any landing above said predetermined landing is operated or, if one or more operated controls at landings above said predetermined landing remain to be responded to, there is another car in effect above that car and in position where its mechanism can respond to such control or controls, and, in the event said mechanism for that car slows down that car at said predetermined landing in response to the up control at that landing or in the event that at the time said mechanism for that car is rendered effective to slow down that car as it nears such landing one or more controls in that car for landings above said predetermined landing are operated or in the event that at such time there are one or more operated controls at landings above said predetermined landing to be responded to under conditions either where no other car is in effect above that car or where there are one or more other cars in effect above that car but none of them is in position where its mechanism can respond to one or more of such operated controls, for causing said mechanism for that car to restart that car in the up direction in response to said starting means for that car after each 40 stop until it brings the car to a stop at a landing above said predetermined landing at which it slows down the car in response to the down control at that landing, and to start the car from such landing in the down direction in response to said starting means for that car after such stop, or for causing said mechanism for that car to restart the car in the up direction in response to said starting means for that car after each stop until it brings the car to a stop at a landing above said predetermined landing at which it slows down the car in response to the control in that car for such landing under conditions where, at the time such mechanism is rendered effective to cause such slow down, the up control at such landing is not operated, no control in that car for any landing above such landing is operated and either no operated control at any landing above that car, to which said mechanism for that car is effective to respond, remains to be responded to or, if one or more operated controls at landings above that car remain to be responded to, there is another car in effect above that car and in position where its mechanism can respond to such control or controls, and to start the car from such landing in the down direction in response to the starting means for that car after such stop.

77. An electric elevator system comprising; a plurality of elevator cars; a plurality of landings 70 served by the cars; actuating and stopping mechanism for each car; a plurality of up controls, one at each of said landings, each up control being common to all cars; a plurality of down controls, one at each of said landings, each down 75

control being common to all cars; a plurality of controls, one for each of said landings, in each car; means for causing said mechanism for any car to slow down that car in response to any operated up control or control within that car as the car, during its travel in the up direction, nears the landing for which such operated control is provided, and to slow down that car in response to any operated down control or control within that car as the car, during its travel in the down direction, nears the landing for which such operated control is provided; means for causing said mechanism for any car to slow down that car in response to any operated one of said down controls for landings above a predetermined intermediate one of said landings as the car, during its travel in the up direction, nears the landing at which such down control is located, under conditions where there is no other car in effect above that car, the up control at such landing is not operated, no control in that car for any landing above such landing remains to be responded to; means for preventing the slowing down of more than one car at a landing in response to an operated control at that landing; means for each car for causing said mechanism for that car, during travel of that car in the up direction, to slow down that car as it nears said predetermined intermediate landing under conditions where, at the time said mechanism is rendered effective to do so, the up control at such landing is not operated, no control in that car for any landing above such landing is operated and either no control at any landing above such landing is operated or, if one or more operated controls at landings above such landing remain to be responded to, there is at least one other car in effect above such car in position where its mechanism is effective to respond to such control or controls; means for each car for causing said mechanism for that car, after it has started to slow down the car, to bring the car to a stop at the landing at which it is slowing down; means for each car operable from within that car to cause the operation of said mechanism for that car to start the car; and means for each car for causing said mechanism for that car, once it has started that car in the up direction, to restart it in that direction in response to said starting means for that car after each stop at least until said predetermined intermediate landing is reached and in the event that it brings the car to a stop at said predetermined landing, under conditions where at the time said mechanism is rendered effective to slow down the car as it nears said predetermined landing preparatory to making such stop, the up control at that landing is not operated, no control in that car for any landing above said predetermined landing is operated and either no control at any landing above said predetermined landing is operated or if one or more operated controls at landings above said predetermined landing remain to be responded to, there is another car in effect above that car and in position where its mechanism can respond to such control or controls, to start the car therefrom in the down direction in response to said starting means for that car after such stop, and, in the event said mechanism for that car slows down that car at said predetermined landing in response to the up control at that landing or in the event that at the time said mechanism for that car is rendered effective to

slow down that car as it nears such landing or would be rendered effective to do so if either the up control at such landing or control in that car for such landing were operated, one or more controls in that car for landings above said predetermined landing are operated or in the event that at such time there are one or more operated controls at landings above said predetermined landing to be responded to under conditions either where no other car is in effect above that car or where there are one or more other cars in effect above that car but none of them is in position where its mechanism can respond to one or more of such operated controls, for causing said mechanism for that car to restart that car in the up direction in response to said starting means for that car after each stop until it brings the car to a stop at a landing above said predetermined landing at which it slows down the car in response to the down control at that landing, and to start the car from such landing in the down direction in response to said starting means for that car after such stop, or for causing said mechanism for that car to restart the car in the up direction in response to said starting means for that car after each stop until it brings the car to a stop at a landing above said predetermined landing at which it slows down the car in response to the control in that car for such landing under conditions where, at the time such mechanism is rendered effective to cause such slow down, the up control at such landing is not operated, no control in that car for any landing above such landing is operated and either no operated control at any landing above that car, to which said mechanism for that car is effective to respond, remains to be responded to or, if one or more operated controls at landings above that car remain to be responded to, there is another car in effect above that car and in position where its mechanism can respond to such control or controls, and to start the car from such landing in the down direction in response to the starting means for that car after such stop.

78. An electric elevator system comprising; an elevator car; a plurality of landings served by the car; car actuating and stopping mechanism; a plurality of up controls, one for each of said landings; a plurality of down controls, one for each of said landings; an up signal for each of said landings; a down signal for each of said landings; means responsive to the operation of said up controls for causing the giving of the up signal for each of the landings for which up controls are operated, as the car in its travel in the up direction nears such landing; means responsive to the operation of said down controls for causing the giving of the down signal for each of the landings for which down controls are operated as the car in its travel in the down direction nears such landing; means responsive to the operation of any one of said down controls for causing the giving of the down signal for the landing for which such control is provided as the car in its travel in the up direction nears such landing under conditions where neither the up control for such landing is operated nor any of the controls for landings above are operated; and means for causing said mechanism to slow down and stop the car at the landings for which signals are given.

79. An electric elevator system comprising; an elevator car; a plurality of landings served by the car; car actuating and stopping mechanism; a

79. An electric elevator system comprising; an elevator car; a plurality of landings served by the car; car actuating and stopping mechanism; a 76

- plurality of up controls, one at each of said landings; a plurality of down controls, one at each of said landings; an up signal at each of said landings; a down signal at each of said landings; 5 means responsive to the operation of said up controls for causing the giving of the up signal at each of the landings at which up controls are operated, as the car in its travel in the up direction nears such landing; means responsive to the 10 operation of said down controls for causing the giving of the down signal at each of the landings at which down controls are operated as the car in its travel in the down direction nears such landing; means responsive to the operation of any 15 one of said down controls for causing the giving of the down signal at the landing at which such control is located as the car in its travel in the up direction nears such landing under conditions where neither the up control at such landing is 20 operated nor any of the controls at landings above are operated; and means for causing said mechanism during upward car travel to slow down and stop the car at each of the landings at which up controls are operated, for causing said mechanism during downward car travel to slow down and stop the car at each of the landings at which down controls are operated, for causing said mechanism during upward car travel to slow down and stop the car at a landing at which the down 25 control is operated, under conditions where neither the up control at such landing is operated nor any of the controls at landings above are operated and for causing said mechanism to start the car away from each landing at which a stop 30 has been made in a direction according to the signal given at that landing.
80. An electric elevator system comprising; an elevator car; a plurality of landings served by the car; car actuating and stopping mechanism; 40 a plurality of up controls, one at each of said landings; a plurality of down controls, one at each of said landings; an up signal at each of said landings; a down signal at each of said landings; means responsive to the operation of said up controls for causing the giving of the up signal at each of the landings at which up controls are operated as the car in its travel in the up direction nears such landing; means responsive to the 45 operation of said down controls for causing the giving of the down signal at each of the landings at which down controls are operated as the car in its travel in the down direction nears such landing; means responsive to the operation of said controls within the car for causing the giving of the down signal at each of said landings for which controls within the car are operated as the car in its downward travel nears such landing and for causing the giving of the up signal at each of said landings for which controls within the car are operated as the car in its upward travel nears such landing provided 50 operated controls above the landing for which such control within the car is provided remain to be responded to; means responsive to the operation of any one of said down controls or any one of said controls within the car for causing the giving of the down signal at the landing for which such control is provided as the car in its travel in the up direction nears such landing under conditions where neither the up control at such landing is operated nor any of the controls 55 for landings above are operated; means responsive to the operation of said controls for causing said mechanism to slow down the car as the car, in its upward travel, nears each of the landings for which up controls or controls within the car are operated, and for causing said mechanism to slow down the car as the car, in its downward travel, nears each of the landings for which down controls or controls within the car are operated; means responsive to the operation of any one of said down controls for causing said mechanism to slow down the car as the car in its upward travel nears the landing at which such down control is located under conditions where neither the up control at such landing is operated nor any of the controls for landings above are operated; means for causing said mechanism, after it has initiated slow down of the car, to bring the car to a stop at the landing at which it has slowed down the car; switching means manually operable from within the car to cause operation of said mechanism after each stop to start the car; and means controlled in accordance with the controls that are operated for causing the direction in which the car is started from a landing 65 after each stop to be in accordance with the direction of the signal given at that landing.
